UNITED STATES PATENT OFFICE

2,317,833

TELEPHONE SYSTEM

John H. Voss, Downers Grove, Ill., assignor to
 Associated Electric Laboratories, Inc., Chicago,
 Ill., a corporation of Delaware

Application July 11, 1940, Serial No. 344,870

55 Claims. (Cl. 179—18)

The present invention relates to automatic telephone systems and more particularly to improvements in automatic switching apparatus adapted for use in exchanges serving the subscribers of small isolated communities. In exchanges of this type, varied operating requirements must be met, depending upon the location of the exchanges and the grade and type of service desired. Accordingly, the present invention has for one of its objects the provision of improved automatic switching equipment which lends itself to the ready adaptation of special service facilities and is so arranged that substantially all service facilities normally required in exchanges of this type may be incorporated therein with a minimum of added equipment.

It is another object of the invention to provide in an automatic telephone system of the character described, an improved and exceedingly simple arrangement for enabling certain telephone stations, such, for example, as toll operators' stations, to obtain access to busy lines of the system for the purpose of ascertaining the actual condition of the lines, for the purpose of offering toll calls to the parties conversing over the busy lines, and in order to render the other services normally possible when facilities for establishing connections of this character are provided.

It is another object of the invention to provide in an automatic telephone system of the character described, improved automatic switching apparatus which is so arranged that equipment common to a plurality of switching links is utilized to permit certain subscribers to obtain access to the trunks of one or more specified trunk groups and to prevent subscribers for which a different type of service is provided from obtaining access to the trunks of the specified groups.

It is a further object of the invention to provide in a telephone system of the character described, an improved impulse-responsive, line-selecting switch which is so arranged that, depending upon the numerical value of a first digit transmitted thereto, the switch is conditioned to perform any one of a number of different functions, and in the event any one of a number of other unused digits is dialed into the switch, the dialed digit is absorbed.

It is still another object of the invention to provide an improved impulse-responsive, line-selecting switch of the character described, which is so connected and arranged that when

5 a predetermined first digit of impulses is transmitted thereto over a calling line of one group, the switch is conditioned to establish a communication connection to a busy called line, whereas if the same first digit is transmitted to the switch over a calling line of another predetermined group, the digit is absorbed without producing any effective operation of the control equipment in the switch.

10 It is a still further object of the invention to provide an impulse-responsive, line-selecting switch of the character described, which is so arranged that the first digit of impulses transmitted thereto may also be utilized for trunk group selection, for subscribers line group selection, for the partial selection of the ringing voltage to be applied to a called subscribers line, and for the purpose of determining the type of ringing to be utilized in signaling over a called subscribers line.

15 It is a further object of the invention to provide in an automatic telephone system of the character described, improved automatic switching equipment which is so arranged that a reverting call connection between two substations served by the same line is set up by the directory number dialing method, and which includes provisions for transmitting a special signal to the answering substation when the call is answered at one of the substations served by the calling line.

20 It is another object of the invention to provide an arrangement of the character just described, wherein the special signal is terminated after a predetermined time interval through the provision of apparatus for releasing the switching equipment involved in setting up the connection shortly after the call is answered.

25 It is a further and more specific object of the invention to provide in an automatic telephone system of the character described, an improved line-selecting switch of the all-relay type, wherein the group relays of the switch terminate two different groups of lines and the selective energization of these relays is determined by the positions occupied by one or more group select relays, each having two different operating positions respectively corresponding to the two different groups of lines.

30 It is still another and more specific object of the invention to provide an improved automatic telephone system of the character described wherein the battery reversing relay embodied in one or more of the final numerical switches of the system is arranged selectively to be con-

trolled over an operating circuit which extends through contacts controlled by a preceding non-numerical switch, whereby the relay is only conditioned for energization in response to calls initiated on certain of the lines of the system.

In the illustrated embodiment of the invention there are provided a plurality of finder-connector links of the all-relay type which, in conjunction with equipment common to the links and including a link distributor, operate to set up connections between the lines of the system. Each finder and connector switch of the system includes provisions for terminating two groups of lines each including one hundred lines. In accordance with one feature of the present invention, the operating circuits for the connector group select relays of each link are extended through contacts controlled by a pair of group select relays so that, depending upon the position of the group select relays, the connector group relays are selectively conditioned for energization. More specifically, the connector group select relays include contacts individual to the operating circuits for the group relays, which are so connected and arranged that when the group select relays occupy non-corresponding positions the operating circuits for one group of the connector group relays are prepared and when the group select relays occupy different non-corresponding positions the operating circuits for another group of the connector group relays are prepared. The group select relays are so connected and arranged that when a first digit of impulses is transmitted to the connector portion of the associated link, they will assume positions corresponding to the group of lines designated by the numerical value of the digit.

In accordance with another feature of the invention, the first digit transmitted to the connector portion of a seized link may also be utilized to condition the link to establish a connection to a busy called line accessible thereto. The apparatus provided for this purpose is so arranged that if the predetermined first digit assigned to this function is transmitted to the link over a calling subscribers line it is absorbed, whereas if it is transmitted to the link over a calling central office trunk line, for example, it performs the function assigned thereto. This apparatus is partially controlled by the auxiliary group and unit relays provided in the equipment common to the link, these relays being utilized to identify the character of the calling line and to thus indicate to the connector end of the link whether or not the calling line is entitled to a connection to a busy called line. The auxiliary group and unit relays of the common equipment may also be used for the purpose of determining which of the subscribers lines served by the finder-connector links are to have access to the central office trunks. These relays, by selectively controlling right-of-way circuits individual to the various links, serve to indicate to the connector portion of a seized link whether or not a particular calling line is entitled to free central office trunk service.

In the arrangement illustrated in the drawings and described with particularity hereinafter, reverting call connections between substations served by the same lines are set up by the well-known directory number dialing method. In accordance with another feature of the invention, apparatus is provided which is operative in response to the answering of a call of the revertive

type for transmitting a special signal to the answering substation, thereby to inform the answering party as to the character of the call answered. More specifically, this apparatus comprises a timing device, means operative in response to the answering of a reverting call for initiating operation of the timing device and for transmitting a signal to the answering substation, and means controlled by the timing device for releasing the link occupied with the call, thereby to terminate the signal a predetermined time interval after the call is answered.

In an exchange serving a community of the character mentioned above, wherein lines of several different types, such, for example, as trunk lines, subscribers lines of the metallic and ground return type, and paystation lines may be provided, it is necessary to make provisions for controlling the supervisory or battery reversing relays of the switching links in accordance with the particular character of the line upon which a call is initiated. Thus, in handling a call initiated on a trunk line, battery reversals for supervisory purposes are essential. Again, in handling calls originating on lines of the paystation type, the reversal of current flow over the calling lines is usually required for coin collect purposes. On the other hand, in handling calls initiated on lines of the local-battery, ground return type, it is desirable to prevent the operation of the battery reversing relays in the links occupied with the calls. In accordance with another feature of the present invention, the selective control of the battery reversing relay embodied in each link is achieved in a simple and reliable manner by extending the operating circuit for the relay through contacts controlled only by the finder group relays which terminate the lines with respect to which operation of the battery reversing relay is required.

The novel features believed to be characteristic of the invention are set forth with particularity in the appended claims. The invention, both as to its organization and method of operation, together with further objects and advantages thereof, will best be understood by reference to the specification taken in connection with the accompanying drawings, in which Figs. 1, 2, 4 to 13, inclusive, 14a and 14b, when combined in the manner indicated in Fig. 3 of the drawings, illustrate an automatic telephone system having incorporated therein the features of the invention briefly outlined above.

DESCRIPTION OF THE APPARATUS INCORPORATED IN THE TELEPHONE SYSTEM

Referring to the drawings, the system there illustrated comprises a community automatic exchange at which may be terminated as many as two hundred lines, certain of which have been indicated in the drawings by the directory number designations assigned thereto. More specifically, these lines are divided into two groups of one hundred lines each, each 100-line group including ten sub-groups of ten lines each. Thus, the subscribers line 215, which is of the metallic type and extends to the substation A, is the fifth line of the first subgroup of lines in the first 100-line group, whereas the line 216, which is of the ground return type and serves the common battery substation B, is the sixth line of the same subgroup of lines. Both of these lines are illustrated as being of the single party type. The line 219, on the other hand, which is the ninth line of the first subgroup of lines in the first 100-line group, is illustrated as being of the multi-

party type, serving the substations C and D. This subgroup of lines also includes four trunks of the well-known ring-down type which extend to a private branch exchange of the manual type. The lines of this trunk group are assigned the first four unit numbers, namely the numbers 1 to 4, inclusive, of the subgroup, and are automatically preselected for use through the provision of a trunk preselect relay group 1480.

The exchange also terminates a group of ten central office trunks, one of which is indicated at 30 as extending to the central office 5. This trunk terminates in the community exchange in a two-way repeater 6 which is connected by a link line to the set of contacts having the directory number 205. In order to preselect idle ones of the central office trunks as these trunks successively become busy, a second group 1485 of trunk preselect relays is provided in association therewith. The two trunk preselect relay groups 1480 and 1485 are identical in arrangement and are wired exactly in accordance with the wiring of trunk preselect relays disclosed in Figs. 11 and 13 of applicant's copending application Serial No. 189,121, filed February 7, 1938, and assigned to the same assignee as the present invention. For switching purposes, each subgroup of ten lines terminating at the finder ends of the links is further subdivided into two smaller subgroups of five lines each in accordance with the units designations of the lines included therein. Thus, the lines having directory numbers ending in 1, 2, 3, 4 and 5 comprise one smaller subgroup of lines in each ten-line subgroup, and the lines having directory numbers ending in the units designations 6, 7, 8, 9 and 0 comprise the second smaller subgroup of lines in each ten-line subgroup.

As indicated above, in order to set up connections between the various lines of the system, a plurality of finder-connector links of the all-relay type are provided. The details of one of the links are illustrated in Figs. 2, 7, 8, 9, 10, 11, 12, 13, 14a and 14b of the drawings. The other links included in the exchange are identical in arrangement with the link illustrated. These links are arranged to be controlled by common equipment which comprises a link distributor, also shown in Fig. 7 of the drawings, a group of distributor control relays illustrated in Fig. 6 of the drawings, and a plurality of guard or auxiliary relays which are illustrated in Fig. 5 of the drawings. Briefly described, the finder portion of the illustrated link comprises twenty group relays, two of which are indicated at R200 and R210, which respectively correspond to the different ten-line subgroups. These relays are preferably of the character disclosed and claimed in Patent No. 2,135,832, granted November 11, 1938, to Herbert F. Obergfell, and only two thereof have been shown in the interests of simplifying the disclosure. The finder portion of the link also comprises five unit relays, each of which corresponds to two lines in each of the ten-line subgroups. Thus, the relay R220, for example, is operative in conjunction with any one of the group relays to select the lines having the unit designations of 5 and 0 in each of the twenty different subgroups of lines. It will be understood that with one of the group relays and any one of the unit relays operated, two lines are selected from the plurality of lines to which the finder switch has access. In order to select one of the two lines thus selected by the group and unit relays, there is provided a subgroup relay R270 which functions to switch

the conductors of the link line 230 between the two link lines 228 and 229. For the purpose of associating the relays of the finder switch with the common equipment illustrated in Figs. 5, 6 and 7 of the drawings, a pair of connect relays R280 and R290 are provided.

The connector portion of the link is similar to the finder switch just described in that twenty group relays, including the two relays R1400 and R1410, and each including contacts terminating ten lines of the system, are provided. These relays are also preferably of the construction disclosed and claimed in the above-cited patent to Obergfell. The connector portion of the link further comprises ten unit relays which individually correspond to different lines of each of the ten-line subgroups. Only three of these relays, R1450, R1460 and R1470, have been illustrated in the drawings, these relays respectively corresponding to the first, ninth and tenth lines of each ten-line subgroup. As indicated previously, the lines terminating at the connector switches of the system are divided into two groups of one hundred lines each. The connector group relays are likewise divided into two groups, each comprising ten relays. For the purpose of selectively controlling the operating circuits of these two groups of connector group relays, two group select relays R1350 and R1360 are provided in the link illustrated.

In order selectively to control the group select relays, the connector group relays, and the connector unit relays to cause the proper relay operations for the selection of a desired called line and the selective signaling of the substations served by called ones of the multi-party lines terminating at the exchange, an impulse-counting chain is provided. This counting chain is illustrated in Figs. 7, 12, and 13 of the drawings, as comprising ten counting relays R1240, R1250, R1260, R1270, R1280, R1290, R1300, R1310, R1320 and R1330, and three associated common control relays R750, R760 and R770.

The control equipment of the link comprises a switching-through relay R800 which is operative to by-pass the repeating coil 834 in handling central office trunk calls routed through the link, a battery reversing relay R810, a pair of line relays R820 and R825, and an impulse-correcting network which includes the two control relays R830 and R840, a slow-acting control relay R850, and a hold relay R860. In order to control the release of the counting chain illustrated in Figs. 7, 12 and 13 of the drawings, there is provided a counting chain release relay R870.

The control equipment embodied in the connector portion of the link also includes a pair of link release relays R900 and R910, a back-bridge relay R920, a control relay R930 which is connected to operate as a slave to the back-bridge relay R920, a pair of reverting-call control relays R940 and R970, a slow-to-release line discharge control relay R950, a ring pickup relay R960, and a slow-to-operate ring cut-off relay R980 which may be used alternatively with the lamp 928 in the ringing circuit of the link, depending upon the type of ring cut-off operation desired.

As illustrated in Fig. 10 of the drawings, the control apparatus of the link further comprises a ringing transfer relay R1000 which is utilized to determine the side of a selected line over which ringing current is to be projected, a ringing control relay R1010, a right-of-way control relay R1020, a line-switching relay R1030, a bus test relay R1040, another line-switching relay R1050,

a slow-to-operate idle test relay R1070, and a slow-to-operate relay R1080 which is used in conjunction with the relay R980 to effect instantaneous ring cut-off when this feature is incorporated in the link circuit. The control equipment illustrated in Fig. 11 of the drawings comprises a verification relay R1140 which is utilized in the establishment of communication connections to busy called lines terminating at the connector end of the link. This equipment also includes three impulse-controlled relays R1100, R1150 and R1160, the last two of which are of the slow-to-release type, a first digit transfer relay R1120, a second digit transfer relay R1110, and a third digit transfer relay R1130.

For the purpose of selecting the type of ringing to be utilized in signaling over a called subscribers line of the multiparty type, of controlling the group select relays R1350 and R1360, and of partially selecting the code of the ringing current to be used in signaling called substations served by the multiparty lines terminating at the exchange, all in response to the impulses comprising a first digit transmitted to the connector portion of the link, two relays R1200 and R1210 are provided which are arranged selectively to be controlled by the relays of the impulse-counting chain during the response of this chain to the impulses of a first digit transmitted to the link. The arrangement referred to above, whereby certain of the subscribers lines terminating at the finder-connector links are permitted to have access to the central office trunks while other subscribers lines are prevented from obtaining access to these trunks, includes a restricted service relay R1340 which is controlled in the manner pointed out hereinafter by the relays of the equipment common to the links.

As pointed out above, the equipment common to the several links comprises a plurality of guard or auxiliary relays which individually correspond to the relays embodied in each of the finder switches. More specifically, this equipment comprises twenty auxiliary group relays, three of which are indicated at R500, R510 and R590, which individually correspond to the twenty group relays of the finder switches. Thus, the two relays R500 and R510 are arranged individually to control the finder group relays R200 and R210 of the link illustrated. The seventeen group relays which are not shown are indicated by the multiple and chain conductors extending between the contacts of the three illustrated auxiliary group relays R500, R510 and R590. Five auxiliary unit relays including the two relays R550 and R560 are also provided, which relays individually correspond to the five unit relays of the various finder switches. The auxiliary relay equipment further comprises a pair of relays R520 and R530 which function to control the subgroup relays embodied in the finder switches.

The link distributor or allotter equipment is also of the all-relay type, a group of link distributor relays R700, R710, R730, etc., being provided which individually correspond to the links and operate in a cyclic manner to assign the respective associated links for use in a predetermined order. These link distributor relays are arranged to be controlled by a group of control relays which are illustrated in Fig. 6 of the drawings as comprising a slow-acting relay R810 for controlling the auxiliary relay start circuits and the call metering device 614, a group of slow-to-release link transfer and distributor control re-

lays R820, R830, R840 and R850, a slow-acting distributor reset relay R860, and an all-links-busy relay R870 which is operated only when an all-busy condition of the respective associated links prevails. The relay R870 is also arranged to control an all-busy metering device 632 which functions to register those instances when calls fail due to an all-busy condition of the links. The common equipment further includes a control relay R600 which is provided for the purpose of controlling the trunk call identification circuits referred to above and described with particularity hereinafter in accordance with the operation of the associated auxiliary relays.

For the purpose of initiating the operation of the common equipment just described, each line of the system is terminated in the usual line circuit which conventionally comprises line, cut-off and lockout relays. Thus, the line 215 which extends to the substation A terminates at the exchange in a line circuit 10, which includes a line relay R100, a cut-off relay R110 and a line lockout relay R105. Similarly, the line 216 which extends to the substation B is terminated at the exchange in a line circuit 15 which includes the line, cut-off and lockout relays R120, R130 and R125, respectively. The line circuit 25 which is diagrammatically illustrated as terminating the multiparty subscribers line 219, is identical in arrangement with the two line circuits 10 and 15. It will also be observed that the line circuit 20 which is provided in association with the two-way repeater 6 and includes the line, cut-off and lockout relays R150, R160 and R155, respectively, is substantially identical in arrangement with the line circuits 10 and 15.

The equipment common to the links also includes the usual ringing apparatus, timing apparatus and tone-generating apparatus. More specifically, the timing apparatus includes a timing device 720a, preferably of the all-relay type, which is provided for the purpose of controlling the release of the links after reverting calls routed by way thereof have been successfully completed. A second timing device 720b, also preferably of the all-relay type, is provided for the purpose of forcibly releasing any link held operated over a faulty line or a line having a permanent calling condition thereon, and of controlling the link release relays of the links for the purpose of timing local call connections established by way of the links. These two timing devices may be of any well-known construction and arrangement, the operation of which is well understood in the art and, accordingly, the details thereof have not been illustrated. The ringing apparatus provided in association with the links includes a ringing current generator, preferably of the pole changer type, and a ringing code interrupter 1395. This interrupter is so arranged that it provides on its associated ten interrupter leads ten sets of differently coded ringing control pulses so that ten fundamental ringing codes are produced. The ringing interrupter also includes provisions for preceding each of the ten fundamental codes by a short ringing code pulse so that ten additional codes are effectively produced. This is accomplished by providing an arrangement for selectively controlling the application of the pickup relay operating potential to the two pickup leads C1215 and C1227. More specifically, the arrangement is such that if one of these pickup leads is utilized in the control of the ring pickup relay of an operated link, the preliminary short rings are

omitted from the ringing code, whereas if the other pickup lead is utilized as a part of the operating circuit for the ring pickup relay in the operated link, the short or preliminary ringing interval is included in each of the ten ringing codes. Since this type of code ringing and the arrangement of the ringing interrupter whereby it may be achieved are well known in the art, the details of the ringing equipment have not been illustrated in detail.

The tone-generating equipment is illustrated in Fig. 4 of the drawings as comprising a dial tone generator 435, a busy tone generator 446, and a reverting-call tone generator 475. The dial and busy tone generators are of identical arrangement and, accordingly, only the details of the busy tone generator have been illustrated in the drawings. Briefly described, this generator comprises a start relay R409 which is common to the tone-generating equipment, a buzzer 436, a slow-to-operate start relay R410, a control relay R420 and a transformer 432. The reverting-call tone generator 475 includes a pole changing relay R480 which is arranged to be controlled by three slow-to-operate, cyclically operating timing relays R450, R460 and R470. These relays are also arranged to control the application of the busy tone potential, generated through operation of the tone generator 440, to the busy tone current lead C1088.

SEIZURE OF THE LINK AND OPERATION OF THE FINDER SWITCH

Referring now more particularly to the operation of the apparatus, a call initiated at the substation A served by the common battery line 215 may be considered by way of example. When the party initiating the call at the substation A removes the receiver provided at this substation from its associated switchhook or cradle, a loop circuit is established which includes the exchange battery and the winding of the line relay R100. This circuit extends from ground by way of the upper winding of R100, the contacts 111, the conductor 215b, the direct current bridge across the conductors of the line 215 at the calling substation, the conductor 215a, the contacts 112, and the lower winding of R100 to battery. In operating, the relay R100 prepares, at its contacts 101, a circuit for energizing the auxiliary unit relay R560 which corresponds to the line 215. At its contacts 103, the relay R100 connects the private conductor 215d to ground, thereby to mark the line 215 as busy in the connector switches having access thereto. At its contacts 102, the relay R100 completes a circuit for energizing the auxiliary group relay R510 which corresponds to the first group of ten lines. This circuit extends from ground by way of the contacts 102 and 101, the start conductor C145, the winding of R510, the contacts 513, C578, the contacts 612, C580, the contacts 594, 514 and 505, the chain-connected contacts controlled by the other auxiliary group relays, and the resistor 522 to battery. When energized over this circuit the relay R510 completes, at its X contacts 513', an obvious holding circuit for itself, and opens, at its contacts 514, a point in the common portion of the operating circuits for the ten auxiliary group relays. At its contacts 515, 516, 517, 518 and 519, the relay R510, in operating, prepares the operating circuits for the five auxiliary unit relays. In the present case, however, only the auxiliary unit relay R560 is operated, the circuit for energizing this relay extending from ground by way

of the contacts 534, the winding of R520, C141, the contacts 108 and 101, C147, the contacts 516, the winding of R560, the contacts 566, C571, the contacts 611, C576, the contacts 564 and 554, 5 similar chain-connected contacts of the other auxiliary unit relays, and the resistor 568 to battery. At its contacts 511, the relay R510 prepares a circuit for energizing the group relay of the assigned link. At its contacts 512, the 10 relay R510 prepares a circuit for energizing the right-of-way control relay R1340, assuming that the lines of the ten-line group including the line 215 are provided with unrestricted trunk service such that the "Y" wiring illustrated in Fig. 5 15 of the drawings is used.

When energized in series with the relay R560 over the above-traced circuit, the slow-to-release relay R520, at its contacts 521, opens a point in the operating circuit for the relay R530, thereby 20 to prevent operation of the latter relay until the call in progress is extended to an assigned link. The auxiliary unit relay R560 also operates when the above-traced circuit is completed, and upon operating, completes, at its X contacts 565, an obvious locking circuit for itself. After this circuit is completed, the relay R560, at its contacts 564, opens a point in the common portion of the operating circuits for all of the auxiliary unit relays. At its contacts 567, the relay R560 prepares a circuit for energizing the unit relay of 25 the assigned link which corresponds to the units designation 5 of the calling line 215. At its contacts 562 and 563, the relay R560 prepares two paths for impressing ground potential upon the trunk call identification lead C681. At its contacts 561, the relay R550 completes a circuit for energizing the connect relays of the link previously selected for use by the link distributor relays. Assuming that all of the links are idle, all 30 of the link distributor relays are operated so that the link illustrated is assigned to the use of the calling line 215. In such case the relay R560, upon operating, completes a circuit for energizing the two connect relays R280 and R290 in parallel, this circuit extending from ground by 35 way of the contacts 561, the common start lead C573, the contacts 702, C234, and the windings of the relays R280 and R290 in parallel to battery. The relay R280, in operating, completes, 40 at its contacts 297, a circuit extending by way of the common guard lead C682 for energizing the slow-acting relay R610. The relay R610 now operates to complete, at its contacts 613, a circuit extending from ground at the contacts 674 for 45 energizing the call metering device 614, whereby the call is registered. At its contacts 611, the relay R610 opens another point in the common portion of the operating circuits for all of the auxiliary unit relays. At its contacts 612, the relay R610 opens another point in the common 50 portion of the operating circuits for all of the auxiliary group relays. Thus, the auxiliary relays are prevented from responding to another call until the finder switch illustrated has completed its operation to seize the calling line 215. The relay R280, in operating, prepares, at the 55 contacts controlled thereby, the operating circuits for the twenty group relays embodied in the finder switch illustrated. In the case under consideration, only the relay R210, which terminates the first group of ten lines, is energized in response to operation of the relay R280, the operating circuits for the other nineteen group relays being held open at the restored contacts 60 of the other auxiliary group relays. More spe- 70

cifically, the circuit for energizing the relay R210 extends from ground by way of the contacts 511, C572, the contacts 281, and the winding of R210 to battery. This relay, in operating, prepares, at its contacts 211 to 213, inclusive, connections between the conductors of the line 215 and the conductors of the link line 228, and, at its contacts 241, prepares a holding circuit for itself. At the remaining contacts controlled by this group relay, connections are prepared between the other nine lines terminating at these contacts and the two link lines 228 and 229.

The relay R290, upon operating, prepares the operating circuits for the five unit relays of the finder switch. In the case under consideration only the operating circuit for the relay R220 is completed, this circuit extending from ground by way of the contacts 532 and 567, C583, the contacts 295, and the winding of R220 to battery. When energized over this circuit the relay R220 operates to prepare a locking circuit for itself at its contacts 221. At its contacts 221, 222 and 223, the relay R220 connects the conductors of the calling line 215 to the conductors of the link line 228. At its contacts 224, 225 and 226, the relay R220 connects the conductors of the line 210 to the other link line 229. At its contacts 293, the relay R290 prepares a circuit for energizing the subgroup relay R270. In the present case wherein the line 215 is in the first subgroup of the first group of lines, the subgroup relay R530 of the common equipment is not operated and hence the operating circuit for the subgroup relay R270 is held open at the contacts 603 of the restored relay R600. Accordingly, the relay R270 remains in its restored position for the duration of the call under consideration. At its contacts 296, the relay R290 prepares alternative operating circuits for the five unit relays of the finder switch, these alternative circuits being held open at the restored contacts 278 of the subgroup relay R270. At its contacts 292, the relay R290 completes a multiple holding circuit for the link distributor relay R700 individual to the link illustrated, this multiple circuit extending from ground by way of the resistor 708, the contacts 706, C232, the contacts 292, C231, and the winding of R700 to battery. At its contacts 298, the relay R290 prepares a circuit including the trunk call identification lead C681 for energizing the right-of-way control relay R1020.

The relay R290, in operating, also completes a circuit for energizing the two line relays R820 and R825, this circuit extending from ground by way of the winding of R825, the winding 835, the contacts 802 and 811, the conductor 230a, the contacts 291, the resistor 283, the conductor 230b, the contacts 813 and 804, the winding 836 and the winding of R820 to battery. When energized over this circuit the relay R820 operates to complete, at its contacts 821, a circuit for energizing the pulsing relay R830, this circuit extending from ground by way of the contacts 918', C890, the contacts 841 and 821, and the winding of R830 to battery.

The relay R825 also operates when energized in series with the relay R820, and, upon operating, prepares, at its contacts 826, the operating circuit for the battery reversing relay R800.

The relay R830, in operating, completes, at its contacts 832, an obvious circuit for energizing the relay R840. At its contacts 834, the relay R830 opens a point in the pulsing circuit traced hereinafter, over which the counting relays illustrated in Figs. 12 and 13 are successively ener-

gized during the transmission of impulses to the connector portion of the link. At its contacts 833, the relay R830 completes a locking circuit for itself, this locking circuit extending from ground by way of the contacts 833, the resistor 823, the contacts 821 and the winding of R830 to battery. At its contacts 831, the relay R830 completes a circuit for energizing the slow-acting relay R850, this circuit extending from ground by way of the contacts 918', C890, the contacts 831 and the winding of R850 to battery. Shortly after this circuit is completed, the relay R840 operates and, in so doing, closes its contacts 842 to shunt the operated contacts 831 and thus complete an obvious multiple circuit for energizing the relay R850. At its contacts 841, the relay R840 opens a point in the above-traced operating circuit for the pulsing relay R830. The relay R850, in operating, prepares, at its contacts 851 a priming circuit for the line relay R820. At its contacts 852, the relay R850 completes an obvious circuit for energizing the hold relay R860. At its contacts 853, the relay R850 opens a point in the circuit traced hereinafter for energizing the reverting-call relay R940. At its contacts 854, the relay R850 completes a path for impressing ground potential upon the tone apparatus start conductor C895, thereby to energize the tone start relay R400. More specifically, this relay is energized over a circuit which extends from ground by way of the contacts 1037, C894, the contacts 854, the tone start lead C895 and the winding of R400 to battery. When energized over this circuit, the relay R400 operates to initiate the operation of the three associated sets of tone apparatus illustrated in Fig. 4 of the drawings. The manner in which this is accomplished is explained in detail hereinafter.

The hold relay R860, in operating, prepares, at its contacts 866, locking and operating circuits for the relays R810 and R1070. At its contacts 869, the relay R860 completes an obvious path for impressing ground potential upon the release conductor C893, thereby to prepare operating and locking circuits, traced hereinafter, for certain of the other control relays embodied in the link. At its contacts 867, the relay R860 completes a path including the contacts 818 for impressing ground potential upon the timer start lead C889, thereby to initiate certain of the timing devices embodied in the timing equipment 720. At its contacts 868, the relay R860 prepares a circuit traced hereinafter for energizing the link release relay R900. At its contacts 864, the relay R860 prepares the above-mentioned circuit for transmitting impulses to the relays of the counting chain illustrated in Figs. 12 and 13 of the drawings. At its contacts 863, the relay R860 opens one of the multiple paths included in the normally completed holding circuit for the link distributor relay R700, this circuit now being closed at the engaged contacts 292 of the operated connect relay R290. At its contacts 865, the relay R860 completes the prepared holding circuits for the group and unit relays R210 and R220, respectively. More specifically, the holding circuit for the units relay R220 extends from ground by way of the contacts 948, C882, the contacts 865, C235, the contacts 227 and the winding of R220 to battery. The holding circuit for the group relay R210 extends by way of the grounded lead C235, the contacts 241 and the winding of R210 to battery. At its contacts 861, the relay R860 completes a path for transmitting dial tone sig-

nal current over the established connection extending to the calling substation, thereby to inform the calling party that the dialing operation may be started. This path may be traced as extending from the ungrounded terminal of the dial tone generator 435 by way of C1168, the contacts 1121, 1111 and 1141, C845, the condenser 843, the contacts 861, 804 and 813, the conductor 230b and the contacts 273, 222 and 212 to the negative side of the calling line 215. From this point the dial tone current is conducted through the windings of the receiver provided at the calling substation A and back over the positive side of the line 215 to the grounded terminal of the dial tone generator 435.

At its contacts 862, the hold relay R860 completes a path for impressing ground potential upon the private conductor 215c of the calling line 215, this path extending from ground by way of the contacts 852 and 862, C233, and the contacts 275, 223 and 213 to the private conductor 215c. When this private conductor is grounded, the line 215 is marked as busy in the relay contacts of the various connector switches and the cut-off relay R110 is energized in series with the slow-acting lockout relay R105. When energized over this circuit, the two relays R105 and R110 both operate. In operating, the relay R110 disconnects the winding terminals of the line relay R100 from the conductors of the line 215. Thus, the line relay R100 is deenergized and the calling loop circuit is cleared of the impedance represented by the windings of this relay. When thus deenergized, the relay R100 restores to open, at its contacts 102 and 101, the established locking circuits for the operated auxiliary group and unit relays R510 and R560, respectively. At its contacts 101, the relay R100, in releasing, also deenergizes the slow-to-release relay R520. At its contacts 103, the relay R100 opens the initially completed path for impressing ground potential upon the private conductor 215d of the calling line 215. At its contacts 103', the relay R100 connects the private conductor 215d to the grounded control conductor 215c, thereby to maintain guarding ground potential upon the private conductor.

The slow-acting lockout relay R105, upon operating, opens, at its contacts 108, a further point in the previously traced circuit for energizing the relay R520 in series with the auxiliary unit relay R560. At its contacts 107, the relay R105 opens another point in the previously traced operating and locking circuits for the auxiliary group relay R210. At its contacts 106, the relay R105 prepares a locking circuit for itself. The relay R510, in releasing, opens, at its contacts 511, the above-traced operating circuit for the relay R210. At its contacts 512, the relay R510 opens the prepared operating circuit for the right-of-way control relay R1340. At its contacts 513 and 514, the relay R510 prepares the operating circuits for the twenty auxiliary group relays. At its contacts 513', the relay R510 opens a further point in its own locking circuit. At its contacts 516, the relay R510 opens a further point in the above-traced circuit for energizing the relays R520 and R560 in series. At the remaining contacts controlled by the relay R510, the prepared operating circuits for the other four auxiliary unit relays of the common equipment are opened. The relay R520, in releasing, reprepares the operating circuit for the subgroup relay R530. When the auxiliary unit relay R560 restores, it opens, at its

5 contacts 567, the previously traced operating circuit for the unit relay R220. At its contacts 565, the relay R560 opens a further point in its own locking circuit. At its contacts 564 and 566, the relay R560 reprepares the operating circuits for the five auxiliary unit relays. At its contacts 562 and 563, the relay R560 opens the prepared paths for impressing ground potential upon the trunk call identification lead C681. At its contacts 561, the relay R560 interrupts the above-traced circuit for energizing the two connect relays R280 and R290 in parallel. The two connect relays R280 and R290 now restore.

The relay R280, in releasing, opens the prepared operating circuit for the twenty group relays of the finder switch. The relay R290, in restoring, opens the prepared operating circuits for the five unit relays and the subgroup relay R210 of the finder switch. At its contacts 288, the relay R290 opens a point in the prepared operating circuit for the right-of-way control relay R1020. At its contacts 299, the relay R290 opens a point in the prepared operating circuit for the right-of-way relay R1340. At its contacts 297, the relay R290 opens the above-traced operating circuit for the relay R610, causing the latter relay to release. At its contacts 292, the relay R290 opens the above-traced multiple holding circuit for the link distributor relay R700. The relay R700 now restores, and at its contacts 702, disconnects the common start lead C573 from the start lead C234 extending to the link illustrated. At its contacts 701, the relay R700 connects the common start lead C573 through the contacts 712 of the second link distributor relay R710 to the start lead individual to the second link, assuming the second link is idle. At its contacts 706, the relay R700 opens a further point in its locking circuit as traced above. At its contacts 707, the relay R700 prepares an operating circuit for itself. At its contacts 705, the relay R700 prepares a point in the chain circuit for energizing the slow-acting reset relay R660. At its contacts 703 and 704, the relay R700 opens the prepared path for short-circuiting its own winding, and prepares a path extending through the contacts 713 for short-circuiting the winding of the second link distributor relay R710. Following the operations just described, the link illustrated is identified as busy in the link distributor relay group, and the relays of this group are in the position required to assign the second link to the use of the next incoming call. Shortly following the release of the relay R700, the slow-acting relay R610 restores to open, at its contacts 613, the circuit for energizing the metering device 614. At its contacts 611 and 612, the relay R610 reprepares the operating circuits for the auxiliary unit and auxiliary group relays, whereby these relays are conditioned to respond to another call. It will be noted that the operating circuits for these auxiliary relays are held open until all of the other relay operations required incident to the handling of the call in progress are completed, thus positively eliminating the possibility of two calling lines obtaining access to the same link.

As indicated previously, the operation of the common equipment and the finder portion of an assigned link to seize a calling line is different, depending upon the unit designation of the calling line. The preceding explanation is predicated upon the operation of the apparatus to select a calling line included in the first sub-group of lines of a particular ten-line group.

Briefly to consider the operation of the apparatus when a call is initiated upon a line, such, for example, as local battery, ground return line 216 included in the second subgroup of the first ten-line group, it is pointed out that if the line relay R120 individual to this line operates, a circuit is completed for energizing the subgroup relay R530 in series with the auxiliary unit relay R550 corresponding to the line 216. The previously traced operating circuit for the group relay R510 is also completed, at the contacts 122, when the line relay R120 operates. More specifically, the series operating circuit for the two relays R530 and R550 extends from ground by way of the lower winding of R530, the contacts 521, C142, the contacts 128 and 121, C148, the contacts 515, the winding of R550, the contacts 556, C577, the contacts 611, C576, the contacts 564 and 554, and corresponding chain-connected contacts of the other three auxiliary unit relays and the resistor 568 to battery. When energized over this circuit, the relay R550 is locked up in series with the lower winding of the relay R530 over a circuit including the X contacts 555. At its contacts 554, the relay R550 opens a point in the common portion of the operating circuits for the five auxiliary unit relays. At its contacts 552 and 553, the relay R550 prepares two paths for impressing ground potential upon the trunk call identification lead C681. At its contacts 557, the relay R560 prepares a circuit for energizing the unit relay R260 of the first link, assuming that the first link has been selected for use by the link distributor relays. At its contacts 551, the relay R550 completes the previously traced circuit for energizing the two connect relays R280 and R290 in parallel. The relay R280, in operating, completes the previously traced operating circuit for the group relay R210. The relay R290, in operating, prepares the operating circuit for the unit and subgroup relays of the finder switch. The relay R290 also performs the other functions described above with reference to the call initiated on the line 215. The subgroup relay R530, in operating, opens, at its contacts 532, the previously traced operating circuit for the selected unit relay of the finder switch, and completes, at its contacts 533, an obvious circuit for energizing its upper winding in parallel with its lower winding and in series with the winding of the auxiliary unit relay R550. At its contacts 534, the relay R530 opens a point in the previously traced operating circuit for the slow-to-release relay R520. At its contacts 531, the relay R530 completes a circuit extending by way of C581 for energizing the relay R600. The relay R600, in operating, opens, at its contacts 601, one of the prepared paths for impressing ground potential upon the trunk call identification lead C681, and, at its contacts 602, prepares another of these paths. At its contacts 603, the relay R600 completes the prepared operating circuit for the subgroup relay R270 of the assigned link, this circuit extending from ground by way of the contacts 603, C683, the contacts 293 and the winding of R270 to battery. When energized over this circuit the relay R270 operates and prepares a locking circuit for itself at its contacts 277. At its contacts 271 to 276, inclusive, the relay R270 disconnects the conductors of the link line 230 from the conductors of the link line 228, and connects the conductors of the first-mentioned link line to the conductors of the link line 229 in preparation for the selection of a line in the second subgroup of the selected group of ten lines.

At its contacts 278, the relay R270 completes the prepared alternative operating circuit for the unit relay R260, this circuit extending from ground by way of the contacts 278 and 298, C532, the contacts 557, C584, the contacts 294, and the winding of R260 to battery. When energized over this circuit, the relay R260 operates and prepares a locking circuit for itself at its contacts 267. At its contacts 264, 265 and 266, the relay R260 connects the conductors 216a, 216b and 216c of the calling line 216 through to the conductors 230a, 230b and C233 of the link line 230. At its contacts 261 to 263, inclusive, the relay R260 prepares a connection from the line 211 to the conductors of the link line 230, but since the subgroup relay R270 is operated, this connection is held open at the contacts 271, 273 and 275. Thus, it will be apparent that, depending upon the position of the subgroup relay R270, either of two lines may be selected through operation of any one of the five unit relays embodied in the finder switch.

When the connect relay R290 operates, it also functions to complete the operating circuit for the line relay R820, thereby to cause the sequential operation of the relays R830, R840, R850 and R860 in the manner pointed out above. In this case, since the calling line 216 is of the ground return type, the conductor 216a is connected to ground. Accordingly the relay R825 is short-circuited and does not operate when the calling loop circuit is extended to the connector portion of the link in the manner just explained. The relay R860, in operating, completes the prepared holding circuits for the group relay R210, the unit relay R260, and the subgroup relay R270, these holding circuits commonly extending by way of the grounded hold conductor C235, and branching through the contacts 247, 267 and 271, respectively, to the windings of the respective enumerated relays. The relay R860, in operating, also completes a path extending by way of the contacts 852 and 862, C233, and the contacts 276, 266 and 246 for impressing ground potential upon the private conductor 216c of the calling line 216. Thus, the calling line is marked as busy in the contacts of the connector group relays, and the cut-off and lockout relays R130 and R125 are caused to operate. In operating, the relay R130 disconnects the winding of the line relay R120 from the conductor of the line 216. When the relay R120 releases, it functions to initiate the release of the common equipment in the manner explained above, it being pointed out that the series holding circuit for the two relays R530 and R550 is interrupted at the contacts 121, when the line relay R120 restores. The relay R530, upon restoring, reprepares, at its contacts 532, certain of the operating circuits for the finder unit relays, and at its contacts 534, reprepares the operating circuit for the slow-to-release relay R520. At its contacts 531, the relay R530 interrupts the above-traced operating circuit for the relay R600. The relay R600, in releasing, opens the prepared path for impressing ground potential upon the trunk call identification lead C681, and, at its contacts 603, opens a point in the common portion of the operating circuits for the subgroup relays of the link finder switches.

In the arrangement illustrated, the tenth group of ten lines in the first larger group of one hundred lines may consist exclusively of trunks, these trunks being terminated at the line contacts

of the group relay R200 in the finder switch illustrated and at corresponding contacts of the corresponding relays in the other finder switches. Alternatively this ten-line group may comprise a mixture of trunks and substation lines, in which case the trunks are terminated at the first sets of contacts of the various finder and connector group relays, namely, those contacts having the lowest assigned directory numbers. For example, the first five lines, namely, those designated by the directory numbers 201 to 205, inclusive, may be trunks, and the remaining five lines, namely, those designated by the directory numbers 206 to 200, inclusive, may be substation lines. If additional trunk capacity is required or the trunk groups must be separated for directory number purposes, the group relays of the finder and connector switches which correspond to the 290 and 280 series of directory numbers may be used to terminate the additional trunks. The purpose achieved by terminating the trunks in this manner is to permit selective control of the trunk group relay R540. This relay is provided in order to control the trunk call identification relay, such, for example, as the relay R1020, of an assigned link. More specifically, this relay is wired for energization in response to the initiation of calls on trunks which are to have the busy line verification facilities described with particularity hereinafter and, in combination with the auxiliary unit relays, serves selectively to control the application of ground potential to the trunk call verification lead C681 in accordance with the character of particular calling lines.

In certain installations the switching equipment illustrated in the drawings may be required to handle calls initiated on substation lines of the paystation type. In such case the paystation lines are terminated in the unused contacts of the finder and connector group relays to which the trunks of the system extend. If the paystations associated with these lines are of the well-known prepay type a reversal of the polarity of the voltage impressed upon a calling one of the lines is required at the time the call is answered, in order to cause the collection of the deposited coin or coins. This is accomplished in the link illustrated by providing a circuit, including the "L" wiring illustrated in Fig. 2 of the drawings and controlled by the group relay or relays terminating the paystation lines, for energizing the battery reversing relay R800. As contrasted with the paystation lines, it is undesirable to reverse battery over a line serving substations of the local battery type. Accordingly, the local battery lines are not terminated in the contacts of the group relays which are utilized to terminate the paystation lines of the system. Local battery lines may, however, be terminated in the unused contacts of the group relays which terminate the trunks of the system. If all of the substations served by the lines terminating at the switching equipment illustrated are of the common battery type, the "N" wiring illustrated in Fig. 2 of the drawings is used. With this wiring arrangement, the completion of the circuit for energizing the battery reversing relay R800 is rendered independent of the switching action of the various group relays of the finder switch.

The mode of operation of the common equipment and the finder portion of an assigned link in handling a call initiated on one of the central office trunks is substantially similar to the operation of the common equipment and the finder portion of the link illustrated, as described above

with reference to calls initiated on the subscribers lines 215 and 218. Thus, if the central office trunk 30 is seized from an operator's position in the central office 5, the line and hold relays conventionally embodied in the two-way repeater 6 operate to set up a local loop circuit which includes the two windings of the line relay R150. Substantially simultaneously with this operation, ground potential is impressed upon the private conductor 215d to mark the trunk 30 as busy in the relay contacts of the connector switches having access thereto. When this conductor is connected to ground, the two relays R155 and R160 are energized in series over a circuit including this conductor and the contacts 153'. This circuit is completed substantially concurrently with the energization of the line relay R150. The latter relay is, however, extremely fast to operate and, accordingly, opens its contacts 153' to interrupt the circuit for energizing the two relays R155 and R160 before either of these relays can operate. At its contacts 152, the line relay R150 completes an obvious alternative path for impressing ground potential upon the conductor 205d. At its contacts 152, the relay R150 completes a circuit including the contacts 157 and C146 for energizing the auxiliary group relay R500 in series with the resistor 522. At its contacts 151, the relay R150 prepares a circuit including the contacts 158 and the two conductors C141 and C144 for energizing the auxiliary unit relay R560 in series with the slow-to-release relay R520. The relay R500, in operating, completes a locking circuit for itself; opens the operating circuits for the nineteen other auxiliary group relays; completes, at its contacts 506, the prepared circuit for energizing the relays R520 and R560 in series; and prepares, at its contacts 505', 507, 508 and 509, the operating circuits for the other four auxiliary unit relays. At its contacts 502, the relay R500 completes an obvious circuit for energizing the trunk group relay R540.

As indicated above, the relay R540 is only energized when calls are initiated on the lines of the line groups which include trunks. This relay, in operating, prepares ten different paths for impressing ground potential upon the trunk call identification lead C681. These paths are selectively controlled by the five auxiliary unit relays and the subgroup relay R600 of the common equipment. By virtue of this arrangement, if any ten-line group is a mixed line group consisting of both trunks and subscribers lines, the paths may be selectively controlled by the auxiliary unit and subgroup relays so that ground potential is only impressed upon the trunk call identification lead in response to calls initiated on the trunks of the mixed group. In the case under consideration, with the unit relay R560 operated, the trunk group relay R540, in operating, completes a path extending from ground by way of the contacts 542 and 562, C574 and the contacts 601 for impressing ground potential upon the trunk call identification lead C681. In this regard, it will be appreciated that since the trunk 30 is terminated at the line contacts having the directory number designation 205, it is included in the first five lines of the ten-line group and, accordingly, the auxiliary group relays R530 and R600 are not operated. The auxiliary unit relay R560, in operating, also completes, at its contacts 561, an obvious path for impressing ground potential upon the common start lead C573. This lead is extended through

the contacts of the link distributor relays to the start lead individual to the assigned link. Assuming, for example, that the link illustrated is assigned to the use of the call, the start lead C234 is connected to the common start lead C573 and, accordingly, the two connect relays R280 and R290 are energized in response to operation of the auxiliary unit relay R560. The relay R280, in operating, completes the prepared operating circuit for the group relay R200, this circuit extending from ground by way of the contacts 541, C571, the contacts 582 and the winding of R200 to battery. The relay R200, in operating, prepares a locking circuit for itself at its contacts 251. At its contacts 253, the relay R200 prepares one of the operating circuits for the right-of-way control relay R1340. As indicated above, depending upon the type of wiring used in association with the group relay R200, this relay may or may not prepare a circuit for energizing the battery reversing relay R800. In the case under consideration, wherein it is assumed that all of the lines terminating at the line contacts of this group relay are trunk lines, both the "L" and "N" wires illustrated in Fig. 2 of the drawings are omitted, so that the engagement of the contacts 252 incident to operation of the relay R200 is without effect. If the "L" wiring is used, the relay R200, in operating, prepares a circuit for energizing the battery reversing relay R800.

When the connect relay R290 operates in the manner pointed out above, it completes the circuit for energizing the unit relay R220 and completes the operating circuit for the two line relays R820 and R825, thereby to cause the sequential operation of the relays R830, R840, R850 and R860, in the manner previously explained. The relay R290 also completes a circuit for energizing the right-of-way control relay R1020, this circuit extending by way of the grounded trunk call identification lead C681, the contacts 298, C236 and the upper winding of R1020 to battery. In operating, the relay R1020 locks to the grounded release conductor C893 through its contacts 1025. The control operations performed incident to operation of the relay R1020 are described with particularity hereinafter. The relay R860, in operating, connects the holding lead C235 to ground, thereby to complete the prepared holding circuits for the group and unit relays R200 and R220, respectively. In operating, the relay R860 also completes the previously traced path for impressing ground potential upon the control conductor 205c of the line 205, thereby to mark the trunk 30 as busy and to energize the relays R155 and R160.

When the cut-off and lockout relays R160 and R155, respectively, of the line circuit 20 operate, the common equipment is released in the exact manner explained above. With the relay R160 in its operated position, the windings of the line relay R150 are disconnected from the link line 205 to clear this line of the impedance represented by the line relay winding. Incident to the release of the common equipment, the two connect relays R280 and R290 are deenergized and restore. After the relay R290 restores, the two line relays R820 and R825 are held operated over a loop circuit extending from these relays through the operating winding of the supervisory relay conventionally embodied in the repeater 6. Following the release of the common equipment, the call is extended to the connector portion of the link and may be forwarded to the desired line under the control of the operator

handling the call in the central office 6, in the manner described hereinafter.

OPERATION OF THE LINK DISTRIBUTOR

As indicated above, each time one of the finder-connector links is assigned to the use of a calling line, the link distributor relay corresponding thereto is deenergized and restores. Thus, when the link illustrated is seized, the corresponding distributor relay R700 is caused to restore to extend the control leads C573, C684 and C865 to the contacts of the distributor relay R710 corresponding to the second link. In a similar manner, when the second link is assigned to the use of a calling line, the relay R710 is caused to release to extend the control circuits to the distributor relay corresponding to the third link. This successive assignment of links continues until the last link, namely that corresponding to the distributor relay R730, is assigned to the use of a calling line. In this regard it is pointed out that in the event the second link corresponding to the distributor relay R710 is occupied with a call at the time the first distributor relay R700 releases, the control circuits are extended through the restored contacts of the relay R710 to the distributor relay corresponding to the third link. Further, if this third link is also occupied with a call, the control circuits are extended through the restored contacts of the corresponding distributor relay to the contacts of the distributor relay corresponding to the fourth link. The arrangement of the distributor is such that the relays thereof are not immediately reoperated in response to the release of the respective associated links. Thus, it will be observed that with the relay R700 in its restored position, no circuit is available for energizing this relay regardless of the position of the hold relay R860. When, however, the last link, corresponding to the distributor relay R730, is assigned for use to cause the release of this distributor relay, a chain circuit is completed for energizing the slow-acting reset relay R660. Under these conditions all of the distributor relays are restored regardless of whether or not the respective associated links are occupied with calls. Accordingly, the circuit for energizing the reset relay R660 may be traced as extending from ground by way of the contacts 734, the chain-connected contacts of the distributor relays other than those illustrated, the contacts 715 and 705, C685, and the winding of R660 to battery. When energized over this circuit the relay R660 operates to prepare, at its contacts 661, a holding circuit for the all-links-busy relay R670. At its contacts 662, the relay R660 completes the operating circuits for those of the link distributor relays which are associated with idle links. For example, if the link illustrated has been released prior to the operation of the reset relay R660, the operating circuit for the corresponding link distributor relay R700 is completed, this circuit extending from ground by way of the contacts 662, C687, the contacts 107, C232, the contacts 863, C880, the contacts 916, C231, and the winding of R700 to battery. Obviously, if the link illustrated is still occupied with a call, this circuit is held open at the contacts 863, so that the distributor relay R700 is not energized. In a similar manner, if the second link is idle, an operating circuit for the associated distributor relay R710 is completed by way of the grounded conductor C687 and the contacts 717. Similar operating circuits are completed for the other distributor relays which

correspond to idle links. In the event the distributor relay R700 is energized over the circuit traced above, this relay operates to complete a locking circuit for itself which extends from ground by way of the resistor 708, the contacts 703, C232, the contacts 663, C880, the contacts 918, C231, and the winding of R700 to battery. At its remaining contacts the relay R700 arranges the associated control circuits so that the link illustrated will be assigned to the use of the next calling line. The other distributor relays which correspond to idle links are similarly locked in their respective operated positions. When the distributor relays which correspond to idle links operate, the chain circuit for energizing the reset relay R660 is broken. The relay R660, accordingly, releases after an interval to open the prepared holding circuit for the relay R670, and to open, at its contacts 662, the respective operating circuits for the distributor relays.

Provisions are made in the link distributing apparatus, whereby in the event an assigned link fails to find and seize a calling line within a reasonable time interval, the assigned link is released and a second link is assigned to the use of the calling line. To this end the common equipment is so arranged that each time a call is initiated upon one of the subscribers lines, the normally energized slow-to-release relay R630 is deenergized. More specifically, the relay R630 is normally energized over a circuit which extends from ground by way of the contacts 613, the winding of R630, the contacts 622, C576, the contacts 564 and 554, the chain-connected contacts of the other auxiliary unit relays, and the resistor 568 to battery. With the relay R630 energized over this circuit an obvious circuit for energizing the slow-to-release relay R640 is held completed at the contacts 631. With the relay R640 operated, the operating circuit for the overflow meter 632 is prepared at the contacts 641, a multiple circuit for energizing the relay R630 is completed at the contacts 642, and the operating circuit for the slow-acting relay R650 is held open at the contacts 643. When any one of the five auxiliary unit relays is caused to operate in the manner previously explained, the chain portion of the above-traced circuit for energizing the relay R630 is opened at the contacts 554, 564, or the corresponding contacts of one of the other auxiliary unit relays. After an interval determined by the slow-to-release characteristic of the relay R630, this relay restores to open the completed operating circuit for the relay R640. In the event the assigned finder switch successfully operates to seize the calling line in its intended manner, the line circuit associated with the calling line operates to open the start circuits to the auxiliary group and unit relays, in the manner previously explained, before the relay R640 is released. When these start circuits are opened, the operated one of the auxiliary unit relays is released to recomplete the above-traced operating circuit for the relay R630. This relay, in reoperating, recompletes the operating circuit for the relay R640. Thus, under normal operating conditions the relay R640 is not released during the time interval required for an assigned finder switch to seize the calling line to which it has been assigned.

If, for any reason, the finder portion of an assigned link fails to seize the line to which it is assigned, thereby to cause the reoperation of the relay R630 before the relay R640 is released, then

the assigned link is released and a second new link is assigned to the use of the calling line. Thus, if the operating circuit for the relay R640 is held open for a sufficiently long interval of time, this relay restores to open, at its contacts 641, the prepared operating circuit for the overflow meter 632, and to open, at the contacts 642, the prepared multiple circuit for energizing the relay R630. At its contacts 643, the relay R640 completes the prepared operating circuit for the slow-acting relay R650, this circuit extending from ground by way of the contacts 674, 624 and 643, and the winding of R650 to battery. The relay R650, in operating, opens, at its contacts 651, the prepared path for short-circuiting the winding of the link distributor relay corresponding to the first assigned link. At its contacts 652, the relay R650 completes an obvious circuit for energizing the slow-acting relay R620. The relay R620, in operating, further prepares, at its contacts 621, the path for short-circuiting the winding of the distributor relay corresponding to the first assigned link. At its contacts 624, the relay R620 opens the above-traced circuit for energizing the relay R630. At its contacts 622, the relay R620 opens a point in the normally completed circuit for energizing the relay R630. At its contacts 623, the relay R620 completes an alternative circuit for energizing the relay R630, this alternative circuit extending from ground by way of the contacts 613, the winding of R630, the contacts 623, C579, and the resistor 522 to battery. When thus energized, the relay R630 reoperates to complete the operating circuit for the relay R640. The relay R640, in turn, reoperates to reprepare the circuit for energizing the overflow meter 632, to complete a multiple circuit for energizing the relay R630, and to open, at the contacts 643, a further point in the operating circuit for the relay R650. Substantially concurrently with the reoperation of the relay R640, the relay R650 restores to open, at its contacts 652, the operating circuit for the slow-acting relay R620. At its contacts 651, the relay R650 completes the previously mentioned path for short-circuiting the winding of the distributor relay corresponding to the first assigned link.

Assuming, for example, that the link illustrated is the first assigned link and, further, that this link has failed to find the calling line to which it was assigned, the link distributor relay R700 is short-circuited when the relay R650 releases in the manner just explained. The path for short-circuiting this distributor relay extends from the negative terminal of the exchange battery through the resistor 625 and by way of the contacts 621 and 651, C684, the contacts 703, C232, the contacts 292, C231, and the winding of R700 back to the negative terminal of the exchange battery. It is noted that the resistance value of the resistor 625 is relatively small as compared with the resistance value of the resistor 708. More specifically, the resistor 708 has a resistance value of approximately 1,000 ohms, whereas the resistor 625 has a resistance value of only 50 ohms. It will be understood, therefore, that when the above-traced path is completed, the relay R700 is effectively short-circuited and caused to release. In releasing, the relay R700, at its contacts 702, disconnects the common start lead C573 from the start lead C234 individual to the link illustrated, whereby the connect relays R280 and R290 are deenergized and restored. At its contacts 701, the relay R700 extends the common start lead to the link start

lead individual to the next available idle link. Thus, if the second link is idle, and the relay R710 is operated, the common start lead C573 is connected through the contacts 701 and 712 to the start lead individual to the second link. At its contacts 706, the relay R700, in releasing, opens a point in the common portion of its two locking circuits as traced previously. At its contacts 707, the relay R700 prepares its own operating circuit. At its contacts 703, the relay R700 opens the path short-circuiting its own winding. At its contacts 704, the relay R700 prepares a path for short-circuiting the winding of the distributor relay corresponding to the next idle link, which, in the case assumed, is the second distributor relay R710. At its contacts 705, the relay R700 prepares the above-traced chain circuit for energizing the reset relay R660. Substantially concurrently with the release of the relay R700, the relay R620 restores to open, at its contacts 621, the above-traced path for short-circuiting the winding of the distributor relay R700, and the prepared path for short-circuiting the winding of the distributor relay corresponding to the second assigned link. At its contacts 624, the relay R620 reprepares the operating circuit for the relay R650. At its contacts 622 and 623, the relay R620 opens the above-traced alternative circuit for energizing the relay R630, and reprepares the initially traced operating circuit for the last-mentioned relay. It will be understood that since one of the auxiliary unit relays illustrated in Fig. 5 of the drawings is at this time still operated, the initially traced operating circuit for the relay R630 is open at the contacts 554, 564, or the corresponding contacts of an operated one of the other auxiliary unit relays. Accordingly, the second timing period is started in response to the release of the relay R620.

When the common start lead C573 is disconnected from the link start lead C234 through the release of the link distributor relay R700, in the manner just explained, the two connect relays R280 and R290 restore to open the operating circuits for the group and unit relays of the finder switch illustrated, and to open the completed operating circuit for the line relays R820 and R825. Thus, the relays R820, R825, R830, R840, R850 and R860 are caused sequentially to restore in an obvious manner. At its contacts 291, the relay R290, in releasing, disconnects the conductor C682 from ground, thereby momentarily to deenergize the relay R610. Since, however, ground potential is impressed upon this conductor through operation of the connect relays embodied in the second assigned link substantially concurrently with the release of the two relays R280 and R290, the relay R610 is held energized and does not restore. The application of ground potential to the link start lead extending to the second assigned link results in the operation of the finder portion of this link to seize the calling line, assuming that the second assigned link is not also defective. In such case, the operated ones of the auxiliary group and unit relays illustrated in Fig. 5 of the drawings, are caused to restore so that the operating circuit for the relay R530 is recompleted before the relay R640 is released. Thus, the normal operation of the distributor equipment is resumed. If, however, the second assigned link is also defective or, for some reason, fails to seize the calling line to cause the operation of the line circuit associated therewith, the cycle of operation of the distributor equipment as described above, is repeated so that the

second assigned link is released and a third link is assigned to the use of the calling line. More specifically, the cyclic operation of the distributor equipment continues until the finder portion of one of the assigned links is successful in its operation to seize the calling line, and thus cause the release of the operated ones of the auxiliary group and unit relays illustrated in Fig. 5 of the drawings.

- 10 In the event all of the links embodied in the exchange are busy at the time the relay R730 corresponding to the last link is released to complete the above-traced chain circuit for energizing the relay R660, none of the distributor relays are immediately energized, although the operating circuits for all of these relays are prepared. Accordingly, the relay R660 remains in its operated position until one of the links is released. With the apparatus in this condition, if a call is initiated upon one of the lines terminating at the exchange, the auxiliary unit relay, illustrated in Fig. 5, which corresponds to the calling line operates to impress ground potential upon the common start lead C573, thereby to complete the operating circuit for the all-links-busy relay R670. This circuit extends by way of the grounded lead C573, the contacts 701, 711, 731 and the other chain-connected contacts controlled by the distributor relays, C686 and the winding of R670 to battery. When thus energized, the relay R670 locks to ground through the contacts 671 and 661. At its contacts 672, the relay R670 completes a circuit extending by way of the grounded conductor C686 and the contacts 641 for energizing the overflow meter 632, whereby the all-busy condition of the links is registered. At its contacts 674, the relay R670 opens a point in the previously traced circuit for energizing the call metering device 614, and a point in the operating circuit for the relay R650. At its contacts 673, the relay R670 opens a point in the multiple operating circuit for the relay R630. Shortly following the initiation of the call, the relays R630 and R640 are caused sequentially to restore in the order named and in the manner previously explained. The relay R640, in releasing, prepares the operating circuit for the relay R650, and opens, at its contacts 641, the circuit for energizing the overflow meter 632. The relay R670 remains in its operated position until the all-busy condition of the links is terminated and one of the links is released. Thus, if the call under consideration is abandoned before one of the links is released, the operated ones of the auxiliary group and unit relays are caused to restore in a manner clearly apparent from the preceding explanation so that ground potential is removed from the common start lead C573 and the operating circuit for the relay R630 is reprepared. Thus, the operating circuit for the all-links-busy relay R670 is opened, but this relay remains energized over its locking circuit as traced above. Further, the relay R630 is not caused to operate since its operating circuit is open at the contacts 642 and 673. Accordingly, further calls initiated prior to the release of one of the links to terminate the all-links-busy condition are prevented from causing further operation of the overflow meter 632. It will be apparent from the foregoing description that with the relay R660 operated, the operating circuits for all of the link distributor relays are prepared. Accordingly, when one of the links is released, the link distributor relay corresponding thereto is

immediately energized. Thus, if all of the links are busy and the link illustrated is the first link to be released, the operating circuit for the associated distributor relay R700 is completed in response to the release of the hold relay R860 individual to this link. The relay R700, in re-operating, opens its operating circuit and locks to ground in the manner previously explained. At its contacts 702, the relay R700 connects the common start lead to the link start lead C234 so that if a call is waiting the assignment of a link, the connect relays R280 and R290 are immediately energized to cause the operation of the finder switch illustrated, in the manner explained above. At its contacts 705, the relay R700 opens the above-traced operating circuit for the relay R660. At its contacts 703, the relay R700 prepares the previously traced path for short-circuiting its own winding. After a time interval determined by the slow-to-release characteristic of the relay R660, this relay restores to open, at its contacts 661, the locking circuit for the relay R670 and to open, at its contacts 662, the prepared operating circuits for the link distributor relays. The relay R670 now releases to open, at its contacts 672, the prepared operating circuit for the overflow meter 632, and to reprepare, at its contacts 673, the operating circuit for the relay R630. At its contacts 674, the relay R670 completes the previously traced operating circuit for the relay R650. Due to the slow-to-release characteristic of the relay R660 and the slow-to-operate characteristic of the relay R650, the operation of the finder switch illustrated, to seize the calling line and thus cause the operation of the line circuit associated therewith to release the operated auxiliary group and unit relays, is completed before the relay R650 can operate. Accordingly, the relays R630 and R640 are caused sequentially to reoperate before the relay R650 operates in response to the release of the relay R670. Thus, the two relays R620 and R650 are prevented from completing the path for short-circuiting the relay R700. In the event these two relays are operated prior to operation of the relay R640, the completion of the path for short-circuiting the winding of the distributor relay R700 is without effect, since, under any circumstances, the finder switch illustrated will complete its operation to seize the calling line before the relay R700 is short-circuited. Accordingly, the short-circuiting path will be opened at the contacts 292 and 863 of the relays R290 and R860, respectively, before the relay R650 is caused to restore in response to release of the relay R620. Thus, even though these two relays may operate, such operation is, in the case under consideration, without effect.

SELECTING A CALLED SUBSCRIBERS LINE

Continuing now with the operation of the link to route a connection to a called one of the lines terminating in the connector portion thereof, it is pointed out above that when the relay R860 operates, a path is completed for conducting dial tone current by way of the receiver provided at the calling substation. The calling subscriber upon thus receiving the dial tone signal is informed that the dialing operation may be started. During impulses, the relay R830 responds to each dialed impulse and repeats the impulse to the relays R1100 and R1150 and the impulse-counting relays illustrated in Figs. 12 and 13 of the drawings. More specifically, when the subscribers loop

circuit is opened at the calling substation at the beginning of the first impulse of the first digit, the line relays R820 and R825 restore. The release of the relay R825 is without effect. The relay R820, in restoring, opens, at its contacts 821, a point in the previously traced operating and locking circuits for the pulsing relay R830. At its contacts 822, the relay R820 prepares a priming circuit for itself. The relay R830, in releasing, opens, at its contacts 833, a further point in the above-traced locking circuit for itself. At its contacts 831, the relay R830 opens a point in the previously traced operating circuit for the slow-acting relay R850. At its contacts 832, the relay R830 opens the operating circuit for the relay R840. The relay R840 now restores to complete the above-mentioned priming circuit for the line relay R820, this circuit extending from ground by way of the contacts 918', C890, the contacts 841, 822 and 851, the resistor 831' and the winding of R820 to battery. The resistance value of the resistor 831' is so proportioned that the relay R820 does not reoperate when the circuit just traced is completed, but is rendered exceedingly fast-to-operate when the calling subscribers loop circuit is subsequently recompleted. At its contacts 842, the relay R840, in restoring, opens the previously traced locking circuit for the relay R850. The latter relay, due to its slow-to-release characteristic, remains operated during impulsion.

At the end of the open-circuit period of the first impulse when the subscribers loop circuit is again completed, the line relay R820 reoperates and again completes the operating circuit for the pulsing relay R830. At its contacts 822, the relay R820 opens the above-traced priming circuit for itself. The relay R830, upon operating, re-completes its locking circuit, re-completes the locking circuit for the slow-acting relay R850, and re-completes the operating circuit for the relay R840. The relay R840, upon operating, again completes the multiple locking circuit for the relay R850. During each succeeding impulse dialed at the calling substation, the three relays R820, R830 and R840 respond in the exact manner just described.

As indicated above, each time the relay R830 restores it completes the pulsing circuit extending to the relays R1100, R1150 and the relays of the counting chain illustrated in Figs. 12 and 13 of the drawings. Thus, when the relay R830 restores at the beginning of the open-circuit period of the first impulse, the relays R1100 and R1150 are energized in parallel with the first counting relay R1240. The circuit for energizing these relays extends from ground by way of the contacts 834, 815 and 864, C881 and the contacts 1056 to the conductor C1081 where it divides, one branch extending through the lower winding of R1100 to battery, a second branch extending through the winding of R1150 to battery, and the third branch extending by way of the contacts 1113, C771, the contacts 754, 764 and 774, C782 and the winding of R1240 to battery. When thus energized, the relay R1150 operates to complete, at its contacts 1152, an obvious circuit for energizing the slow-to-release relay R1160 in parallel with the upper winding of the relay R1100. At its contacts 1151, the relay R1150 completes a path including the conductor C844 for shunting the repeater winding 835 and the winding of the line relay R825 from the established loop circuit extending to the calling substation, thereby to reduce the resistance of this circuit and correspondingly to enhance the energization of the

relay R820 during impulsion. The relay R1160, in operating, completes a multiple path including the 750 ohm resistor 1147 in shunt with the series path including the repeater winding 835 and the winding of the relay R825. The relay R1100, upon operating, opens, at its contacts 1101, a point in the common portion of the circuits for energizing the ringing control relay R960 and the counting chain release relay R870. These contacts are also included in additional control circuits referred to with particularity hereinafter. At its remaining contacts 1102, 1103 and 1104, the relay R1100 opens points in the common portions of the operating circuits for the respective group and unit relays of the connector portion of the link and other control circuits subsequently described in detail. Due to the slow-to-release characteristic of the relay R1150, this relay and the associated relays R1100 and R1160 all remain operated during impulsion.

Operation of the counting chain

The relay R1240, upon operating at the beginning of the first impulse, completes, at its contacts 1246, a locking circuit for itself and, in so doing, closes a path for short-circuiting the winding of the control relay R770. This locking circuit extends by way of the grounded release conductor C893, the contacts 871, C897, the contacts 766, the winding of R770, C783, the contacts 1246 and the winding of R1240 to battery. It will be observed that so long as the pulsing relay R830 occupies its restored position, both winding terminals of the relay R770 are connected to ground and, accordingly, this relay is short-circuited. At its contacts 1245, the relay R1240 prepares a circuit for energizing the second counting relay R1250. At its contacts 1244, the relay R1240 prepares a circuit, traced hereinafter, for energizing the ringing relay R1010 in accordance with the coded ground pulses impressed upon the first ringing interrupter lead C1249. At its contacts 1243, the relay R1240 prepares a circuit for energizing the group relay R1410 embodied in the connector portion of the link and terminating the first group of ten lines. At its contacts 1242, the relay R1240 prepares a circuit for energizing the units relay R1450 embodied in the connector portion of the link and corresponding to the first line of each ten-line subgroup. At its contacts 1241, the relay R1240 prepares a circuit, traced hereinafter, for energizing the verification relay R1140 in series with the counting chain release relay R870.

At the end of the open-circuit period of the first impulse, the pulsing relay R830 restores in the manner explained above and, in so doing, opens its contacts 834 to interrupt the path short-circuiting the winding of the control relay R770. The relay R770 is thus energized in series with the first counting relay R1240 and operates to open, at its contacts 776, a point in the operating circuit for the relay R750. At its contacts 774, the relay R770 opens a further point in the above-traced operating circuit for the first counting relay R1240. At its contacts 775, the relay R770 further prepares the operating circuit for the second counting relay R1250. At its contacts 773, the relay R770 prepares a point in the common portion of certain operating circuits described hereinafter. At its contacts 772, the relay R770 prepares a path for impressing ground potential upon the ringing interrupter start lead C789. At its contacts 771, the relay R770 prepares a path for impressing

ground potential upon the ringing generator start conductor C1167.

At the beginning of the open-circuit period of the second impulse when the pulsing relay R830 again restores, the operating circuit for the second counting relay R1250 is completed, this circuit extending from ground by way of the contacts 834, 815 and 884, C881, the contacts 1056, C1081, the contacts 1113, C771, the contacts 754, 764 and 775, C781, the contacts 1245 and the winding of R1250 to battery. When thus energized, the relay R1250 operates and locks to ground over a path including the contacts 1256, C784, the winding of R760, the contacts 756, C897, the contacts 871 and the grounded release conductor C893. At its contacts 1255, the relay R1250 prepares the operating circuit for the third counting relay R1260. At its remaining contacts, the relay R1250 performs additional control operations apparent from the above explanation with respect to the operation of the first counting relay R1240. At the end of the open-circuit period of the second impulse when the pulsing relay R830 again operates, the path short-circuiting the winding of the second control relay R760 is interrupted, permitting this relay to be energized in series with the second counting relay R1250. The relay R760 now operates to open, at its contacts 766, the above-traced series locking circuit for the two relays R770 and R1240, causing both of these relays to restore. At its contacts 764, the relay R760 opens a further point in the operating circuit for the second counting relay R1250. At its contacts 765, the relay R760 further prepares the operating circuit for the third counting relay R1260. At its contacts 761, 762 and 763, the relay R760 completes obvious paths individually shunting the contacts 771, 772 and 773 of the relay R770.

At the beginning of the open-circuit period of the third impulse when the pulsing relay R830 again restores, the operating circuit for the third counting relay R1260 is completed, this circuit extending by way of the grounded pulsing lead C771, the contacts 754 and 765, C780, the contacts 1255 and the winding of R1260 to battery. The relay R1260, upon operating, locks to the grounded release conductor C893 over a path including the contacts 1266, C785, the contacts 776, the winding of R750, C897 and the contacts 871. When this path is completed, the relay R750 is obviously short-circuited. At its contacts 1265, the relay R1260 prepares the operating circuit for the fourth counting relay R1270. The remaining circuit-switching operations performed by the third counting relay R1260 are of no consequence at the present point in the operation of the system. At the end of the open-circuit period of the third impulse when the pulsing relay R830 again operates, the path short-circuiting the winding of the relay R750 is opened, permitting this control relay to be energized in series with the third counting relay R1260. The relay R750 now operates to open, at its contacts 756, the series-locking circuit for the two relays R760 and R1250, causing both of these relays to restore. At its contacts 754 and 755, the relay R750 opens a further point in the operating circuit for the third counting relay R1260 and further prepares the operating circuit for the fourth counting relay R1270. At its remaining contacts 751, 752 and 753, the relay R750 completes obvious paths individually shunting the contacts 761, 762 and 763 of the relay R760.

At the beginning of the open-circuit period of the fourth impulse when the pulsing relay R830 again restores, the prepared operating circuit for the fourth counting relay R1270 is completed, this circuit extending by way of the grounded pulsing lead C771, the contacts 755, C779, the contacts 1265 and the winding of R1270 to battery. When thus energized, the relay R1270 locks to the grounded release conductor C893 over a path including the contacts 1276, C783, the winding of R170, the contacts 766, C891 and the contacts 871. When this path is completed, the winding of the relay R170 is obviously short-circuited. At its contacts 1275, the relay R1270 prepares the operating circuit for the fifth counting relay R1280. The remaining circuit-switching operations performed by the relay R1270 are of no effect at this time. At the end of the open-circuit period of the fourth impulse when the relay R830 again operates, the path short-circuiting the winding of the relay R170 is interrupted, permitting this control relay to be energized in series with the fourth counting relay R1270. The relay R170 now operates to open, at its contacts 776, the above-traced series locking circuit for the two relays R1750 and R1260, causing both of these relays to restore. At its contacts 774 and 775, the relay R170 opens a point in the operating circuit for the first counting relay R1240 and further prepares the operating circuit for the fifth counting relay R1280. The relay R1750, in releasing, opens its contacts 755 and closes its contacts 754, thereby to open a further point in the operating circuit for the fourth counting relay R1270 and further to prepare the operating circuit for the fifth counting relay R1280. It is believed that the manner in which the remaining counting relays R1280, R1290, R1300, R1310, R1320 and R1330 respond to additional impulses transmitted thereto through operation of the pulsing relay R830, will be clearly apparent from the preceding explanation. Thus, it will be noted that the relays R1290, R1300, R1310, R1320 and R1330 sequentially respond to the sixth, seventh, eighth, ninth and tenth impulses of a digit, in the order named. It will also be noted that the relays R1280 and R1310 lock to ground over the lead C784 in series with the control relay R1760; the relays R1290 and R1320 lock to ground over the lead C785 in series with the third control relay R1750; and the relays R1300 and R1330 lock to ground over the lead C783 in series with the first control relay R1770. The three enumerated control relays operate sequentially in response to succeeding impulses successively to prepare the operating circuits to the various counting relays, and to release the previously operated counting relays and their associated control relays.

The directory numbering arrangement

In order to facilitate an understanding of the manner in which the different types of lines are seized through the connector portion of the link, and the manner in which the various control operations performed incident to the seizure of these lines are carried out, it is desirable to consider briefly the directory numbering arrangement utilized in the system. A four digit directory numbering arrangement is used for selecting the called subscribers lines and for selectively signaling the substations associated therewith. The first digit of a directory number dialed at a calling telephone station is used for several different purposes. Thus, if a first digit comprising one

impulse is inadvertently dialed at a substation served by the switching equipment illustrated, the digit or impulse is absorbed. On the other hand, if a first digit comprising one impulse is dialed at a calling operator's position in the central office 5, and the single impulse thereof is transmitted to the connector portion of the link illustrated, it is utilized as a prefix digit for conditioning the connector portion of the link to establish a dry talking circuit to a busy called line. If a first digit comprising either two, four or five impulses is dialed at a calling telephone station, the first group of one hundred lines, namely, the 200-line group, is selected thereby. 10 A first digit of two impulses also indicates that ten-party code ringing is to be utilized in signaling over a desired subscribers line. A first digit of four impulses on the other hand, indicates that twenty-party code ringing is to be used in signaling over a called subscribers line and, further, that the code corresponding to the desired substation is included in the first ten codes of the available twenty codes. A first digit of five impulses also indicates that twenty-party code ringing is to be used in signaling over a called subscribers line, but further indicates that the code corresponding to the desired substation is included in the second group of ten codes of the available twenty codes. A first digit comprising three impulses is utilized to select the subscribers lines included in the second 100-line group, namely, the lines having the "300" series of directory numbers assigned thereto. In all cases, the selective signaling of the substations associated 20 with the multiparty lines of this group is accomplished by using the ten-party code ringing facilities as contrasted with the twenty-party code ringing facilities available. This is accomplished by terminating the multiparty subscribers line 25 serving less than ten substations in the second group of one hundred lines.

In the arrangement illustrated, wherein inter-office communication facilities are only provided between the central office 5 and the exchange 45 embodying the switching equipment illustrated, a single central inter-office trunk group is provided, this trunk group being terminated in the contacts of the tenth group relay R1400 and forming a part of the first 100-line group. This group of inter-office trunks may be selected by any calling subscriber by dialing a single digit comprising ten impulses. In the arrangement illustrated, if first digits comprising six, seven, eight or nine impulses are dialed at a calling telephone station, the impulses are absorbed. If, however, the requirements of a particular installation dictate that additional inter-office switch-through trunks be provided, the ninth or the eighth and ninth groups of lines in the first 50 100-line group may constitute such additional trunks. In such case first digits comprising nine or eight and nine impulses may be utilized for inter-office trunk selection.

The second and third digits of a directory number designating a desired subscribers substation are utilized respectively to control the connector group and unit relays, so that a connection to the line serving the desired substation is effected. The fourth digit of the directory number is utilized for ringing code selection, i. e., to select the ringing code corresponding to the desired substation.

Absorbing unused first digits

Briefly to consider the manner in which the

unused first digits are absorbed, it will be recalled from the preceding explanation that if a first digit of one impulse is dialed at a calling substation such, for example, as the substation A, the first counting relay R1240 is locked energized in series with the first control relay R1770 at the end of the digit. At the end of the digit, the pulsing relay R830 is held in its operated position, as will be understood from the preceding explanation. Accordingly, the previously traced operating circuits for the relays R1100 and R1150 are held open. Shortly following the end of the digit, therefore, the relays R1150, R1100 and R1160 sequentially restore in the order named. The relays R1150 and R1160, in releasing, open the two previously traced paths for short-circuiting the repeater winding 835 in series with the winding of the line relay R825. The relay R1100, in restoring, completes a circuit for energizing the lower winding of the relay R1140 in series with the counting chain release relay R870, this circuit extending by way of the grounded release conductor C893, the contacts 773, C786, the contacts 1101, 1117, 1128 and 1104, C1221, the contacts 1241, C1214, the lower winding of R1140, C887 and the winding of R870 to battery. The remaining circuit-switching operations performed incident to the release of the relay R1100 are without effect at this time. Also, the operation of the verification relay R1140 is of no consequence at this time. The relay R870, in operating, opens, at its contacts 871, the previously traced series-locking circuit for the two relays R1770 and R1240, causing both of these relays to restore. When these two relays restore, two points are opened, at the contacts 773 and 1241, in the above-traced circuit for energizing the relay R870 in series with the lower winding of the relay R1140. Thus, the two latter relays are caused to release, and the equipment is restored to the condition which prevailed before the first digit of one impulse was dialed.

The manner in which the counting chain is released when first digits comprising six, seven, eight and nine impulses are inadvertently dialed is substantially similar to the release of this equipment when a first digit of one impulse is inadvertently dialed at a calling substation. Thus, if the digit 6, for example, is dialed at a calling substation, the counting relay R1290 is locked energized in series with the third control relay R1750 at the end of the digit. Accordingly, when the relay R1100 restores shortly following the end of the digit, the relay R870 is energized over a circuit which extends from ground by way of the contacts 869, the release conductor C893, the contacts 753, C786, the contacts 1101, 1117 and 1128, C1222, the contacts 1291, C887 and the winding of R870 to battery. It will be noted that the contacts 1291 included in this circuit are paralleled by the contacts 1311 of the eighth counting relay R1310 and, accordingly, this circuit is completed if a first digit comprising eight impulses is dialed at a calling substation. In the case where a first digit comprising seven or nine impulses is dialed, the circuit completed at the end of the digit for energizing the counting chain release relay R870 is slightly different. More particularly, with either the seventh counting relay R1300 or the ninth counting relay R1320 operated at the end of a dialed first digit, the circuit for energizing the relay R870 extends by way of the grounded release conductor C893, the contacts 773 or 753, C786, the contacts 1101, 1117, 75

1128 and 1104, C1221, the contacts 1301 or 1321, C887 and the winding of R870 to battery. When energized over any one of these circuits, the relay R870 operates to open, at its contacts 871, a point in the common portion of the previously traced locking circuits for the ten counting relays and their associated control relays, causing the two operated ones of these relays to release. Thus, it will be apparent that with the arrangement illustrated when first digits comprising one, six, seven, eight or nine impulses are inadvertently dialed, the counting chain is automatically released and the control equipment of the link is restored to the condition which prevailed prior to the dialing of the digit.

Selecting a called subscribers line in the 200-line group

As indicated above, a subscribers line, such, for example, as the line 219, included in the first group of one hundred lines, may be selected by dialing at the calling telephone station, a first digit comprising two, four or five impulses followed by the group and units digits respectively designating the ten-line subgroup including the called line and the particular line of this subgroup. Assuming, for example, that the multi-party subscribers line 219 is desired by a calling subscriber and, further, that this line is arranged for ten-party code ringing, a first digit comprising two impulses is dialed at the calling substation. Accordingly, the counting relay R1250 is locked energized in series with its associated control relay R760 at the end of the digit. When the relays R1150, R1100 and R1160 sequentially restore shortly after the digit is ended, one of the prepared operating circuits for the relay R1200 is completed. This circuit extends by way of the grounded release conductor C893, the contacts 763, C786, the contacts 1101, 1117 and 1128, C1222, the contacts 1251 and the upper winding of R1200 to battery. The remaining circuit-switching operations performed incident to the release of the relay R1100 are without effect at this time.

45. The relay R1200, upon operating, prepares, at its contacts 1204, a circuit for energizing the relay R1210. At its contacts 1203, the relay R1200 prepares a circuit for energizing the relay R1350. At its contacts 1201, the relay R1200 prepares a circuit for energizing the ring pickup relay R960 in accordance with the battery pulses impressed upon the first pickup lead C1215 by the ringing interrupter 1395. At its contacts 1202, the relay R1200 completes a circuit including the grounded lead C1222 and the conductor 1217 for energizing the group select relay R1360 individual to the first group of one hundred lines. The relay R1360, in operating, prepares, at its contacts 1362, an alternative circuit for energizing the ring pickup relay R960 in accordance with the battery pulses impressed upon the first pickup lead C1215. At its contacts 1363, the relay R1360 completes a locking circuit for itself and the relay R1200. This locking circuit extends by way of the grounded release conductor C893 and the winding of R1120 to the conductor C1080 where it divides, one branch extending through the contacts 1363 and the winding of R1360 to battery, and the other branch extending by way of the contacts 1163, C1217, the contacts 1202 and the upper winding of R1200 to battery. When this locking circuit is completed, both winding terminals of the relay R1200 are connected to ground and, accordingly, this relay is short-circuited. 75 At its break contacts 1364 to 1368, inclusive, the

relay R1360 opens points in the operating circuits for five of the connector group relays terminating fifty of the lines included in the second group of one hundred lines. At its make contacts 1364 to 1368, inclusive, the relay R1360 prepares the operating circuits for five of the connector group relays terminating fifty of the lines included in the first group of one hundred lines. In this regard it will be apparent that with the other group select relay R1350 occupying its restored position, the operating circuits for the remaining five connector group relays terminating lines included in the first group of one hundred lines are all prepared. On the other hand, with this latter group select relay restored, the operating circuits for the five remaining connector group relays terminating lines of the second group of one hundred lines are held open at the contacts 1353 to 1357, inclusive. Thus, with the relay R1360 operated and the relay R1350 restored, the connector switch is conditioned to select a line included in the first group of one hundred lines.

At its contacts 1361, the relay R1360 completes an alternative circuit for energizing the counting chain release relay R870, this circuit extending from ground by way of the contacts 1361, C1086, the contacts 1126, C887 and the winding of R870 to battery. When thus energized, the relay R870 operates to open, at its contacts 871, the previously traced locking circuit for the second counting relay R1250 and its associated control relay R760, causing both of these relays to restore. Thus, the impulse-counting equipment of the connector switch is fully restored to normal. During the release of the relay R1250, the operating circuit for the relay R1200 is opened at the contacts 1251. Further, with the two relays R1250 and R760 deenergized, the previously described path for short-circuiting the winding of the transfer relay R1120 is opened at the contacts 123 and 1251. When this path is opened, the relay R1120 is energized in series with the parallel-connected relays R1200 and R1360. In operating, the relay R1120 opens, at its contacts 1121, the previously traced path for transmitting dial tone signal current over the calling end of the connection. Thus, the dial tone signal is terminated. At its contacts 1122, the relay R1120 completes an obvious shunt path across the restored contacts 1113 of the relay R1110, these contacts being commonly included in the above-described circuit for transmitting impulses to the relays of the counting chain. At its contacts 1123, the relay R1120 opens the path normally short-circuiting the winding of the slow-to-operate idle test relay R1070. At its contacts 1124, the relay R1120 shunts the restored contacts 1114 to prepare a multiple point in the locking circuit for the verification relay R1140. At its contacts 1125, the relay R1120 opens a point in the circuit, traced hereinafter, for energizing the switching-through relay R810. At its contacts 1125', the relay R1120 opens a point in the common portion of the circuits, traced hereinafter, over which the unit relays of the connector switch are selectively energized in setting up an inter-office trunk call. At its contacts 1126', the relay R1120 prepares another of the operating circuits for the counting chain release relay R870. At its contacts 1128, the relay R1120 opens another point in the previously traced operating circuits for the two relays R1200 and R1360. At its contacts 1127, the relay R1120 prepares a point in the common portion of the operating circuits of

the twenty group relays embodied in the connector portion of the link.

At its contacts 1128, the relay R1120 opens the previously traced alternative operating circuit for the counting chain release relay R870, causing the latter relay to restore. Following the release of the relay R870, the control equipment of the link is conditioned to respond to the impulses comprising the second digit of the directory number designating the desired substation associated with the called line 219.

Before proceeding with the explanation relating to the final selection of the called line, it is in order to point out the mode of operation of the apparatus when directory numbers having first digits comprising four and five impulses, respectively, are dialed. In this regard it will be understood from the previous explanation that if a first digit of four impulses is dialed at the calling substation, the fourth counting relay R1270 is locked energized in series with its associated control relay R770 at the end of the digit. Accordingly, when the relays R1150, R1100 and R1160 restore shortly following the end of the digit, the group select relay R1360 is directly energized. In this case the circuit for energizing the relay R1360 extends by way of the grounded release conductor C893, the contacts 113, C786, the contacts 1101, 1117 and 1128, C1222, the contacts 1271, C1217 and the winding of R1360 to battery. The relay R1360, in operating, performs the functions described above, among which are the short-circuiting of the transfer relay R1120 and the completion of the operating circuit for the counting chain release relay R870. The latter relay, in operating, opens the locking circuit for the two relays R170 and R1270, whereby the impulse-counting equipment is released. In response to the release of the relays R170 and R1270, the path short-circuiting the winding of the transfer relay R1120 is opened at the contacts 1271 and 113, permitting this relay to be energized in series with the group select relay R1360. The relay R1120, in operating, opens, at its contacts 1126, the completed circuit for energizing the counting chain release relay R870, causing the latter relay to release. Thus, the control apparatus of the link is conditioned to respond to the impulses of the second digit. It will be apparent from the above explanation that, when a first digit comprising four impulses is dialed at the calling substation, the relay R1360 is alone operated, whereas in the case of a first digit comprising two impulses, both this relay and the relay R1200 are locked energized at the end of the digit.

In the event a first digit comprising five impulses is dialed at the calling substation, the fifth counting relay R1280 is locked energized in series with its associated control relay R760 at the conclusion of the digit. Accordingly, when the relays R1150, R1100 and R1160 sequentially restore at the end of the digit, a circuit is completed for energizing the relay R1210, this circuit extending by way of the grounded release conductor C893, the contacts 763, C786, the contacts 1101, 1117, 1128 and 1104, C1221, the contacts 1281 and the winding of R1210 to battery. In operating, the relay R1210 prepares, at its contacts 1212, a circuit for energizing the ring pickup relay R960 in accordance with the battery impulses impressed upon the second pickup lead C1221 by the ringing interrupter 1395. At its contacts 1214, the relay R1210 opens a point in one of the previously mentioned circuits for energizing the ring

pickup relay R860 in accordance with the battery pulses impressed upon the first pickup lead C1215 by the ringing interrupter 1385. At its contacts 1213, the relay R1210 completes a circuit including the grounded conductor C1221 and the conductor C1217 for energizing the group select relay R1360. The relay R1360, upon operating, closes its contacts 1362 to complete the previously traced locking circuit for itself. A branch of this circuit extends by way of C1217 and the contacts 1213 to maintain the relay R1210 energized. When these holding circuits are completed, the transfer relay R1120 is short-circuited in the manner explained above. At its contacts 1361, the relay R1360 completes the previously traced operating circuit for the counting chain release relay R870, whereby the relays R1280 and R760 are caused to restore. These relays, in releasing, open the path short-circuiting the winding of the relay R1120, permitting this relay to be energized in series with the parallel connected relays R1210 and R1360. In restoring, the relay R760 also opens the circuit for energizing the counting chain release relay R870, whereby the latter relay is deenergized and restores. Following the release of the relay R870, the control apparatus of the link is conditioned to respond to the impulses comprising the second digit of the directory number designating the desired substation. From the above explanation it will be apparent that in the case where a first digit comprising five impulses is dialed at the calling substation, the relays R1210 and R1360 are locked energized at the end of the digit, as distinguished from the other two cases considered above.

Continuing now with the operation of the control apparatus to select the desired line 219, it will be understood that the counting relays respond to the impulses of the second digit in the exact manner previously explained. It will also be understood that since the called line is the ninth line of the first subgroup of lines in the first group of one hundred lines, the second and third digits dialed at the calling substation will respectively comprise one and nine impulses. During the dialing of the second digit, the relays R1110, R1150 and R1160 are caused to re-operate in the manner previously described. At the end of the second digit, the first counting relay R1240 is locked energized in series with its associated control relay R770. When the relays R1150, R1160 and R1160 sequentially restore at the end of the second digit, the operating circuit for the group relay R1410, having contacts terminating the conductors of the called line 219, is completed at the contacts 1101 and 1103 of the relay R1160. This circuit extends from ground by way of the contacts 869, the release conductor C893, the contacts 713, C786, the contacts 1101, 1117, 1121 and 1103, C1226, the contacts 1243, C1248, the contacts 1353', C1248' and the winding of R1410 to battery. When energized over this circuit, the relay R1410 operates to complete, at its contacts 1411, a path including the conductor C1164 and the grounded release conductor C893 for short-circuiting the winding of the transfer relay R1110. At its contacts 1413, the relay R1410 prepares a circuit for energizing one of the unit relays embodied in the connector portion of the link. At its contacts 1412, the relay R1410 completes another of the operating circuits for the counting chain release relay R870, this circuit extending by way of the grounded release conductor C893, the contacts 1412, C1166, the contacts 1126' and 1115, C887 and the winding of

R870 to battery. At its remaining contacts, the relay R1410 connects the ten lines associated therewith to the ten link lines respectively extending to the make contacts of the ten unit relays R1450, R1460, R1470, etc.

When energized over the circuit just traced, the counting chain release relay R870 operates to open, at its contacts 871, the series-locking circuit for the two relays R770 and R1240, causing both of these relays to restore. Upon restoring, the relays R770 and R1240 open, at their contacts 773 and 1243, respectively, two points in the previously traced operating circuit for the relay R1410 and, in so doing, interrupt the path short-circuiting the winding of the transfer relay R1110. The relay R1110 is thus energized in series with the connector group relay R1410 over a circuit which extends by way of the grounded release conductor C893, the winding of R1110, C1164, the contacts 1411 and the winding of R1410 to battery. Upon operating, the relay R1110 opens, at its contacts 1111, a further point in the previously traced path for transmitting dial tone current over the calling end of the connection. At its contacts 1112, the relay R1110 prepares a path for transmitting busy tone current over the calling end of the connection. At its contacts 1113, the relay R1110 opens the path shunting the operated contacts 1122 of the transfer relay R1120. At its contacts 1114, the relay R1110 opens the path shunting the operated contacts 1124 of the relay R1120. At its contacts 1117, the relay R1110 opens a further point in the above-traced operating circuit for the connector group relay R1410. At its contacts 116, the relay R1110 prepares a point in the common portion of the operating circuits for the ten unit relays embodied in the connector portion of the link. At its contacts 1115, the relay R1110 opens the completed circuit for energizing the counting chain release relay R870, causing the latter relay to restore. Following the release of the relay R870, the control apparatus of the link is conditioned to respond to the impulses comprising the third digit of the directory number designating the desired substation.

From the above explanation it will be understood that the numerical value of the second digit dialed at the calling substation determines the subgroup of lines which is to be selected and, hence, the connector group relay which is to be energized. More specifically, the operating circuits for the five connector group relays terminating the first fifty lines of the first 100-line group commonly include the portion of the operating circuit for the connector group relay R1410 which is traced above as extending from the grounded release conductor C893 to the lead C1226. From this point, the operating circuits for the first five connector relays branch through the contacts 1243, 1253, 1263, 1273 and 1283 to the conductors C1248, C1258, C1268, C1278 and C1288, respectively. From these conductors the circuits are carried through the break contacts 1353' to 1357', inclusive, to the operating leads individual to the five connector group relays under consideration. The operating circuits for the other five connector group relays terminating the remaining fifty lines of the first 100-line group are slightly different. These latter circuits commonly include a portion which extends from the grounded release conductor C893 by way of the contacts 753, 763 or 773, C786, the contacts 1101, 1117

and 1127, and the lead C1225. From this lead, these operating circuits branch through the contacts 1283, 1303, 1313, 1323 and 1333 of the sixth to tenth counting relays R1290, R1300, R1310, R1320 and R1330, respectively, to the conductors C1298, C1308, C1318, C1328 and C1338, respectively. From these conductors, the circuits are carried through the operated make contacts 1364 to 1368, inclusive, of the group select relay R1360 to the operating leads individual to the five connector group relays under consideration. Thus, it will be apparent that depending upon the setting of the impulse-counting chain at the end of the second digit, any one of the selected ten connector group relays may be energized.

As indicated above, the impulses of the third digit are utilized to select the particular desired line from the selected ten-line subgroup. In the case under consideration, wherein the line 219 is to be selected, it will be understood that the ninth counting relay R1320 is locked energized in series with its associated control relay R1750 at the end of the third digit. When the relays R1110, R1100 and R1160 restore shortly following the end of this digit, the operating circuit for the ninth unit relay R1460 is completed at the contacts 1101 and 1102. This circuit extends by way of the grounded release conductor C893, the contacts 1753, C1766, the contacts 1101, 1116, 1137 and 1102, C1223, the contacts 1322, C1327 and the winding of R1460 to battery. The relay R1460, upon operating, locks to ground over a path including the contacts 1462, C1163, the winding of R1130 and the grounded release conductor C893. When this path is completed, the relay R1130 is obviously short-circuited. At its contacts 1461, the relay R1460 completes another of the operating circuits for the counting chain release relay R870. This circuit extends from ground by way of the contacts 869, the grounded release conductor C893, the contacts 1461, C1165, the contacts 1135, C887 and the winding of R870 to battery. When energized over this circuit, the relay R870 operates to open the previously traced locking circuit for the two relays R1750 and R1320. When thus deenergized, the two relays R1750 and R1320 restore to open, at their contacts 753 and 1322, respectively, two points in the path short-circuiting the winding of the relay R1130. When this path is broken, the relay R1130 is energized in series with the unit relay R1460 over the locking path traced above. Upon operating, the relay R1130 opens its contacts 1135 to interrupt the operating circuit for the counting chain release relay R870, causing the latter relay to restore. At its contacts 1137, the relay R1130 opens a further point in the above-traced operating circuit for the unit relay R1460. At its contacts 1136, the relay R1130 prepares the operating circuit for the relay R1050. At its contacts 1133, the relay R1130 prepares the operating circuit for the relay R1000. At its contacts 1134, the relay R1130 prepares a circuit for energizing the switching-through relay R810. At its contacts 1131, the relay R1130 opens a point in the operating circuit for the busy test relay R1040. At its contacts 1132, the relay R1130 prepares a circuit, traced hereinafter, for energizing the slow-to-operate idle test relay R1070.

From the above explanation it will be understood that the numerical value of the third digit dialed at the calling substation or operator's

position determines the particular line of the selected subgroup which is to be selected and, hence, the connector unit relay which is to be energized. More specifically, the operating circuits for the ten unit relays commonly include the release conductor C893, the contacts 753, 763 or 773 of the counting chain control relays, C1766, the contacts 1101, the contacts 1116 and the contacts 1137. From this point the respective operating circuits for the ten unit relays are divided into two groups. Thus, the five unit relays representing the even-numbered lines are energized over circuits which commonly extend through the contacts 1137 by way of 15 C1224 to the contacts 1252, 1272, 1292, 1312 and 1332, respectively. From this point the circuits respectively extend by way of the conductors C1267, C1277, C1297 and C1317 and C1337 to the windings of the unit relays representing 20 the digits 2, 4, 6, 8 and 0. The unit relays designating the odd-numbered lines, on the other hand, are energized over operating circuits which extend from the contacts 1137 by way of the contacts 1102 and the conductor C1223 to the contacts 1242, 1262, 1282, 1302 and 1322. From these points the circuits respectively extend over the conductors C1247, C1267, C1287, C1307 and C1327 to the windings of the unit relays designating the lines 1, 3, 5, 7 and 9, respectively. From the above explanation it will be apparent that the particular unit relay which is energized depends entirely upon which of the counting relays is operated at the end of the third digit dialed at the calling substation or operator's position. It will further be noted that these relays all lock to the grounded release conductor C893 over a path including the conductor C1163 and the winding of the transfer relay R1130. Accordingly, the transfer relay 40 is in every case locked energized in series with the selected one of the unit relays. It will further be apparent that these relays include the contacts 1452, 1461, 1471, etc., which are connected in multiple in the above-traced alternative operating circuit for the counting chain release relay R870. Accordingly, this relay is energized in response to operation of any one of the ten unit relays shortly following the end of the third digit.

Busy test

As indicated in the above explanation, the transfer relay R1130, upon operating, opens a point in the operating circuit for the busy test relay R1040 and prepares a circuit for energizing the idle test relay R1070. A short interval occurs between the operation of the unit relay R1460 and the operation of this transfer relay. During this interval the called subscriber's line 219 is tested to determine the idle or busy condition thereof. In this regard it will be understood from the previous description that, if the called line 219 is busy, the private conductor 219c thereof is connected to ground, whereas if the line is idle, negative battery potential is impressed upon this conductor over a path including the winding of the cut-off relay embodied in the line circuit 25. Assuming that the line 219 is busy at the time it is selected, the relay R1460, upon operating, completes the prepared operating circuit for the busy test relay R1040, this circuit extending by way of the grounded release conductor 219c, the contacts 1416, C1483, the contacts 1465, C1162, the contacts 1131, C1076 and the lower winding of R1040 to battery. In operating, the relay

R1040 locks to ground over a path including the contacts 1044, C1075, the contacts 1144, C886, the contacts 842 and the grounded release conductor C883. At its contacts 1041 and 1043, the relay R1040 prepares a dry talking circuit to the selected line 219. At its contacts 1046, the relay R1040 opens a point in the operating circuit for the slow-to-operate idle test relay R1070. At its contacts 1047, the relay R1040 opens a point in the operating circuit for the switching-through relay R810. At its contacts 1048, the relay R1040 prepares a circuit for energizing the reverting call relay R840. At its contacts 1042, the relay R1040 completes a path for transmitting busy tone signal current over the calling end of the connection. This path extends from the busy tone current lead C1089 by way of the contacts 1042, C1073, the contacts 1112 and 1141, C845, the condenser 843 and the contacts 881, 884 and 813 to the negative side of the calling line. From this point the busy tone current is transmitted over the negative side of the calling line, through the receiver provided at the calling station, back over the positive side of the calling line through the contacts 811 and 802, the winding 835 and the winding of the relay R825 to the grounded terminal of the busy tone generator. The current transmitted over this circuit is reproduced by the receiver provided at the calling station to inform the calling subscriber or operator that the desired line is busy. Following operation of the busy test relay R1040 to perform the functions described above, no further operation of the apparatus occurs until the connection is released. The manner in which the switching equipment is restored to normal when the call is abandoned at the calling telephone station is explained in detail in a following portion of the specification.

Idle test

In the event the called line 219 is idle at the time it is selected in the manner pointed out above, the lower winding of the busy test relay R1040 is short-circuited over the test circuit and, accordingly, this relay does not operate. Shortly following the selection of the called line, the transfer relay R1130 operates to complete the above-mentioned circuit for energizing the slow-to-operate control relay R1070. This circuit extends from ground by way of the contacts 868 and 817, C885, the winding of R1070, C1083, the contacts 1046, C1082, the contacts 1132, C1162, the contacts 1468, C1483, the contacts 1416, the private conductor 219c of the called line 219, and the winding of the cut-off relay embodied in the line circuit 25 to battery. When thus energized, the relay R1070 and the cut-off relay of the line circuit 25 both operate. The latter relay, in operating, disconnects the windings of its associated line relay, not shown, from the conductors of the line 219, thereby to clear this line of the impedance represented by the line relay windings. Further, the application of ground potential to the private conductor 219c serves to mark the line 219 as busy in the relay contacts of the other connector switches. The relay R1070, upon operating, closes its contacts 1071 to complete a circuit including the grounded release conductor C883 for energizing the line-switching relay R1030. In operating, the relay R1030 locks through its X contacts 1033 to the grounded release conductor C883 and completes, at its contacts 1034, an obvious path for short-circuiting the winding of the slow-to-operate

control relay R1070, causing the latter relay to restore. At its contacts 1035, the relay R1030 prepares a point in the common portion of the three available operating circuits for the ring pickup relay R800. At its contacts 1037, the relay R1030 opens a point in the above-traced path for grounding the tone apparatus start conductor C895. At its contacts 1038, the relay R1030 prepares a circuit for impressing ground potential upon the ringing code interrupter start lead C108. At its contacts 1031 and 1032, the relay R1030 connects the line terminals of the repeating coil windings 837 and 838 by way of the link line conductors C847 and C849 and the operated line contacts of the unit and group relays R1460 and R1410 to the talking conductors of the line 219.

By virtue of the above-described arrangement whereby the repeating coil 834 is connected to the line 219, it is possible for an operator in the central office 5, for example, in setting up a delayed call connection, to seize the desired line and delay the ringing of the called substation until the ringing code-selecting digit is dialed. During this interval, if a subscriber served by the called line removes his receiver, the operator will receive answer supervision due to the action of the relay R800 which functions to reverse battery over the calling end of the connection. Thus, if during the interval between the dialing of the third and fourth digits, a subscriber at the substation C, for example, removes his receiver from its supporting hook or cradle, a loop circuit is established which extends from ground by way of the winding of the balancing coil 824, the repeater winding 837, C848, the contacts 951, C982, the contacts 1011 and 1031, C847, the contacts 1463, C1481, the contacts 1414, the positive side of the called line 219, the bridge across the conductors of the line 219 at the substation C, the negative side of the line 219, the contacts 1415, C1482, the contacts 1484, C849, the contacts 1032 and 1013, C983, the contacts 953, C848, the winding 838, C872 and the winding of R920 to battery. When energized over this circuit, the relay R920 operates to complete, at its contacts 921, an obvious circuit for energizing the relay R930. At its contacts 922, the relay R920 completes a circuit including the grounded conductor C287 and the contacts 826 for energizing the battery-reversing relay R800. In this regard it will be recalled from the preceding explanation that in handling calls involving calling trunk lines and calling subscribers lines arranged for common battery loop operation, the line relay R825 is energized in series with the line relay R820 and, accordingly, occupies its operated position. On the other hand, when calls are initiated on subscribers lines of the ground return type, the line relay R825 is short-circuited and, accordingly, the operating circuit for the battery-reversing relay R800 is held open at the contacts 826. It will also be understood that if the "L" wiring illustrated in Fig. 2 of the drawings is used and the calling line is included in a subgroup of lines terminating at a finder group relay not having the "L" wiring arrangement, the lead C287 is open circuited. Accordingly, the battery reversing relay R800 will not be energized in response to operation of the back bridge relay R920, regardless of the position of the line relay R825. In the case under consideration, the operation of the relay R930 is without effect. The relay R800, upon operating, locks to ground over a path including the con-

tacts 805, C884, the contacts 822 and the grounded conductor C237. At its contacts 801 to 804, inclusive, the relay R800 reverses the direction of current flow over the calling end of the connection. This current reversal is utilized in the two-way repeater 6 for the purpose of causing the operation of a supervisory relay embodied therein, with the result that the direction of current flow over the loop circuit established between this repeater and the trunk circuit terminating the trunk 30 in the central office 5 is reversed. A supervisory relay is also incorporated in this trunk circuit, which relay functions to energize a signal lamp provided at the calling operator's position. Thus, the arrangement of the finder-connector link is such that if a call is routed from an operator's position to a subscribers line and a second call is initiated on this line before the called substation is signaled, the calling operator will receive an answer signal, and a communication connection will be established between the calling operator's position and the substation at which the second call is initiated.

Selecting the ringing code

As pointed out previously, the fourth digit dialed at the calling substation is utilized for the purpose of selecting the code of the ringing current corresponding to the desired substation. In this regard it will be apparent that the impulse-counting equipment and, more particularly, the counting chain illustrated in Figs. 12 and 13 of the drawings, operates in the exact manner previously described in response to the impulses of the fourth digit.

The numerical value of the fourth digit not only determines the code of the ringing current but, in addition, is utilized to select the side of the called line over which ringing current will subsequently be transmitted. In this regard it is pointed out that with respect to those lines arranged for twenty-party code ringing, the bridged type of ringing is used in all cases. When using this type of ringing, the numerical value of the fourth digit determines which code of the selected subgroup of ten codes will be used in signaling over the called line, the subgroup of codes having been previously selected in response to the impulses of the first digit. On the other hand, if the called subscribers line is arranged for ten-party code ringing, either the bridged or divided type of ringing may be used. If the line is arranged for bridged ringing, the numerical value of the fourth or code-selecting digit is of no consequence aside from the determination of the ringing code. On the other hand, if the called line is arranged for divided ringing, the fourth digit is also utilized to determine the side of the line over which the ringing current will subsequently be projected. More specifically, if a fourth digit comprising from one to five impulses is dialed at the calling substation, the ringing control apparatus is conditioned to transmit ringing current over the negative side of the selected line. If a fourth digit comprising from six to ten impulses is dialed, the ringing control equipment is conditioned to transmit ringing current over the positive side of the selected line.

If it be assumed, for example, that the substation C is desired by the calling party; that the line 219 is arranged for ten-party divided ringing; that the ringer provided at the called substation C is connected between the positive side of the line 219 and ground; and that the ringing

code assigned to this substation corresponds to the code of the voltage pulses impressed upon the ringing interrupter lead C1299, a fourth digit comprising six impulses will necessarily be dialed at the calling telephone station. It will be recalled that under the assumptions made, a first digit of two impulses is dialed at the calling substation so that at the conclusion of this digit the relay R1200 is locked operated for the duration of the call. Accordingly, at the end of the digit, the relay R1290 is locked energized in series with its associated control relay R750. When the relay R1290 operates, it completes the prepared operating circuit for the transfer relay R1000, this circuit extending by way of the grounded release conductor C893, the contacts 1291' and 1204, C1219, the contacts 1133, C1077 and the winding of R1000 to battery. When thus energized, the relay R1000 operates and locks to the grounded release conductor C893 over a path including the contacts 1005. At its contacts 1001 to 1004, inclusive, the relay R1000 arranges the ringing circuit for the transmission of ringing current over the positive side of the selected line.

When the relays R1150, R1100 and R1160 sequentially restore shortly following the end of the digit, a circuit is completed at the contacts 1101 for energizing the relay R1050. This circuit extends by way of the grounded release conductor C893, the contacts 753, C786, the contacts 1101, 1116 and 1136, C1079, the contacts 1054 and the winding of R1050 to battery. In operating, the relay R1050 locks to the grounded release conductor C893 through its contacts 1053 and then opens a point in its operating circuit at its contacts 1054. At its contacts 1051 and 1052, the relay R1050 completes obvious paths in shunt with the resistors 1038 and 1039, respectively. At its contacts 1056, the relay R1050 opens a point in the above-traced circuit for delivering current pulses to the relays R1100 and R1150, and the relays of the counting chain illustrated in Figs. 12 and 13 of the drawings. At its contacts 1057', the relay R1050 opens one of the completed multiple paths over which ground potential is impressed upon the ringing generator start conductor C1167. At its contacts 1058, the relay R1050 prepares a locking circuit for the reverting call relay R840. At its contacts 1058', the relay R1050 connects the leads C1228 and C1229 together, thereby to associate the ten ringing interrupter leads with the ringing control relay R1010. At its contacts 1059, the relay R1050 completes a path for impressing ground potential upon the ringing interrupter start lead C789, this path extending from ground by way of the contacts 1036 and 1059, C778 and the contacts 752 to the start lead C789. When this lead is grounded, operation of the ringing interrupter 1395 is initiated, providing this unit, which is common to the exchange, is not already in operation. At its contacts 1055, the relay R1050 prepares an alternative locking circuit for the hold relay R860. At its contacts 1057, the relay R1050 prepares another point in the common portion of the three operating circuits for the ringing control relay R960. Following operation of the relay R1050, the transmission of coded ringing current over the called line 219 is started. As pointed out in the general description of the apparatus, the ringing interrupter 1395 is of the well-known all-relay type and functions to impress differently coded ground pulses upon the ten interrupter leads C1249, C1259, C1269, etc., during each cycle of operation thereof. At the

beginning of each cycle of its operation, the interrupter 1395 impresses a negative battery pulse upon each of the two pick-up leads C1215 and C1221. In the case under consideration, the relay R960 is energized in response to the first negative battery pulse impressed upon the first pickup lead C1215 following energization of the relay R1050. More specifically, the relay R960 is energized over a circuit which extends from the grounded release conductor C883 by way of the contacts 753, C786, the contacts 1057, C991, the contacts 924, the upper winding of R960, C992, the contacts 1035, C991, the contacts 963, C993 and the contacts 1261 to the negative terminal of the exchange battery as connected to the pickup lead C1215 through the contacts of the coding relays embodied in the ringing interrupter 1395. When thus energized, the relay R960 operates and completes a locking circuit for itself, this locking circuit extending by way of the grounded release conductor C883, the contacts 753, C786, the contacts 1057, C991, the contacts 924, the upper winding of R960, C992, the contacts 1035, C991, the contacts 962 and 917, and the hold lead C883 to the negative terminal of the exchange battery as connected to the hold lead C883 through the contacts of the coding relays included in the interrupter 1395. After this circuit is completed, the relay R960 opens its contacts 963 to interrupt its operating circuit as traced above. At its contacts 965, the relay R960 prepares an alternative path for grounding the tone apparatus start conductor C895. At its contacts 961, the relay R960 prepares an auxiliary path for transmitting dial tone current over the calling end of the connection. At its contacts 964, the relay R960 further prepares the operating circuit for the ringing relay R1010.

Following operation of the pickup relay R960, the ringing relay R1010 operates each time ground potential is impressed upon the selected ringing interrupter lead. In the case under consideration, this relay is energized each time the interrupter lead C1299 is grounded by the coding relays of the ringing interrupter 1395. The circuit for energizing the relay R1010 extends by way of the grounded lead C1299, the contacts 1284, C1228, the contacts 1058, the winding of R1010, C996 and the contacts 964 to battery. It will be apparent that nine similar circuits are prepared following operation of the relay R960, which circuits individually include the make contacts 1244, 1256, 1264, etc., of the nine other counting relays. Accordingly, the operation of the relay R1010 is determined in accordance with the one of the counting relays which remains operated at the end of the fourth digit. In this regard it is pointed out that the odd-numbered interrupter leads C1249, C1269, C1289, etc., are arranged to deliver ground pulses to the ringing relay R1010 over a circuit commonly including the conductor C1229, whereas the even-numbered interrupter leads C1259, C1279, C1299, and so on, are arranged to deliver ground pulses to the ringing control relay over the lead C1228.

In the case under consideration, the relay R1010 functions to transmit ringing current over the positive side of the called line 219 each time it operates. The path traversed by the ringing current depends upon the type of wiring used in the link. Thus, if the link is to be arranged for instantaneous ring cut-off when the called party answers, the "K" wiring and associated apparatus is used. With this wiring arrangement, the ringing current traverses a circuit

which extends from one terminal of the ringing current generator by way of the winding of the slow-to-operate relay R980, C984, the contacts 1002, 1012 and 1031, C847, the contacts 1463, C1481, the contacts 1414, the positive side of the line 219 and through the windings of the ringer provided at the substation C to ground. From this point, the ringing current is transmitted over a ground return path and through the exchange battery to the opposite terminal of the ringing current generator. Portions of the ringing current are by-passed through the ringers bridged between the positive side of the line 219 and ground, and provided at other substations served by this line. The coded character of the signals produced by these ringers indicates, however, that only the substation C is being called.

In the event the link is to be arranged so that the ring cut-off operation occurs only during a silent interval following the answering of a call, the "J" wiring illustrated in Fig. 9 of the drawings is used, in which case the ringing current traverses the filament of the lamp 928 rather than the winding of the relay R980. In this case also, the relay R980, the relay R1060 and the circuits associated with these relays are omitted from the link wiring.

In order to complete the explanation pertaining to the different types of ringing which may be used, it is pointed out that if the fourth or code-selecting digit comprises less than six impulses, the previously traced operating circuit for the relay R1000 is not completed and, accordingly, this relay occupies its restored position during the ringing operation. With the relay R1000 de-energized, ringing current is transmitted over the negative side of the selected line. Thus, if the code designating the called substation C corresponds to the ground pulses impressed upon the ringing interrupter lead C1269, the counting relay R1268 will be operated at the end of the code-selecting digit so that the ringing relay R1010 is energized in accordance with the ground pulses impressed upon the lead C1269. In this case, the ringing current traverses a circuit which extends from one terminal of the ringing current generator through the winding of the relay R980 or the filament of the lamp 928, depending upon the type of wiring used, and by way of C984, the contacts 1003, 1014, and 1032, C849, the contacts 1464, C1482, the contacts 1415, the negative side of the line 219 and through the windings of the ringers bridged between this side of the line 219 and ground. From this point, the ringing current is transmitted over a ground return path and through the exchange battery to the other terminal of the ringing current generator. From the foregoing explanation it will be understood that, depending upon the number of impulses of the fourth digit, the relay R1000 will be energized or deenergized to determine the side of the line over which ringing current is projected.

It will be recalled from the preceding explanation that, if a called subscribers line is arranged for twenty-party code ringing, a first digit comprising four or five impulses is dialed and, depending upon the numerical value of the digit, one of two groups of ringing codes is selected. Thus, if a first digit of four impulses is dialed, the relay R1360 is operated and the relay R1210 is restored. On the other hand, if a first digit of five impulses is dialed, both the relays R1210 and R1360 are operated. It will be observed that in neither case is the relay R1200 operated. Ac-

cordingly, the operating circuit for the relay R1000 is held open at the contacts 1204, and this relay has no function when the twenty-party type of code ringing is used. With the relay R1210 in its restored position, the pickup relay R960 is, at the beginning of a ringing operation, energized over a circuit which extends from the grounded release conductor C893 by way of the contacts 753, 763 or 773, C786, the contacts 1057, C997, the contacts 924, the upper winding of R960, C992, the contacts 1035, C991, the contacts 963, C998, the contacts 1211, C1216 and the contacts 1362 to the first pickup lead C1215. When thus energized, the pickup relay R960 operates to perform the functions described above. Following the operation of this relay, the ringing relay R1010 operates in accordance with the ground pulses impressed upon the selected one of the interrupter leads C1247, C1257, C1267, etc., to complete a circuit for transmitting ringing current through the windings of the ringers bridged across the called line. Thus, if the line 219 is arranged for this type of ringing, the ringing current traverses a circuit which may be traced as extending from the ungrounded terminal of the ringing current generator by way of the winding of R980 or the filament of the lamp 928, C984, the contacts 1003, 1014 and 1032, C849, the contacts 1464, C1482, the contacts 1415, the negative side of the line 219, the ringers bridged across the conductors of this line, the positive side of the line, the contacts 1414, C1481, the contacts 1463, C847, the contacts 1031, 1012 and 1001, and the exchange battery to the other terminal of the ringing current generator. The coded character of the signals, produced by the ringers bridged across the line 219 and provided at the substations served by this line, indicates which substation is being called.

As pointed out in the general description of the system, the arrangement of the ringing interrupter 1395 is such that the two groups of ringing codes are substantially similar. More specifically, the codes of the second group are differentiated from those of the first group by the addition of a short ring at the beginning of each ringing or code cycle. This is accomplished by wiring the interrupter in a well-known manner so that the pickup hold lead C883 is disconnected from ground at the end of each code cycle, and by arranging the coding relays so that the battery pickup pulse is not impressed upon the first pickup lead C1215 until after the periods of each ringing code during which the short or preliminary ring ground pulses are concurrently applied to the ten ringing interrupter leads. Thus, the pickup relay R960 is, in all cases, deenergized to open, at its contacts 964, the operating circuit for the ringing relay R1010 at the end of each code cycle, and is reenergized by the application of a battery pulse to the pickup lead C1215 or C1227 in use at an appropriate point in the next succeeding code cycle. Thus, by eliminating the short or preliminary ring battery pulses from the first pickup lead C1215, the short rings are not included in the codes of the first group. In the case under consideration, wherein a ringing code of the first group is selected, it will be understood that the called substation is signaled by using a code from which the short or preliminary ring is eliminated.

As indicated above, in the event the code designating a desired substation is included in the second group of ten codes, the relays R1210 and R1360 are both locked energized at the end of the first digit of five impulses dialed at the calling

substation. Accordingly, the pickup relay R960 is, during the ringing operation, energized over a circuit including the second pickup lead C1227. More particularly, the operating circuit for the relay R960 extends from the grounded release conductor C893 by way of the contacts 153, 163 or 173, C786, the contacts 1057, C997, the contacts 924, the upper winding of R960, C992, the contacts 1035, C991, the contacts 963, C998, the contacts 1212, the second pickup lead C1227 and through the contacts of the coding relays embodies in the ringing interrupter 1395 to the negative terminal of the exchange battery. When thus energized, the relay R960 operates and locks to the negative terminal of the exchange battery over the previously traced path including the locking lead C883. With the circuit arranged in this manner, the relay R960 is deenergized in response to removal of battery potential from the locking lead C883 at the end of each code cycle, and is subsequently reenergized at the beginning of the next succeeding cycle through the application of another pickup pulse to the second pickup lead C1227. It will be noted that, each time the relay R960 restores, it opens, at its contacts 964, the operating circuit for the relay R1010 so that the latter relay will not be energized by ground pulses applied to a selected one of the ringing interrupter leads. In this case, however, the pickup pulse applied to the second pickup lead C1227 at the beginning of each code cycle precedes the interval during which the short ring ground pulses are concurrently impressed upon the ten ringing interrupter leads. Accordingly, the pickup relay R960 is energized and operates to prepare the circuit for energizing the ringing relay R1010 before the preliminary or short ring period of each code cycle starts. The manner in which ringing current is transmitted over the called line each time the relay R1010 operates, in response to a ground pulse applied to the selected ringing interrupter lead, is exactly the same as described above with reference to the signaling of a called substation designated by a code of the first ten-code group.

Regardless of the type of ringing employed in signaling a particular station, or the code of the signaling current used, a portion of the ringing current is transmitted back over the calling end of the connection so that the usual ringback tone signal is produced by the receiver provided at the calling telephone station. Thus, each time the ringing relay R1010 operates, it completes a path which extends from the ungrounded terminal of the ringing current generator by way of the contacts 1015, C985, the condenser 926, C873 and the contacts 804 and 813 to the negative side of the loop circuit including the calling line. From this point, the ringing current is transmitted through the receiver provided at the calling station back over the positive side of the calling loop circuit and through the exchange battery to the other terminal of the ringing current generator. The resulting operation of the receiver provided at the calling station serves to inform the calling party or operator that the called substation is being rung. Each time the ringing relay R1010 operates, it also functions to complete, at its contacts 1016, a circuit including the conductor C987 for energizing the slow-to-release relay R950. The relay R950, upon operating, prepares, at its contacts 952, a path for connecting the positive side of the called line 219 to ground. At its contacts 954, the relay R950 prepares a path including the resistor 927 for connecting the

negative side of the line to the negative terminal of the exchange battery. The purpose of this arrangement is to provide a low resistance path including the exchange battery and the resistor 927 for draining the called line of any charge accumulated thereon during the preceding ringing interval. Thus, each time the ringing relay R1010 restores at the end of a ringing period, it completes, at its contacts 1011 and 1013, the two paths mentioned above, whereby the exchange battery is connected in series with the resistor 927 across the two conductors of the called line to provide a low resistance path for dissipating any accumulated charge on this line. In releasing, the relay R1010 also opens the above-traced operating circuit for the slow-to-release relay R850. The latter relay, accordingly, restores after a short interval determined by its release period. It is during this interval that the line is drained of any accumulated charge.

The call is answered

The desired conversational circuit between the calling and called substations is completed when the call is answered at the called substation associated with the selected line 219. More specifically, if the "K" wiring illustrated in the drawings is used, the ringing operation is terminated and the desired conversational circuit is completed instantly following the answering of the call at the called substation. Thus, if the call is answered at the substation C, for example, a direct current bridge is connected across the conductors of this line so that the relay R980 is energized over a circuit substantially identical with the bridged ringing circuit traced above. When thus energized, the slow-to-operate relay R980 operates to complete a circuit including the contacts 981 and the conductor C990 for energizing the slow-to-operate relay R1060. The relay R1060, in operating, locks to the grounded release conductor C893 through its contacts 1061, and, at its contacts 1062, completes another circuit for energizing the counting chain release relay R870. This latter circuit extends from ground by way of the contacts 751, 761 or 771, C896, the contacts 1062 and the "K" wiring associated therewith, C897 and the winding of R870 to battery. When thus energized, the relay R870 operates to open, at its contacts 871, the established series-locking circuit for the operated one of the counting relays and its associated control relay, causing both of these relays to restore. The operated counting relay, upon releasing, disconnects the selected ringing interrupter lead from the parallel-connected conductors C1223 and C1224, thereby to open a point in the operating circuit for the ringing control relay R1010. Thus, the relay R1010 is deenergized and restores. In releasing, the operated one of the three counting chain control relays R750, R760 and R770 opens, at its upper make contacts, the completed path for impressing ground potential upon the ringing generator start lead C1167 and, in so doing, interrupts the above-traced operating circuit for the counting chain release relay R870. Thus, the relay R870 is deenergized and restores. The relay R1010, upon restoring, completes the previously traced circuit for energizing the back-bridge relay R920 in series with the line balancing coil 824.

In the event the "J" wiring illustrated in the drawings is used in lieu of the "K" wiring, the circuit for energizing the back-bridge relay R910 is not completed until the ringing interval in progress at the time the call is answered termi-

nates. In such case, the relay R1010, in releasing to terminate the ringing period in progress at the time the call is answered, completes, at its contacts 1011 and 1013, the previously traced circuit for energizing the back-bridge relay R920. In this case, the operated relay of the counting chain and its associated control relay are not deenergized instantly following the answering of the call for the reason that the relays R980 and R1060 are not provided.

In either case, the relay R920, upon operating, completes, at its contacts 822, the previously traced circuit for energizing the battery-reversing relay R800, assuming that the calling line is of the metallic type arranged for loop operation. In this regard it will be recalled from the above explanation that, in the event the calling line is of the ground return type, the relay R825 occupies its restored position and, accordingly, the operating circuit for the battery-reversing relay R800 is held open at the contacts 826 for the duration of the call. In the event the relay R800 is energized in response to operation of the back-bridge relay R920, it functions to reverse the direction of current flow over the calling loop circuit in the manner set forth above.

At its contacts 824, the relay R920 opens a point in the common portion of the previously traced operating circuits for the pickup relay R980. At its contacts 823, the relay R920 completes a circuit for energizing the counting chain release relay R870, this circuit extending by way of the grounded release conductor C893, the contacts 753, 763 or 773, C786, the contacts 1051, C997, the contacts 923, C887 and the winding of R870 to battery. When thus energized, the relay R870 operates to initiate the release of the impulse-counting equipment in the manner previously explained. During the release of this equipment, the operated one of the three relays R750, R760 and R770 restores to open, at its contacts 753, 763 or 773, the above-traced operating circuit for the counting chain release relay R870, causing the latter relay to restore. At its contacts 921, the relay R920 completes a circuit including the grounded release conductor C893 for energizing the relay R930. The operation of this relay is without effect on a call of the character under consideration.

Following the relay operations just described, the desired conversational circuit between the calling and called substations is completed by way of the link illustrated. In this regard it will be noted that talking battery is impressed upon the calling end of the connection through the windings of the line relays R820 and R825. Talking battery is impressed upon the called end of the connection through the winding of the balancing coil 824 and the winding of the back-bridge relay R920.

Release

The release of a connection established in the manner set forth above is primarily under the control of the calling party. Thus, if the called party is the first to restore his receiver to its supporting hook or cradle, the loop circuit extending to the called substation is interrupted with the result that the two relays R920 and R930 are sequentially deenergized and restore. In releasing, the back-bridge relay R920 also functions to open, at its contacts 822, the operating and locking circuits for the battery-reversing relay R800, causing the latter relay to release, if operated. The relay R800, in releasing, reverses the

direction of current flow over the conductors of the calling line. In the event the call under consideration is a central office trunk call routed by way of the trunk 30, for example, this current reversal may be utilized for the purpose of causing the energization of a supervisory signal lamp provided at the position of the operator handling the call in the central office 5, whereby the operator is informed that the connection is ready to be released. In this regard it will be apparent that the called subscriber may recall the operator in the central office 5 in a well-known manner by operating the switchhook provided at the called substation up and down a number of times to cause the repeated operation and release of the three relays R920, R930 and R800, whereby a flashing recall signal is produced by the supervisory signal lamp provided at the position of the operator handling the call in the central office 5. When this signal is received, the operator may enter the connection and converse with the called subscriber for the purpose of ascertaining the service desired. As contrasted with the flashing recall signal, the release of the connection at the called substation results in the continuous energization of the supervisory signal lamp provided at the position of the operator handling the call in the central office 5. Following the release of the relays R920 and R930, and the relay R800, if operated, no further operation of the apparatus occurs until the connection is cleared out at the calling telephone station. More specifically, when the calling loop circuit is interrupted at a calling substation or in the repeater 6, for example, the relays R820, R830, R840, R850 and R860 are deenergized and sequentially restore in the order named and in the manner previously explained. The relay R825, if operated, is also deenergized and restores in response to interruption of the calling loop circuit. The relay R860, in restoring, opens, at its contacts 865, a point in the common portion of the previously traced locking circuits for the relays embodied in the finder portion of the link. Thus, the operated finder unit and group relays are deenergized and restore. Since the subgroup relay R270 is also arranged to be locked energized over a circuit including the locking lead C235, this relay, if operated, is also deenergized and restores in response to the release of the hold relay R860. Thus, the finder end of the link is fully restored to normal. During the release of this portion of the link, the private conductor of the calling line, such, for example, as the conductor 215c of the line 215, is disconnected from ground. The path for impressing ground potential upon this conductor is initially opened at the contacts 852 in response to the release of the relay R850. When this conductor is thus open-circuited, the cut-off and lock-out relays, such, for example, as the relays R110 and R105, of the line circuit associated with the calling line, are deenergized and restore in an obvious manner. Further, the removal of ground potential from the private conductor of the calling line permits negative battery potential to be impressed upon this conductor through the windings of the cut-off and lock-out relays embodied in the line circuit associated with the calling line, whereby the line is marked as idle in the relay contacts of the various connector switches.

The relay R860, upon restoring, also completes, at its contacts 863, a point in the previously traced operating circuit for the link distributor relay R100 corresponding to the link illustrated.

Thus, the link is identified in the distributor illustrated in Fig. 7 of the drawings as being in an idle condition.

- At its contacts 869, the relay R860 disconnects the release conductor C893 from ground. In response to this operation, all of the relays which are locked up over holding circuits including the release conductor are deenergized and restore. Thus, if the call is successfully completed in the manner explained above, the relays R1030, R1060, R1110, R1120, R1130, R1410 and R1460 are all deenergized in response to the removal of ground potential from the release conductor C893. Further, the operated ones of the relays R1200, R1210, R1350 and R1360 are obviously deenergized when the release conductor C893 is disconnected from ground. When these relays are all released, the link illustrated is fully restored to normal.
- It will be understood from the above explanation that in the event the connection is cleared out at the calling telephone station prior to the release thereof at the called substation, the back-bridge relay R920 is deenergized and restores when the relays R1030, R1460 and R1410 restore to open the loop circuit extending to the called substation.

The manner in which a connection routed to a busy called subscribers line is released under the control of the calling party is substantially similar to the release of the connection as described above. In this case, the busy test relay R1040 is operated at the time the call is abandoned. This relay is deenergized and restores in response to the release of the hold relay R860 to disconnect holding ground potential from the release conductor C893.

In the event a call is abandoned before it is completely set up, or is abandoned after the ringing operation is started but before the call is answered, the impulse-counting equipment illustrated in Figs. 7, 12 and 13 of the drawings, is released in the manner previously explained in response to the removal of ground potential from the release conductor C893.

During the release of the connector end of the link, the relays R1130, R860, R1410 and R1460 function to open points in the previously traced path for impressing ground potential upon the private conductor 219c of the called line 219. When this conductor is disconnected from ground, the cut-off and lock-out relays embodied in the line circuit 25 are deenergized and restore in a manner clearly apparent from the preceding explanation with reference to the line circuits 10 and 15. Following the release of these relays, negative battery potential is impressed upon the private conductor 219c of the line 219 to mark this line as idle in the relay contacts of the various connector switches having access thereto. Thus, all of the equipment involved in setting up the connection is fully restored to normal.

65 Selecting a called subscribers line in the "300"-line group

As indicated above, if a subscribers line in the "300" group of one hundred lines is to be selected, a first digit of three impulses is dialed at the calling telephone station. Accordingly, at the end of the digit the third counting relay R1260 is locked energized in series with the third control relay F150. When the relays R1150, R1160 and R1160 restore shortly following the end of the digit, an alternative circuit is com-

pleted for energizing the control relay R1200. This circuit extends by way of the grounded release conductor C893, the contacts 753, C786, the contacts 1101, 1117, 1128 and 1104, C1221, the contacts 1261 and the lower winding of R1200 to battery. When thus energized, the relay R1200 operates to complete a circuit including the contacts 1203 and C1218 for energizing the relay R1350. At its contacts 1204, the relay R1200 prepares the operating circuit for the relay R1000. At its contacts 1202, the relay R1200 prepares a circuit for energizing the relay R1360. At its contacts 1201, the relay R1200 prepares the above-traced circuit for energizing the ringing control relay R960 in accordance with the negative battery pulses impressed upon the first pick-up lead C1215 by the ringing interrupter 1395.

The relay R1350, in operating, completes, at its contacts 1352, a holding circuit for itself and the relay R1200. This circuit extends by way of the grounded release conductor C893 and the winding of R1120 to C1080 where it divides, one branch extending through the contacts 1352 and the winding of R1350 to battery; and the second branch extending by way of the contacts 1352, C1218, the contacts 1203 and the lower winding of R1200 to battery. When this circuit is completed, ground potential is impressed upon both winding terminals of the transfer relay R1120 and, accordingly, this relay is short-circuited. At its contacts 1353 to 1357, inclusive, the relay R1350 prepares the operating circuits individually extending to the five group relays terminating the five subgroups of lines assigned the directory numbers 310 to 360, inclusive. At its break contacts 1353' to 1357', the relay R1350 opens the normally prepared operating circuits for the five group relays terminating the five subgroups of lines assigned the directory numbers 210 to 260, inclusive. In this regard it will be noted that the five group relays terminating the lines forming the other five ten-line subgroups and assigned numbers in the "300" directory number series, are prepared at the break contacts 1364' to 1368', inclusive, of the restored relay R1360. Further, the operating circuits for the other five group relays terminating lines assigned the directory numbers 261 to 200, inclusive, are held open at the restored make contacts 1364 to 1368, inclusive, of the restored relay R1360. Thus, the group relay operating circuits are conditioned for the energization of one of the ten connector group relays terminating the subscribers lines assigned directory numbers in the "300" number series.

The relay R1350, in operating, also completes, at its contacts 1351, an alternative circuit for energizing the counting chain release relay R870, this circuit extending from ground by way of the contacts 1351, C1086, the contacts 1126, C887 and the winding of R870 to battery. When thus energized, the relay R870 operates to open, at its contacts 871, the previously traced locking circuit for the series-connected relays R750 and R1260, causing both of these relays to restore. Thus, the impulse-counting equipment is conditioned to respond to the impulses of a second digit. Upon restoring, the relay R1260 opens, at its contacts 1261, the above-traced operating circuit for the relay R1200. The relay R750, upon restoring, opens, at its contacts 753, the previously described path short-circuiting the winding of the relay R1120, permitting the latter relay to be energized in series with the parallel-connected relays R1350 and R1200. When thus

energized, the relay R1120 operates to open, at its contacts 1126, the above-traced alternative operating circuit for the counting chain release relay R870. The relay R870 is thus deenergized and restores. In operating, the relay R1120 performs the other functions described previously in connection with the selection of the line 219.

Following the operation of the relay R1120, the control apparatus of the link is conditioned to respond to the impulses comprising the second digit of the directory number designating the desired substation. If it be assumed, for example, that the desired line is the eighth line of the fourth subgroup of lines in the larger group of one hundred lines having assigned directory numbers in the "300" series, the second and third digits dialed at the calling telephone station will comprise four and eight impulses, respectively. The manner in which these impulses are utilized to control the relays of the counting chain illustrated in Figs. 12 and 13 of the drawings, is exactly the same as described previously. In this regard it will also be understood that the three relays R1150, R1160 and R1170 operate at the beginning of the first impulse of the second digit and remain operated until shortly after the digit is ended. In the case assumed, the fourth counting relay R1270 is locked energized in series with its associated control relay R1170 at the end of the second digit. Accordingly, when the relays R1150, R1160 and R1170 sequentially restore shortly following the end of the digit, a circuit is completed for energizing the connector group relay which terminates the ten lines forming the fourth subgroup of the selected 100-line group. This circuit may partially be traced as extending from ground by way of the contacts 869, the release conductor C893, the contacts 773, C786, the contacts 1101, 1117, 1127 and 1103, C1226, the contacts 1273, C1278, the contacts 1356, C1278' and the winding of the indicated connector group relay to battery. It will be understood that if the desired line is included in another of the ten-line subgroups of the second group of one hundred lines, the corresponding group relay is operated in accordance with the setting of the counting relay chain. Thus, the five connector group relays terminating the first five subgroups of lines in this 100-line group are energized over circuits commonly including the portion of the above-traced circuit which extends to the conductor C1226. From this point the various group relay operating circuits branch through the contacts 1243, 1253, 1263, 1273 and 1283 of the counting relays, over the leads C1248, C1258, C1268, C1278 and C1288, and through the contacts 1353, 1354, 1355, 1356 and 1357 to the operating leads of the indicated group relays. The circuits for energizing the connector group relays terminating the other five subgroups of lines in the second 100-line group are slightly different. These latter circuits commonly include a portion which may be traced as extending from the grounded release conductor C893 by way of the contacts 753, 763 or 773, C786, the contacts 1101, 1117 and 1127, and the lead C1225. From this lead the operating circuits for the last-mentioned connector group relays branch through the contacts 1293, 1303, 1313, 1323 and 1333 to the leads C1298, C1308, C1318, C1328 and C1338. From these leads the operating circuits are individually carried through the break contacts 1364' to 1368', inclusive, of the restored relay R1360 to the operating windings of the indicated group relays. From the above explana-

tion it will be apparent that depending upon the setting of the counting relay chain at the end of the second digit dialed at a calling substation or at an operator's position in the central office 5, the connector group relay terminating any line assigned a directory number of the "300" series may be energized.

Continuing now with the specific case under consideration, when the connector group relay terminating the fourth subgroup of lines of the second 100-line group operates, it functions in the manner previously explained to impress ground potential upon the conductor C1166 and thus energize the counting chain release relay R870. This relay, in operating, restores the impulse-counting equipment to normal, following which it is itself released, all in the manner described above. During these operations the relay R1110 is locked energized in series with the operated connector group relay in the manner described above.

From this point on, the manner in which the called line is selected from the selected subgroup of ten lines; the called line is tested to determine the idle or busy condition thereof; the desired ringing code is selected; the desired substation is signaled; and the connection is released, is exactly the same as described previously with reference to the call routed to the subscribers line 219.

BUSY LINE VERIFICATION

Provisions are made whereby the operators in the central office 5 having access to the switching equipment illustrated in the drawings over the two-way trunks connecting the central office with this switching equipment, may establish talking circuits to busy lines. The purpose of this arrangement is to enable the central office operators to ascertain whether or not a desired line is actually busy. If desired, the arrangement for this purpose may also be used for toll offering purposes. The manner in which a call of this character may be routed over the trunk 30 and through the finder portion of the link illustrated to the connector portion of this link, has already been considered. From this explanation it will be recalled that when the connect relay R290 operates, a circuit is completed for energizing the relay R1020. Assuming that the call is initiated on the trunk 30, this circuit, when completed, extends from ground by way of the contacts 542 and 562, C574, the contacts 601, the trunk call identification lead C681, the contacts 298, C236 and the upper winding of R1020 to battery. When thus energized, the relay R1020 operates to prepare a locking circuit for itself which includes the contacts 1025 and the release conductor C893. This locking circuit is completed shortly thereafter in response to operation of the hold relay R860 to impress ground potential upon the release conductor C893. In operating, the relay R1020 prepares, at its contacts 1024, an alternative circuit for energizing the battery-reversing relay R800. At its contacts 1021, the relay R1020 opens a point in one of the operating circuits for the link release relay R900. At its contacts 1022, the relay R1020 opens a point in one of the locking circuits for the relay R860. At its contacts 1025, the relay R1020 also prepares one of two possible operating circuits for the right-of-way control relay R1340 and a point in the locking circuit for the verification relay R1140.

The circuit for energizing the relay R1340 is 75

completed in response to operation of the hold relay R860 and the finder group relay R290. This circuit extends from ground by way of the contacts 869, the release conductor C893, the contacts 1025, C238, the contacts 253, C239 and the winding of R1340 to battery. Upon operating, the relay R1340 prepares the operating circuit for the connector group relay R1400, having contacts at which the central office trunk lines are terminated. Following the relay operations just described, the control equipment of the link is conditioned to respond to the impulses constituting the digits of the directory number designating the desired line.

15 In order to obtain access to the desired busy line, it is necessary for the calling operator to dial a prefix digit comprising one impulse before dialing the remaining digits constituting the directory number assigned to the desired line. The 20 manner in which the control equipment responds to the single impulse of this prefix digit is exactly the same as set forth previously. At the end of the digit, the first counting relay R1240 is locked energized in series with its associated control relay R770. When the relays R1150, R1160 and R1160 restore shortly following the 25 end of this digit, a circuit is completed for energizing the lower winding of the verification relay R1140 in series with the counting release relay R870. This circuit extends by way of the grounded release conductor C893, the contacts 1173, C786, the contacts 1101, 1117, 1128 and 1104, C1221, the contacts 1241, C1214, the lower winding of R1140, C887 and the winding of R870 to 30 battery. When thus energized, the relay R1140 operates to complete, at its X contacts 1146, the prepared locking circuit for itself. This circuit extends by way of the grounded release conductor C893, the contacts 1025, C238, the contacts 35 1141, the relay R1140 opens a point in the previously traced path for impressing busy tone signal voltage upon the calling end of the connection. At its contacts 1142 and 1143, the relay R1140 prepares the previously mentioned dry talking circuit to the desired line. At its contacts 1144, the relay R1140 opens a point in the 40 previously traced locking circuit for the busy 50 test relay R1040. At its contacts 1145, the relay R1140 prepares an alternative locking circuit for the busy test relay R1040.

The relay R870 also operates when energized in series with the lower winding of the verification relay R1140. Upon operating, the relay R870 opens the established series-locking circuit for the two relays R770 and R1240 in the manner previously explained, causing both of these relays to restore. These relays, in releasing, open, at 60 the contacts 113 and 1241, two points in the above-traced circuit for energizing the relays R1140 and R870 in series. Thus, the relay R870 is deenergized and restores. Following the release of this relay, the control equipment of the link is conditioned to respond to the impulses comprising the first digit of the directory number assigned to the desired subscribers line. The manner in which this line is selected in response to the next three digits dialed at the calling operator's position is exactly the same as described above with reference to the call routed to the line 219. From this explanation it will be recalled that during the dialing of the third digit of the subscribers line directory number, the relays R1100, R1150 and R1160 are operated.

Assuming that the line 219 is the desired busy line, a circuit is completed for energizing the busy test relay R1040 in response to the operation of the relay R1460 which occurs shortly following the dialing of the third digit of the directory number designating this line. This circuit extends by way of the grounded private conductor 219c, the contacts 1416, C1483, the contacts 1465, C1162, the contacts 1131, C1076 and the lower winding of R1040 to battery. When thus energized, the relay R1040 locks to the grounded private conductor 219c over a path including the contacts 1044, C1075, the contacts 1145, C1162, the contacts 1465, C1483 and the contacts 1416. Shortly after this locking path is completed, the transfer relay R1130 operates to open its contacts 1131 and thus interrupt the operating circuit for the busy test relay. The relay R1130 also performs the other functions assigned thereto and described above with reference to the call routed to the line 219.

The relay R1040, upon operating, closes its contacts 1041 and 1043 to connect the line terminals of the repeating coil windings 837 and 838 to the talking conductors of the selected line 219 over paths including the resistors 1038 and 1039, and the condensers 1038' and 1039'. At its contacts 1042, the relay R1040 prepares the previously traced circuit for transmitting busy tone current over the calling end of the connection, this circuit now being held open at the disengaged contacts 1141 of the operated verification relay R1140. At its contacts 1047, the relay R1040 opens a point in the operating circuit for the switching-through relay R810. At its contacts 1048, the relay R1040 prepares a circuit for energizing the reverting call relay R940. At its contacts 1046, the relay R1040 opens a point in the previously traced operating circuit for the relay R1070, thereby to prevent the operation of the relays R1070 and R1030 in response to the subsequent operation of the transfer relay R1130.

When the fourth digit of the directory number assigned to the line 219 is dialed at the calling operator's position, the control equipment of the link responds in the exact manner described above. Shortly following the end of the digit, the relays R1150, R1160 and R1100 restore. The relay R1100, in releasing, completes the previously traced operating circuit for the relay R1050. In operating, the relay R1050 locks to the grounded release conductor C893 and performs the other switching operations previously explained. At its contacts 1051 and 1052, the relay R1050 completes obvious paths for short-circuiting the two resistors 1038 and 1039. When these resistors are excluded from the paths connecting the line terminals of the repeating coil windings 837 and 838 with the talking conductors of the line 219, a communication connection is established between the calling operator's position in the central office 5 and the busy called line. With this connection established, the operator may monitor the called line to determine whether or not it is actually in use. This arrangement permits the operator to locate faulty lines which are in fact not in use although a permanent calling condition is present thereon. If the called line is actually in use and the operator so desires, she may break in upon the conversation being held over this line, to inform the parties conversing over the connection that she requires the use of the line in order to complete a toll connection. It will be observed that the condensers 1038' and 1039' are included in the

portion of the connection which extends from the repeating coil 834 to the conductors of the called line 219. Accordingly, the previously established connection involving the line 219 may be cleared out without interference occasioned by the completed dry talking circuit extending through the link illustrated.

If the previously established connection involving the line 219 is released before the verification connection just described is cleared out at the calling operator's position in the central office 5, the relay R1040 is deenergized and restores in response to the removal of ground potential from the private conductor 219c. Upon restoring, the relay R1040 opens, at its contacts 1041 and 1043, two points in the dry talking circuit described above. At its contacts 1042, the relay R1040 opens a point in the previously traced path for transmitting busy tone current over the calling end of the connection. At its contacts 1044, the relay R1040 opens a further point in its locking circuit. At its contacts 1048, the relay R1040 completes the previously traced circuit for energizing the relay R1070 in series with the operated cut-off relay embodied in the line circuit 25. Thus, this cut-off relay is prevented from releasing. At its contacts 1048, the relay R1040 opens a point in the prepared operating circuit for the reverting call relay R940.

When energized in series with the cut-off relay of the line circuit 25, the relay R1070 operates to complete the operating circuit for the line-switching relay R1030. The relay R1030, in operating, short-circuits the relay R1070 and initiates the ringing operation to signal the desired substation in the exact manner previously explained. The manner in which the called substation is signaled, and the connection is released under the control of the calling operator in the central office 5, is exactly the same as set forth above.

In the event the connection is cleared out at the calling operator's position in the central office 5 before the previously established connection involving the line 219 is released under the control of the parties conversing thereover, or before a permanent condition present on this line is cleared, the finder-connector link is restored to normal in a manner which will be clearly apparent from the preceding explanation. In this regard it is pointed out that the right-of-way relay R1340 and the verification relay R1140 are deenergized and restored in response to the release of the hold relay R860 to remove ground potential from the release conductor C893.

PRIVATE BRANCH EXCHANGE CALLS

Calls involving the trunks extending to a private branch exchange are handled by the links in substantially the same manner as calls involving the subscribers lines. Provisions are made, however, for the automatic preselection of idle P. B. X trunks. Thus, the trunk preselect relay group diagrammatically illustrated at 1490 is provided for automatically selecting an idle one of the four associated trunks each time a previously selected trunk is seized and thus rendered busy. These preselect relays are arranged selectively to control the unit relays of the link in accordance with the condition of the four associated trunks. More specifically, if a call intended for the private branch exchange terminating this group of trunks is routed through the finder-connector link illustrated, the group of trunks is selected by dialing at the calling telephone sta-

tion the directory number assigned to the trunk group. During the dialing of the first two digits of this number, the group relay R1410 is caused to operate in the manner previously described. With the arrangement illustrated, the third digit of the directory number designating the P. B. X trunk group is the digit 1. Accordingly, at the end of this digit, the first counting relay R1240 is locked energized in series with its associated control relay R770. Shortly thereafter, the relays R1150, R1100 and R1160 restore. In restoring, the relay R1100 functions to complete the operating circuit for the connector unit relay which corresponds to the preselected idle trunk. Thus, if the first trunk of the group is idle, the connector unit relay R1450 is energized over a circuit which extends by way of the grounded release conductor C883, the contacts 113, C786, the contacts 1101, 1116, 1137 and 1102, C1223, the contacts 1242, C1241, the contacts 1413, C1484, the contacts of the preselect relays embodied in the relay group 1490, C1491 and the winding of R1450 to battery. The relay R1450, in operating, locks to ground over the previously traced path including the winding of the transfer relay R1130, and completes the previously traced operating circuit for the counting chain release relay R870. At its contacts 1453 to 1455, inclusive, the relay R1450 connects the conductors of the first trunk 211 to the conductors of the link line C847, C849, C1162. From this point on, the manner in which the call is forwarded to the private branch exchange and the connection is released under the control of the calling party is exactly the same as described above with reference to the call routed to the subscribers line 219.

In the event the first trunk line of the group is busy at the time the above-described call is initiated, the preselect relays of the relay group 1490 occupy positions such that the conductor C1484 is connected through the contacts of these relays to the conductor C1492 which extends to the winding of the second connector unit relay. Accordingly, the second connector unit relay operates to connect the second trunk of the group to the conductors of the link line C847, C849, C1162. Similarly, if the first two trunks of the group are busy at the time the call is initiated, the lead C1484 is connected through the contacts of the trunk preselect relays 1490 to the conductor C1493 which extends to the winding of the third connector unit relay. Accordingly, the third connector unit relay is energized and operates to connect the third trunk of the group to the link line C847, C849, C1162. Finally, if the first three trunks of the group are all busy, the lead C1484 is connected through the contacts of the trunk preselect relays 1490 to the lead C1494 which extends to the winding of the fourth unit relay. This relay, in operating, connects the conductors of the fourth trunk to the link line C847, C849, C1162 in a manner which will readily be understood from the above explanation. As indicated previously, the arrangement of the trunk preselect relays is such that if the first trunk becomes idle, it is utilized in routing the next P. B. X call to the private branch exchange in preference to the second, third, and fourth trunks which may also be idle at the time the first trunk is released.

The trunk preselect relays 1490 are controlled over the private conductors of the associated trunks. Thus, when ground potential is impressed upon the private conductor 211c of the

first trunk 211, the corresponding trunk preselect relays operate to open the connection between the lead C1484 and the lead C1481, and to establish a connection between the lead C1484 and the lead C1492, providing the second trunk is idle. In the event the second trunk is also busy, the lead C1484 is connected through the contacts of the trunk preselect relays to the third connector unit relay operating lead C1493, and so on. By virtue of this arrangement, the trunk preselect relays are controlled automatically to prevent seizure of busy corresponding trunks regardless of whether the calls present on the corresponding trunks are incoming or outgoing calls. In this regard it will be understood from the preceding explanation that each line is marked busy through the application of ground potential to the private conductor thereof, regardless of whether the line is seized through the connector switch of one of the links or is seized in the distant P. B. X.

CENTRAL OFFICE CALLS

As indicated previously, a call may be routed to the central office 5 from a calling one of the substations served by the illustrated automatic switching equipment, in response to the dialing of a single digit comprising ten impulses at the calling substation. Idle ones of the trunks extending to the central office are automatically preselected through operation of the preselect relay group 1495. This relay group is identical in arrangement with the P. B. X trunk preselect relay group 1490 except that the capacity thereof is enlarged to accommodate ten trunks.

Briefly to consider the manner in which a central office trunk call connection is completed, it may be assumed that a call of this character is initiated at the substation A, for example, and 40 that the link illustrated is assigned to the use of the call. It may further be assumed that the subscriber at the substation A is entitled to non-restricted central office service. The manner in which the link operates in response to initiation of the call is substantially the same as described above with respect to the call routed to the line 219. It is pointed out, however, that with the auxiliary group relay R510 operated, the finder connect relay R290, upon operating, completes a circuit for energizing the right-of-way relay R1340. This circuit extends from ground by way of the contacts 512, the restricted service lead C585, the contacts 299, C896 and the upper winding of R1340 to battery. When energized over this circuit, the relay R1340 operates and prepares a locking circuit for itself at its contacts 1342. This locking circuit, which includes the lower winding of R1340, is completed in response to the subsequent operation of the hold relay R860 to impress ground potential upon the release conductor C893. At its contacts 1341, the relay R1340, in operating, prepares a circuit for energizing the connector group relay R1400 at which the central office trunks are terminated.

Following seizure of the link in the manner just described, and when the single central office trunk digit comprising ten impulses is dialed at the calling substation A, the impulse-counting chain responds in the manner previously described. At the end of the digit, the tenth counting relay R1330 is locked energized in series with its associated control relay R770. When the relays R1150, R1100 and R1160 restore shortly following the end of the digit, the prepared operating circuit for the connector group relay

R1400 is completed. This operating circuit extends by way of the grounded release conductor C893, the contacts 773, C786, the contacts 1101, 1117 and 1128, C1222, the contacts 1331 and 1341, C1343 and the winding of R1400 to battery. Upon operating, the relay R1400 connects the conductors of the ten associated trunks to the ten link lines of the connector switch and completes, at its contacts 1402, a path including the conductor C1164 and the grounded release conductor C893 for short-circuiting the winding of the transfer relay R1110. At its contacts 1403, the relay R1400 prepares one of the previously traced operating circuits for the counting chain release relay R870, but this circuit is now open at the restored contacts 1126' of the transfer relay R1120. At its contacts 1401, the relay R1400 completes a circuit for energizing the connector unit relay which corresponds to the trunk pre-selected for the use of the call by the trunk pre-select relay group 1495. Thus, if the first trunk of the central office trunk group is idle, the lead C1486 is connected through the contacts of the trunk preselect relays to the operating lead C1491 extending to the unit relay R1450 corresponding to the first trunk of the group. On the other hand, if the first trunk is busy at the time the call is initiated and the second trunk of this group is idle, the lead C1486 is connected through the contacts of the trunk preselect relays 1495 to the operating lead extending to the connector unit relay corresponding to the second trunk of the group. More generally stated, the lead C1486 is connected through the contacts of the trunk preselect relays 1495 to the operating lead of the connector unit relay which corresponds to the preselected idle trunk. Assuming that the first trunk of the group is idle, the connector unit relay R1450 is energized over a circuit which may be traced as extending by way of the grounded release conductor C893, the contacts 773, C786, the contacts 1101 and 1125, C1085, the contacts 1331', the conductor C1344, the contacts 1401, C1486, the contacts of the trunk preselect relays 1495, C1491, and the winding of R1450 to battery. In operating, the relay R1450 closes its contacts 1453, 1454 and 1455 to connect the conductors of the first trunk 201 to the link line conductors C1162, C849 and C847. At its contacts 1451, the relay R1450 locks to the grounded release conductor C893 over a path including the conductor C1163 and, in so doing, short-circuits the transfer relay R1130. At its contacts 1452, the relay R1450 completes a circuit for energizing the counting chain release relay R870, this circuit extending by way of the grounded release conductor C893, the contacts 1452, C1165, the contacts 1135, C887 and the winding of R870 to battery. When thus energized, the relay R870 functions to release the operated relays R770 and R1330 of the counting chain in the manner previously explained. During the release of these relays, the paths short-circuiting the transfer relays R1110 and R1130 are opened at the contacts 1331 and 1331', respectively, permitting these two transfer relays to be energized in series with the connector group and unit relays R1400 and R1450, respectively. The relay R1130, upon operating, opens its contacts 1135 to interrupt the above-traced operating circuit for the counting chain release relay R870, causing the latter relay to restore. At its contacts 1134, the relay R1130 completes a circuit for energizing the switching-through relay R810, this circuit extending from ground by way of the contacts

5 tacts 852 and 862, C233, the contacts 1134 and 1125, C1084, the contacts 1041, C886 and the winding of R810 to battery. At its contacts 1132, the relay R1130 completes a path for impressing ground potential upon the private conductor of the selected central office trunk 201, this path extending from ground by way of the contacts 866 and 817, C885, the contacts 1123, C1083, the contacts 1046, C1082, the contacts 1132, C1162, the contacts 1455, C1489 and the contacts 1407. The relay R810, upon operating, opens its contacts 818 to disconnect the timer start conductor C889 from ground, and opens its contacts 815, further to interrupt the previously traced pulsing circuit, thereby to prevent further impulses from being transmitted to the impulse-counting equipment and the associated control relays R1100, R1150 and R1160. At its contacts 819, the relay R810 opens a point in the operating circuit for 10 the link release relay R900. At its contacts 812 and 814, the relay R810 connects the link line conductors 230a and 230b to the link line conductors C847 and C849, whereby the calling loop circuit is extended through the connector end of the link to the repeater associated with the central office trunk 201. At its contacts 811 and 813, the relay R810 opens two points in the circuit for energizing the line relays R820 and R825, thereby to cause the sequential release of these 15 relays and the relays R830, R840 and R850. At its contacts 817, the relay R810 opens a point in the previously traced operating circuit for the relay R1070. At its contacts 816, the relay R810 completes an alternative path for impressing 20 ground potential upon the private conductor 201c of the selected central office trunk 201. This path extends from ground by way of the contacts 852 and 862, C233, the contacts 1134 and 1125, C1084, the contacts 1047, C886, the contacts 816, C885, the contacts 1123, C1083, the contacts 1046, C1082, the contacts 1132, C1162, the contacts 1455, C1489 and the contacts 1407 to the private conductor 201c of the trunk 201. 25 After this alternative path is completed, the relay R810 opens its contacts 817 to interrupt the initially completed path for grounding the private conductor 201c.

When the calling loop circuit is extended to the repeater associated with the trunk 201, and ground potential is impressed upon the private conductor of this trunk in the manner just explained, the repeater operates in a manner well understood in the art to extend the call to the central office 5 and to complete a multiple path 30 for impressing ground potential upon the private conductor 201c of the trunk 201. More specifically, when the indicated repeater is seized, the line and holding relays conventionally embodied therein operate to connect the private conductor 201c to ground, thus establishing multiple holding 35 circuits for the switching-through relay R810 and the hold relay R860. These holding circuits commonly extend by way of the grounded private conductor 201c, the contacts 1407, C1489, the contacts 1455, C1162, the contacts 1132, C1082, the contacts 1046, C1083, the contacts 1123, C885 to the contacts 816 where they divide, one circuit 40 extending through the winding of R810 to battery, and the other circuit extending by way of C886, the contacts 1047, C1084, the contacts 1125 and 1134, C233, the contacts 862 and the winding of R860 to battery. Due to the completion of these 45 holding circuits, the relays R810 and R860 are held operated following the release of the relays 50 R820, R830, R840 and R850. With the hold 55

relay R860 operated, ground potential is maintained upon the release conductor C893 to prevent the transfer relays R1110 and R1130 and the connector group and unit relays from releasing.

When the private conductor 201c of the trunk 201 is connected to ground, the trunk preselect relays 1495 operate to connect the lead C1486 to the connector unit relay operating lead which corresponds to the next idle central office trunk. Thus, if the second, third and fourth central office trunks are all busy at the time ground potential is impressed upon the private conductor 201c, the lead C1486 is connected through the contacts of the trunk preselect relays to the operating lead individual to the fifth unit relay of the connector switch. In a similar manner, the common trunk select leads of the other links are, through operation of the trunk preselect relays, connected to the operating leads individual to the corresponding fifth connector unit relays. Thus, the fifth central office trunk is selected for use in setting up the next central office trunk call. In this regard, it will be apparent that when a trunk is seized in the central office, the repeater associated therewith functions to impress ground potential upon the associated private conductor so that operation of the trunk preselect relays 1495 is initiated to select another of the trunks for use in setting up the next succeeding trunk call.

When the central office trunk call originating at the substation A is routed to the central office in the manner explained above, and the call is answered at one of the operator's positions terminating the trunk 201 in this office, the calling subscriber may inform the answering operator as to the party desired, and the connection may be forwarded to the desired line in the manner conventionally followed in manual office practice. If desired, a tone signaling arrangement may be associated with those lines of the system which are arranged for free central office trunk circuit, so that the answering operator is informed, upon answering the call, that the calling subscriber is entitled to free service with respect to the subscriber's lines terminating at the central office 5. An arrangement for this purpose conventionally comprises apparatus for impressing an alternating signal voltage upon the control conductor of each line arranged for free central office calls when a call is initiated on the line. This voltage is repeated through the repeater associated with the central office trunk in use in the answering operator's telephone instrument. Thus, the central office operators are able to distinguish between calls initiated at substations entitled to free service, and calls initiated at substations which are not entitled to this service.

The release of a central office trunk call connection of the character just described is entirely under the control of the operator handling the call at the central office 5. Thus, if the calling subscriber at the substation A restores the receiver provided at the calling substation to its supporting hook or cradle before the connection is cleared out at the answering operator's position in the central office 5, the supervisory relay embodied in the repeater associated with the trunk 201 operates to transmit a disconnect signal to the position of the operator handling the call in the central office. This disconnect signal serves to inform the operator that the connection is no longer desired. In this regard, it will be apparent that if the calling subscriber desires

- to recall the operator he may do so by repeatedly operating his switchhook to cause the intermittent operation of the disconnect signal device provided at the position of the operator handling the call in the central office. Thus, a flashing recall signal is produced by this signal device at the operator's position. This signal serves to inform the operator handling the call that she is being recalled from the calling substation A. 10 When, however, the disconnect signal device is continuously energized, the operator is informed that the connection is no longer desired. When the connection is cleared out at the operator's position in the distant central office, the repeater associated with the trunk 201 is released. During the release of the control equipment embodied in this repeater, the private conductor 201c of the trunk 201 is disconnected from ground, thereby to deenergize the switching-through relay R810 15 and the hold relay R860. The hold relay, upon restoring, disconnects the release conductor C893 from ground to initiate the release of the connector portion of the link in the manner described above. This relay also disconnects the 20 finder hold lead C235 from ground, whereby the connector portion of the link is released in the manner previously explained. In addition, the hold relay functions to mark the link as idle in the link distributor and to remove ground potential from the control conductor extending to the 25 line circuit associated with the calling line. In response to the latter operation, the cut-off and lockout relays embodied in the line circuit associated with the calling line are deenergized and restore in the previously described manner. Thus, the connection is fully released and the apparatus utilized therein is conditioned for further use.

Restricted service

The arrangement of the switching equipment is such that if a call is initiated at a substation for which central office trunk service is not provided, the call will fail. Thus, if a central office trunk call is initiated on one of the lines in the ten-line subgroup corresponding to the auxiliary group relay R590, and the link illustrated is assigned to the use of the call, the link is seized in the manner previously explained. In this case, however, the auxiliary group relay R590, upon operating, does not impress ground potential upon the restricted service lead C585 and, accordingly, no circuit is completed for energizing the right-of-way relay R1340. Hence, when the single central office trunk digit of ten impulses is dialed at the calling substation to cause the operation of the tenth counting relay R1330, no circuit is completed at the end of the digit for energizing the connector group relay R1400, this circuit being held open at the disengaged contacts 1341 of the restored right-of-way relay R1340. Thus, it will be seen that the central office trunks are only accessible to the subscribers lines which are included in the ten-line subgroups corresponding to the auxiliary group relays which are arranged to impress ground potential upon the restricted service lead C585. It will also be apparent that it is necessary to group the subscribers lines according to the type of service to be rendered to the substations associated therewith, the lines serving substations entitled to central office trunk service being included in the same ten-line subgroups, and the other lines being included in different ten-line subgroups.

REVERTING CALLS

The arrangement of the finder-connector links is such that reverting call connections are established by the well-known directory number dialing method. Thus, if a call intended for the substation D, for example, is initiated at the substation C, also served by the line 219, and the link illustrated is assigned to the use of the call, the connection is extended to the connector portion of the link in the manner previously explained with reference to the calls initiated on the lines 215 and 216. The manner in which the connector portion of the link responds to the impulses of the digits comprising the directory number assigned to the called substation D is exactly the same as explained above. In this regard it will be recalled that, at the end of the third digit, the line selected through the connector portion of the link, in this case the calling line 219, is tested to determine the idle or busy condition thereof. Obviously, this line tests busy due to the operated condition of the line circuit 25. Accordingly, the busy test relay R1040 is energized and operates at the end of the third digit to perform the previously explained functions assigned thereto. One of these functions, it will be recalled, is that of transmitting the usual busy tone signal to the calling subscriber.

After dialing the fourth or ringing code-selecting digit, the calling subscriber restores the receiver provided at the calling substation to its supporting hook or cradle, thereby to open the established loop circuit extending through the finder portion of the link to the line relays R820 and R825. These two relays are thus deenergized and restore. The relay R820, in restoring, initiates the sequential release of the three relays R830, R840 and R850 in the manner previously explained. The relay R860, however, is held energized over a locking circuit which may be traced as extending from ground by way of the contacts 834, 815 and 864, C881, the contacts 1055, 1023 and 1045, C1082, the contacts 1132, C1162, the contacts 1465, C1483, the contacts 1416, the private conductor 219c, the contacts of the line relay embodied in the line circuit 25, the control conductor of the line 219, the operated contacts of the finder group and unit relays, the conductor 229c, the contacts 276, C233, the contacts 862 and the winding of R860 to battery. With the hold relay R860 operated, the link is prevented from releasing, for reasons clearly apparent from the preceding explanation.

The relay R850, upon restoring, completes a circuit for energizing the reverting call relay R940, this circuit extending by way of the grounded conductor C233, the contacts 853, C898, the upper winding of R940, C993 and the contacts 1048 to battery. When thus energized, the relay R940 closes its X contacts 949 to complete a locking circuit for itself. This locking circuit extends from ground by way of the contacts 918 and 949, C995, the contacts 1058, C994, the contacts 973 and the lower winding of R940 to battery. At its contacts 949, the relay R940 prepares an alternative locking circuit for itself. At its contacts 941, the relay R940 prepares a bath for transmitting a reverting call tone signal current over the connection to inform the answering party as to the character of the call answered. At its contacts 942, the relay R940 opens the previously traced locking circuit for the busy test relay R1040, causing the latter relay to restore. At its contacts 943, the relay R940 prepares a

locking circuit for the relay R930. At its contacts 944, the relay R940 prepares the operating circuit for the relay R970. At its contacts 945, the relay R940 prepares a path for impressing ground potential upon the timer start lead C878. At its contacts 946, the relay R940 completes a multiple locking circuit for the hold relay R860, this circuit extending from ground by way of the contacts 946, C233, the contacts 862 and the winding of R860 to battery. At its contacts 947, the relay R940 prepares a path for impressing ground potential upon the tone start lead C879. At its contacts 947, the relay R940 opens the previously traced locking circuits for the operated finder group, subgroup and unit relays, thereby to cause the release of the finder portion of the link in the manner previously explained.

The busy test relay R1040, upon restoring, disconnects the busy tone current source from the line 219, thereby to terminate the busy signal being transmitted over this line. At its contacts 1045, the relay R1040 opens the previously traced path for impressing ground potential upon the private conductor 219c of the line 219. When this path is opened, the relay R1070 is energized with the cut-off and lockout relays of the line circuit 25 over a circuit which extends from ground by way of the contacts 866 and 817, C885, the winding of R1070, C1083, the contacts 1046, C1082, the contacts 1132, C1162, the contacts 1465, C1483, the contacts 1416, the conductor 219c, the restored contacts of the line relay embodied in the line circuit 25, and the windings of the cut-off and lockout relays of this line circuit to battery. When thus energized, the relay R1070 operates to complete, at its contacts 1071, the previously traced operating circuit for the line-switching relay R1030. The relay R1030, upon operating, locks to the grounded release conductor C893 and, at its contacts 1034, shorts-circuits the winding of the relay R1070. When this short-circuiting path is completed, the relay R1070 is deenergized and restores. In addition, ground potential is again impressed directly upon the private conductor 219c of the called line 219 to maintain the energization of the cut-off and lockout relays in the line circuit 25, and to maintain the busy marking of the line 219 in the various connector switches having access thereto. The relay R1030, upon operating, also prepares, at its contacts 1035, the previously traced operating circuits for the pickup relay R960, and completes, at its contacts 1036, the previously traced path for impressing ground potential upon the ringing interrupter start lead C789. Thus, the relay R1030, in operating, initiates the ringing operation in the manner previously described.

When the call is answered at the called substation D, a loop circuit is completed by way of the line 219 for energizing the back-bridge relay R920. Upon operating, the relay R920 completes the operating circuit for the relay R930. At its contacts 922, the relay R920 prepares the operating circuit for the battery-reversing relay R800. At its contacts 924, the relay R920 opens the operating circuit for the pickup relay R960. At its contacts 923, the relay R920 completes the previously traced operating circuit for the counting chain release relay R870. The relay R870, upon operating, initiates the release of the impulse-counting equipment in the manner previously described. During the release of this equipment, the operating circuit for the relay R870 is opened at the contacts 753, 763 or 773, whereby this relay is deenergized and restores.

The relay R930, upon operating, locks to ground over a path including the contacts 932 and 943, and the grounded release conductor C893. At its contacts 933, the relay R930 further prepares the operating circuit for the relay R970. At its contacts 935, the relay R930 opens a point in one of the operating circuits for the link release relay R900. At its contacts 937, the relay R930 completes the above-mentioned path including the contacts 947 for impressing ground potential upon the tone apparatus start lead C879, whereby operation of the reverting call signal current generator 475 is initiated in the manner subsequently described. This apparatus, in operating, functions to impress an alternating voltage of a predetermined frequency upon the reverting call tone lead C907. This voltage is impressed through the condenser 925 and the engaged contacts 931 and 941 upon the negative side of the loop circuit extending to the answering substation, and is reproduced by the receiver provided at this substation to inform the answering party that the answered call is of the reverting type. The purpose of this arrangement is to prevent the answering party from receiving the impression, upon answering the call, that the answered call has been abandoned.

The relay R930, in operating, also completes the above-mentioned path including the contacts 934 and 945 for impressing ground potential upon the timer start lead C878. When this lead is grounded, operation of the timing device 720a is initiated. A predetermined time interval thereafter, this device functions to transmit a ground pulse over the time pulse lead C876, and to impress ground potential upon the holding lead C891. When the lead C876 is connected to ground, a circuit including this lead and the contacts 933 and 944 is completed for energizing the upper winding of the relay R970. When thus energized, the relay R970 locks to the grounded release conductor C893 over a path including its contacts 971. Thus, the relay R970 is held operated after the pulse impressed upon the time pulse lead C876 by the timing device 720a is terminated. At its contacts 972, the relay R970 completes an alternative locking circuit for the reverting call relay R940, this circuit extending by way of the grounded time cut-off lead C891, the contacts 949, the contacts 972 and the lower winding of R940 to battery. After this circuit is completed, the relay R970 opens its contacts 973 to interrupt the initially completed locking circuit for the relay R940. A short time interval following operation of the relay R970, the timing device 720a operates to disconnect the time cut-off lead C891 from ground and thus de-energize the reverting call relay R940. The relay R940, upon restoring, opens its contacts 946 to de-energize the hold relay R860. When the latter relay restores, the release conductor C893 is disconnected from ground to de-energize all of the operated relays in the connector portion of the link, thus causing the link to release. It will be understood that during the release of the link, the above-traced path for impressing the reverting call signal voltage upon the line 219 is interrupted at a number of points. The hold relay R860, upon restoring, also opens, at its contacts 866, the previously traced path for impressing ground potential upon the private conductor 219c of the line 219.

When the private conductor 219c is disconnected from ground, the line circuit 25 functions to lock the line 219 out of service for the duration

of the call, and to impress guarding ground potential upon the private conductor 219c for the purpose of guarding the line 219 against seizure by the connector switches having access thereto.

5 The manner in which this is accomplished may best be explained by reference to the line circuit 10 associated with the subscribers line 215. It will be noted from an inspection of this line circuit that when the conductors 215c and 215d are disconnected from ground, the relays R105 and R110 are deenergized. The relay R110 immediately restores to reconnect the windings of the line relay R100 across the conductors of the associated line. In the case under consideration, 15 when the line relay of the line circuit 25 associated with the line 219 is thus reconnected to the line 219 it is again energized. From an inspection of the line circuit 10, it will be understood that when this occurs a locking circuit is completed for the associated lockout relay. Accordingly, the line lockout relay of the line circuit 25 remains in its operated position. With this relay operated, ground potential is again impressed upon the private conductor 219c through the winding of the associated cut-off relay, and 20 the marking leads extending to the common equipment illustrated in Figs. 5 and 6 of the drawings are disconnected from ground.

The desired conversational circuit between the calling and called substations C and D associated with the line 219 is completed when the calling subscriber again removes the receiver provided at the calling substation from its supporting hook or cradle. In the event this line is arranged for common battery operation, current for energizing the transmitters respectively provided at the calling and called substations is supplied to the line 219 through the windings of the line relay embodied in the line circuit 25.

30 40 When the connection is cleared out at both the calling and called substations, the loop circuit established by way of the line 219 is interrupted. In response to this operation, the line relay of the line circuit 25 is deenergized and restores to open 45 the established locking circuit for its associated lockout relay. Thus, the line circuit 25 is released and guarding ground potential is removed from the private conductor 219c to render the line 219 accessible to the connector switches having access thereto.

RELEASE ON PERMANENTS AND CONVERSATION TIMING

As indicated previously, provisions are made in 55 the finder-connector links for automatically releasing any operated one thereof when it is seized over a faulty line having a permanent calling condition thereon, or a partially established connection is held for an unreasonable time interval. Thus, it is pointed out above that when a call is routed to the connector portion of the link illustrated, the hold relay R860 functions to impress ground potential upon the timer start lead C889 over a path including the contacts 867 and 818. In operating, the relay R860 also closes its contacts 868 to prepare a circuit for energizing the relay R900. When ground potential is impressed upon the start lead C889, operation of the timing device 720b is initiated. Thereafter, the timing device 720b operates at regular intervals to impress ground potential upon the lead C892. When this lead is first grounded following operation of the hold relay R860, the circuit for energizing the relay R900 is completed, this circuit 60 65 70 extending by way of the grounded lead C892, the

contacts 868 and 819, C877, the contacts 935 and 915, and the lower winding of R900 to battery. A parallel branch of this circuit may extend by way of the conductor C877, the contacts 1021 and the conductor C988. Upon operating, the relay R900 locks to ground over a path including the contacts 903 and 913, C897 and the contacts 871 and 869. Thus, the relay R900 is held operated after the ground pulse impressed upon the lead C892 by the timing device T20b terminates. At its contacts 906, the relay R900 opens a point in an alternative operating circuit for the relay R960. At its contacts 901, the relay R900 opens a point in an alternative path for transmitting dial tone signal current over the calling end of the connection. At its contacts 902, the relay R900 prepares a circuit for energizing the relay R910. At its contacts 904, the relay R900 prepares an alternative path for impressing ground potential upon the release conductor C893. At its contacts 905, the relay R900 opens a point in an alternative holding circuit for the relay R850. Assuming that no further operation of the connector portion of the link occurs following operation of the hold relay R860, no further operation of the relay equipment thereof embodied therein occurs for a predetermined time interval. At the expiration of this interval, the timing device T20b functions to impress a ground potential upon the time pulse lead C874, thereby to energize the relay R910 over a circuit including this conductor and the contacts 902. When thus energized, the relay R910 locks to ground over a path including the contacts 914 and the grounded release conductor C893. At its contacts 911, the relay R900 prepares a point in the above-mentioned alternative circuit for transmitting dial tone current over the calling end of the connection. At its contacts 915, the relay R910 opens a point in the previously traced operating circuit for the relay R900. At its contacts 912, the relay R910 completes an alternative locking circuit for the relay R900, this alternative circuit including the grounded time pulse lead C875 and the contacts 912 and 903. In this regard it is noted that the timing device T20b normally maintains ground potential upon the time pulse lead C875 but functions to disconnect this lead from ground at regularly spaced intervals. Following the completion of this alternative circuit, the relay R910 opens its contacts 913 to interrupt the initially completed locking circuit for the relay R900. At its contacts 916, the relay R910 opens a further point in the previously traced operating circuit for the link distributor relay R700, thereby further to insure the busy marking of the link illustrated in the link distributor. At its contacts 917, the relay R910 opens a point in the previously traced locking circuit for the pickup relay R960. At its contacts 918, the relay R910 opens the previously traced holding circuit for the relay R850. The relays R850 and R860 are thus sequentially de-energized and restored. Upon restoring, the hold relay R860 initiates the release of the link in the manner previously described. During the release of the link equipment, the relay R910 is deenergized in response to the removal of ground potential from the release conductor C893. Under the conditions assumed, a calling condition is still present on the line responsible for seizure of the link. Accordingly, the line and lockout relays of the line circuit associated with this line are held energized to lock the line out of service in the manner described previously with reference to

the reverting call connection established between the substations C and D served by the line 219.

The above description pertaining to the forcible release of the link only applies when the link is seized and no dial pulses are transmitted thereto. In the event the dialing operation is started following operation of the relay R900 but prior to operation of the relay R910, the timing operation in progress is arrested and is started anew at the end of each digit dialed. Thus, the counting chain release relay R870 operates to open, at its contacts 871, the previously traced locking circuit for the relay R900 shortly following the end of each series of impulses transmitted to the connector portion of the link. The relay R900 is thus deenergized and restores so that a second timing period is started. This arrangement insures that the link will be forcibly released in the event the directory number designating a particular substation is partially dialed at a calling substation and the call is abandoned without a release of the connection at the calling substation. In this regard it will be noted that if the central office trunk digit comprising ten impulses is dialed at a calling substation arranged for unrestricted service to cause the operation of the switching-through relay R810 in the manner previously explained, the relay R810, in operating, opens its contacts 818 to disconnect the timer start lead C889 from ground and opens its contacts 819 to prevent further energization of the relay R900. The counting chain release relay R870 also operates shortly following the end of a digit of this character to open the holding circuit for the relay R900 and thus cause the release of the latter relay, if operated. It will be apparent, therefore, that when the link illustrated is occupied with a central office trunk call, the apparatus for forcibly releasing the link is rendered inactive.

In the event a timing operation is in progress at the time a call routed by way of the link is answered at the called substation, the relay R900 will occupy its operated position for reasons apparent from the above explanation. When, however, the call is answered at the called substation, the back-bridge relay R920 operates to complete, at its contacts 921, the previously traced operating circuit for the relay R930. The relay R920, in operating, also completes, at its contacts 923, the previously traced operating circuit for the counting chain release relay R870. The latter relay, upon operating, opens its contacts 871 to interrupt the established locking circuit for the relay R900, causing the latter relay to release. Thus, the timing operation in progress is terminated. With the arrangement illustrated, a second timing operation is immediately started in order to time the duration of the call.

In the event a connection is established by way of the link, the called party releases the connection but the calling party fails to release the connection, the timing equipment functions automatically to release the link after a predetermined time interval. Thus, when the called subscriber restores the receiver provided at the called substation to its supporting hook or cradle to terminate the conversation, the loop circuit extending to the called substation is interrupted to deenergize the back-bridge relay R920. The relay R920, upon restoring, opens the operating circuit for the relay R930. When the relay R930 restores, it closes its contacts 935 to re-prepare the operating circuit for the timing relay R900. Thus, a timing operation is started which results

in the forcible release of the link in the event the calling party fails to restore the receiver provided at the calling substation to its supporting hook or cradle.

The two timing or link release relays R900 and R910 are utilized for the purpose of timing the duration of established connections routed by way of the link illustrated, and for releasing the link after a connection routed by way thereof has been established for a predetermined time interval. This feature of the link is optional and may be omitted, if desired, by deleting the "S" wiring arrangement comprising the conductors C988 and C871, and the contacts 1021 of the relay R1020.

Assuming that the "S" wiring is used, the timing of a call routed by way of the link is started when the call is answered at the called substation to cause the operation of the back-bridge relay R920 followed by the operation of the relays R930 and R870. Thus, the counting chain release relay R870, upon momentarily operating in response to the answering of the call, opens its contacts 871 to deenergize the relay R900, assuming that a timing operation is in progress. Thus, the relay R900 is normalized incident to the completion of the desired talking circuit. Thereafter, this relay and the relay R910 are sequentially operated in response to the ground pulses applied at spaced intervals to the time pulse leads C871 and C874, respectively. In this regard it will be understood that the operating circuit for the relay R900 extends, following operation of the relay R930, by way of the "S" wiring arrangement comprising the conductors C871 and C988, and the contacts 1021. It will further be apparent that if the call in progress is a central office trunk call, such that the relay R1020 is operated in the link, this circuit will be held open at the contacts 1021. Thus, conversation timing is limited to calls originating at the substations directly served by the switching equipment illustrated.

When the relay R910 operates in response to the ground pulse applied to the time pulse lead C874 by the timing device 720b, it establishes, at its contacts 912, the previously traced alternative locking circuit for the relay R900. At its contacts 918, the relay R910 completes an alternative locking circuit for the relay R850, this circuit extending by way of the grounded release conductor C893, the contacts 1022, C989, the contacts 936, 904 and 918, C890, the contacts 831 and 842 in parallel and the winding of R850 to battery. After this circuit is completed, the relay R910 opens its contacts 918' to interrupt the initially completed holding circuit for the relay R850. After a predetermined time interval, the timing device 720b functions in the manner pointed out above to remove ground potential from the time pulse lead C875, thereby to deenergize the relay R900. Upon restoring, the relay R900 prepares the previously mentioned alternative path for impressing dial tone voltage upon the connection. At its contacts 906, the relay R900 prepares the above-mentioned alternative operating circuit for the pickup relay R960. At its contacts 904 and 905, the relay R900 transfers the holding circuit for the relay R850 from the release conductor C893 to the normally grounded release lead C888. This lead is normally connected to ground through the contacts of the timing device 720b. Shortly after the release of the relay R900, the timing device 720b functions to impress a ground pulse upon the lead C892',

thereby to energize the relay R960 over a circuit including this lead, the contacts 906 and 919, and the lower winding of R960. The relay R960, upon operating, completes the above-mentioned path for impressing dial tone signal voltage upon the established connection, this path extending from the ungrounded terminal of the dial tone generator 435 by way of the lead C1168, the contacts 961, 811 and 901, the conductor C845, the condenser 843 and the contacts 861 to the negative side of the established connection. From this point, the dial tone current is conducted through the receivers respectively provided at the calling and called substations, whereby the usual dial tone signal is reproduced thereby. The parties conversing over the established connection are thus informed that the allotted conversation time has expired and that the connection will shortly be forcibly released. Immediately after the termination of this signal, which occurs when the timing device 720b operates to disconnect ground from the lead C892' and thus deenergize the relay R960, the timing device 720b functions to disconnect the holding lead C888 from ground and thus open the above-traced alternative holding circuit for the relay R850. When deenergized in this manner, the relay R850 restores to open the circuit for energizing the hold relay R860. The relay R860, upon restoring, initiates the release of the link in the manner previously explained. During the release of the link, ground potential is removed from the private conductors of the calling and called lines, with the result that the line and lockout relays of the line circuits respectively associated therewith are locked operated. Thus, the calling and called lines are effectively locked out of service until the receivers respectively provided at the calling and called substations associated therewith are restored to their respective supporting hooks or cradles.

OPERATION OF THE TONE GENERATING EQUIPMENT

As indicated previously, the dial tone generator 435 and the busy tone generator 440 are identical in arrangement. The operation of these two tone units is initiated in response to the application of ground potential to the start lead C895. Thus, when this lead is connected to ground, an obvious circuit is completed for energizing the start relay R400. The relay R400, upon operating, completes, at its contacts 401, an obvious path for grounding the start lead C405 individual to the dial tone generator 435. At its contacts 403, the relay R400 completes a circuit including the resistor 473 for energizing the slow-to-operate relay R470, thereby to initiate the operation of the reverting call tone generator 475. At its contacts 404, the relay R400 completes a circuit for energizing the start winding of the tone buzzer 430, this circuit extending from ground by way of the contacts 404 and 422, the right or start winding of the buzzer 430 and through the contacts 426 and the resistor 413 to battery. Parallel branches of this circuit also extend through the resistor 437 and the lower winding of the transformer 432' to battery. It is noted that in the preferred arrangement the right or start winding of the buzzer 430 is of approximately 400 ohms resistance, the left winding of this resistor is of approximately 1000 ohms resistance, the lower winding of the transformer is of approximately 600 ohms resistance, and the three resistors 437, 432 and 413 are of 1500 ohms, 2000 ohms and 100 ohms resistance, respectively. Accordingly, when the low resistance start wind-

ing of the buzzer 430 is energized in series with the resistor 413, it is energized by a heavy current which causes the armature controlling the contacts 431 rapidly to be attracted to its extreme operated position. In response to this operation the contacts 431 are closed to complete a circuit for energizing the slow-to-operate relay R410. This circuit extends from ground by way of the contacts 404, 431 and 424, and the winding of R410 to battery. The relay R410 operates after an interval and locks to ground through the contacts 411 and 404. At its contacts 412, the relay R410 completes an obvious operating circuit for the relay R420. The slow-operating period of the relay R410 and the operating time of the relay R420 afford the buzzer 430 an opportunity fully to attract the vibratory armature controlling the contacts 431 before the initially completed start circuit is interrupted in the manner described below.

In operating, the relay R420 first opens its contacts 422 to interrupt the path normally shunting the left winding of the buzzer 430 and the resistor 432, thereby to insert these parallel connected elements in the above-traced circuit for energizing the right or start winding of the buzzer. Thus, the current flow over the circuit for energizing the buzzer is reduced somewhat. The relay R420, in operating, next opens its contacts 426 to remove the 100 ohm resistor 413 from the buzzer operating circuit. After these contacts are opened the buzzer windings are energized over branch circuits, one of which extends from ground through the two windings of the buzzer in series and the parallel network including the resistor 437 and the lower winding of the transformer 432' to battery. Another branch of this circuit extends from ground through the contacts 421, the resistor 432, the right or start winding of the buzzer 430 and the parallel network including the resistor 437 and the lower winding of the transformer 432' to battery. It will be noted that the removal of the resistor 413 from the operating circuit for the buzzer results in a further reduction in the magnitude of the current flow through the buzzer windings.

The third function performed by the relay R420 is that of opening its contacts 421 to open the path including the resistor 432 in shunt with the left winding of the buzzer 430. Thus, the current flow through the right or start winding of the buzzer 430 is further reduced. The purpose of reducing the current flow through this buzzer winding in steps is to prevent the sudden and premature release of the vibrating armature controlling the contacts 431 due to a too sudden reduction of the start current.

Following the operations just described the relay R420 closes its contacts 423 to complete the tone circuit and opens its contacts 424 to interrupt the above-traced operating circuit for the relay R410. Finally, the relay R420 completes, at its contacts 425, an obvious path for short-circuiting the series-connected windings of the tone buzzer. When this path is completed, the tone buzzer is deenergized and releases its vibratory armature to open the contacts 431. Immediately these contacts are opened, the two windings of the buzzer are energized in series over a circuit including the contacts 404 and the lower winding of the transformer 432'. Thus, the buzzer operates intermittently to open and close its contacts 431 so long as the start relay R400 is held in its operated position. It will be ob-

served that each time the contacts 431 are closed, the full voltage of the exchange battery is impressed across the lower winding of the transformer 432'. On the other hand, when the contacts 431 are opened, a portion of the available voltage is dissipated as a potential drop across the parallel network comprising the windings of the buzzer 430, the resistor 433 and the condenser 434. Thus, a periodically varying current is caused to traverse the lower winding of the transformer 432'. This current causes an induced voltage to be developed in the upper winding of the transformer 432', which is impressed across the terminals of the condenser 436 and is also impressed through the windings of the radio frequency choke coil 454 upon the busy tone lead C1089. It will be observed that the condenser 436 is periodically charged and discharged by the induced voltage developed in the upper winding of the transformer 432' and, thus, acts as a smoothing capacitance to improve the wave form of the voltage impressed upon the busy tone lead C1089. The series-connected resistor 433 and condenser 434 function to prevent sparking at the contacts 431 during the intermittent opening and closing of these contacts. Due to the fact that the voltage output of the generator 440 is derived from the secondary winding of the transformer 432', the load imposed upon the generator does not influence the operation of the buzzer 430. Hence, the generator will operate as well when its output circuit is heavily loaded or short-circuited as when no load is imposed on the generator.

The three slow-to-operate relays R450, R460 and R470 serve a dual purpose. One of the functions assigned to these relays is that of intermittently connecting the busy tone current lead C1089 to the high potential terminal of the condenser 436. The other function assigned to these relays is that of intermittently connecting the reverting call tone lead C907 to the negative terminal of the exchange battery. Operation of these relays is initiated in response to operation of the relay R400 or the application of ground potential to the tone start lead C879. More specifically, when the conductor C879 is grounded, the relay R470 is energized in series with the resistor 473 and operates after an interval to prepare, at its contacts 471, the operating circuit for the relay R480. At its contacts 472, the relay R470 opens the path normally short-circuiting the relay R460, permitting the latter relay to be energized in series with the resistor 474. The relay R460, upon operating, opens the path normally short-circuiting the winding of the relay R450, permitting the latter relay to be energized in series with the resistor 463. The relay R450, upon operating, completes the above-mentioned operating circuit for the relay R480 and closes its contacts 452 to short-circuit the relay R470. At its contacts 453, the relay R450 connects the busy tone lead C1089 to the high potential terminal of the condenser 436. When its winding is short-circuited, the relay R470 restores to short-circuit the relay R460. The relay R460 in turn restores to short-circuit the relay R450. The relay R450, upon restoring, opens the operating circuit for the relay R480, disconnects the busy tone lead C1089 from the high potential terminal of the condenser 436, and opens the path short-circuiting the relay R470. It will be observed that during the cyclic operation of these relays, the busy tone lead C1089 is only connected to the high potential terminal of

the condenser 436 during those intervals when the relay R450 is operated. It will also be observed that the operating circuit for the relay R480 is closed and opened twice during each cycle of operation of the three cyclically operating relays. This circuit is initially completed in response to operation of the relay R450. It is thereafter opened in response to the release of the relay R470. It is again closed in response to the release of the relay R460 and again opened in response to the release of the relay R450. Thus, the relay R480 is caused intermittently to operate and restore. Each time this relay operates, it opens its contacts 481 to disconnect the reverting call tone lead C907 from the grounded resistor 483, and closes its contacts 482 to connect the indicated lead through the resistor 484 to the negative terminal of the exchange battery. This operation of the relay R480 alternately to connect the lead C907 to opposite terminals of the exchange battery causes an undulating voltage to be impressed upon the lead which is utilized for the signaling purposes previously described.

The release of the dial and busy tone generators is entirely under the control of the tone start relay R400. Thus, it will be apparent that when this relay is deenergized and restores, the operating and locking circuits for the relays R410 and R420, and the circuits for energizing the windings of the tone buzzer 430, are all interrupted. The dial tone generator 435 is restored to normal in a similar manner when the start relay R400 restores to disconnect ground potential from the start lead C405 individual thereto. The release of the reverting call tone generator 475 only occurs when ground potential is removed from the start lead C879, the three slow-to-operate relays R450, R460 and R470 all being deenergized when this lead is disconnected from ground.

While there has been described what is at present considered to be the preferred embodiment of the invention, it will be understood that various modifications may be made therein, and it is contemplated to cover in the appended claims all such modifications as fall within the true spirit and scope of the invention.

What is claimed is:

1. In a telephone system, a line selecting switch of the all-relay type including a plurality of group relays having contacts terminating different groups of lines, operating circuits for said relays, a group select relay including contacts individual to said operating circuits, said last-named contacts being connected to prepare a portion of said operating circuits when said group select relay occupies one position and to prepare another portion of said operating circuits when said group select relay occupies another position, and means controllable over a calling line of the system for determining the position of said group select relay.

2. In a telephone system, a line selecting switch of the all-relay type including a plurality of group relays having contacts terminating different groups of lines, operating circuits for said relays, a pair of group select relays including contacts individual to said operating circuits, said last-named contacts being connected to prepare the operating circuits for one group of said group relays when said group select relays occupy non-corresponding positions and to prepare the operating circuits for another group of said group relays when said group select relays occupy dif-

ferent non-corresponding positions, and means controllable over a calling line of the system for selectively determining the positions of said group select relays.

5. 3. In a telephone system, a line selecting switch of the all-relay type including a plurality of group relays having contacts terminating different groups of lines, operating circuits for said relays, a pair of group select relays including contacts individual to said operating circuits, said last-named contacts being connected to prepare the operating circuits for one group of said group select relays when one of said group select relays is operated and the other of said group select relays

10 is released and to prepare the operating circuits for another group of said group relays when said other group select relay is operated and said one group select relay is released, and means controllable over a calling line of the system for selectively energizing said group select relays.

4. In a telephone system, an impulse responsive line selecting switch of the all-relay type including a plurality of group relays having contacts terminating different groups of lines, operating circuits for said relays, a group select relay including contacts individual to said operating circuits, said last-named contacts being connected to prepare a portion of said operating circuits when said group select relay occupies one

15 position and to prepare another portion of said operating circuits when said group select relay occupies another position, and means operative in response to a series of impulses transmitted to said switch for determining the position of said group select relay.

5. In a telephone system, an impulse responsive line selecting switch of the all-relay type including a plurality of group relays having contacts terminating different groups of lines, operating circuits for said relays, a pair of group select relays including last-named contacts individual to

20 said operating circuits, said contacts being connected to prepare the operating circuits for one group of said group relays when said group select relays occupy non-corresponding positions and to prepare the operating circuits for another group of said group relays when said group select relays occupy different non-corresponding positions, and means operative in response to a series of impulses transmitted to said switch for determining the positions of said group select relays.

40 6. In a telephone system, an impulse responsive line selecting switch of the all-relay type including a plurality of group relays having contacts terminating different groups of lines, operating circuits for said relays, a pair of group select relays occupying non-corresponding positions and to prepare the operating circuits for another group of said group relays when said group select relays occupy different non-corresponding positions, and means operative in response to a series of impulses transmitted to said switch for determining the positions of said group select relays.

45 5. In a telephone system, an impulse responsive line selecting switch of the all-relay type including a plurality of group relays having contacts terminating different groups of lines, operating circuits for said relays, a pair of group select relays including last-named contacts individual to said operating circuits, said contacts being connected to prepare the operating circuits for one group of said group relays when one of

50 said group select relays is operated and the other of said group select relays is released and to prepare the operating circuits for another group of said group relays when said other group select relay is operated and said one group select relay is released, and means controllable in accordance with the number of impulses of a series of impulses transmitted to said switch for energizing one or the other but not both of said group select relays.

60 6. In a telephone system, an impulse responsive line selecting switch of the all-relay type including a plurality of group relays having contacts terminating different groups of lines, operating circuits for said relays, a pair of group select relays including last-named contacts individual to said operating circuits, said contacts being connected to prepare the operating circuits for one group of said group relays when one of

65 said group select relays is operated and the other of said group select relays is released and to prepare the operating circuits for another group of said group relays when said other group select relay is operated and said one group select relay is released, and means controllable in accordance with the number of impulses of a series of impulses transmitted to said switch for energizing one or the other but not both of said group select relays.

7. In a telephone system, an impulse responsive line selecting switch of the all-relay type including a plurality of group relays having contacts terminating different groups of lines, operating circuits for said relays, a pair of group select relays including last-named contacts individual to said operating circuits, said contacts being connected to prepare the operating circuits for one group of said group relays when one of

70 said group select relays is operated and the other of said group select relays is released and to prepare the operating circuits for another group of said group relays when said other group select relay is operated and said one group select relay is released, and means controllable in accordance with the number of impulses of a series of impulses transmitted to said switch for energizing one or the other but not both of said group select relays.

erating circuits for said relays, a group select relay including contacts individual to said operating circuits, said last-named contacts being connected to prepare a portion of said operating circuits when said group select relay occupies one position and to prepare another portion of said operating circuits when said group select relay occupies another position, means controlled in accordance with the number of impulses in one series of impulses transmitted to said switch for determining the position of said group select relay, and means operative in response to a succeeding series of impulses transmitted to said switch for selecting a prepared one of said circuits and for completing the selected circuit.

8. In a telephone system, an impulse responsive connector switch of the all-relay type including a plurality of group relays having contacts terminating different groups of lines, operating circuits for said relays, a group select relay including contacts individual to said circuits, said last-named contacts being connected to prepare a portion of said operating circuits when said group select relay occupies one position and to prepare another portion of said operating circuits when said group select relay occupies another position, ringing apparatus for signaling over said lines and including means for providing ringing voltages having different station indicating characteristics, and means operative in response to one series of impulses transmitted to said switch for determining the position of said group select relay and for at least partially selecting the ringing voltage to be applied to a called one of said lines.

9. In a telephone system, an impulse responsive connector switch of the all-relay type including a plurality of group relays having contacts terminating different groups of lines, operating circuits for said relays, a group select relay including contacts individual to said circuits, said last-named contacts being connected to prepare a portion of said operating circuits when said group select relay occupies one position and to prepare another portion of said operating circuits when said group select relay occupies another position, ringing apparatus for signaling over said lines and including means for providing ringing voltages having different station indicating characteristics, means operative in response to one series of impulses transmitted to said switch for determining the position of said group select relay and for partially selecting the ringing voltage to be applied to a called one of said lines, and means operative in response to a succeeding series of impulses transmitted to said switch for completing the selection of the ringing voltage to be applied to the called line.

10. In a telephone system, an impulse responsive connector switch of the all-relay type including a plurality of group relays having contacts terminating different groups of lines, operating circuits for said relays, a group select relay including contacts individual to said circuits, said last-named contacts being connected to prepare a portion of said operating circuits when said group select relay occupies one position and to prepare another portion of said operating circuits when said group select relay occupies another position, ringing apparatus for signaling over said lines and including means for providing ringing voltages having different station indicating characteristics, means operative in response to one series of impulses transmitted to said switch for determining the position of said

group select relay and for partially selecting the ringing voltage to be applied to a called one of said lines, means operative in response to a second series of impulses transmitted to said switch for selecting and completing one of said prepared operating circuits, and means operative in response to a succeeding series of impulses transmitted to said switch for completing the selection of the ringing voltage to be applied to the called line.

11. In a telephone system, an impulse responsive line selecting switch of the all-relay type including a plurality of group relays having contacts terminating different groups of lines, operating circuits for said relays, a group select relay including contacts individual to said circuits, said last-named contacts being connected to prepare a portion of said operating circuits when said group select relay occupies one position and to prepare another portion of said operating circuits when said group select relay occupies another position, means operative in response to one series of impulses transmitted to said switch for determining the position of said group select relay, an auxiliary operating circuit for one of said group relays, and means operative in the event said one series of impulses comprises a predetermined number of impulses for completing said auxiliary operating circuit.

12. In a telephone system, an impulse responsive line selecting switch of the all-relay type including impulse counting means and a plurality of group relays having contacts terminating different groups of lines, operating circuits for said relays, a group select relay including contacts individual to said circuits, said last-named contacts being connected to prepare a portion of said operating circuits when said group select relay occupies one position and to prepare another portion of said operating circuits when said group select relay occupies another position, means controlled in accordance with the setting of said impulse counting means after the transmission of a series of impulses to said switch for determining the position of said group select relay, an auxiliary operating circuit for one of said group relays, and means for completing said operating circuit in the event said impulse counting means occupies a predetermined setting at the end of said series of impulses.

13. In a telephone system, a pair of lines, an impulse responsive line selecting switch accessible to said lines and adapted to have a predetermined impulse train comprising at least one impulse transmitted thereto over either of said lines, a plurality of lines accessible to said switch, means operative in the event said impulse train is transmitted to said switch over one of said pair of lines for absorbing the impulse or impulses of the train, and means operative in the event said impulse train is transmitted to said switch over the other of said pair of lines for conditioning said switch to establish a communication connection between said other line and a busy one of said plurality of lines.

14. In a telephone system, a trunk line, a subscribers line, an impulse responsive line selecting switch accessible to said lines and adapted to have a predetermined impulse train comprising at least one impulse transmitted thereto over either of said lines, a plurality of lines accessible to said switch, means operative in the event said predetermined impulse train is transmitted to said switch over said subscribers line for absorbing the impulse or impulses of the train, and

means operative in the event said predetermined impulse train is transmitted to said switch over said trunk line for conditioning said switch to establish a communication connection between said trunk line and a busy one of said plurality of lines.

15. In a telephone system, a pair of lines, an impulse responsive line selecting switch accessible to said lines and adapted to have impulses transmitted thereto over either of said lines, said switch including impulse counting means, means controlled by said counting means and operative in the event a predetermined impulse train comprising at least one impulse is transmitted to said switch over one of said pair of lines for conditioning said switch to establish a communication connection between said one line and a busy one of said plurality of lines, and means for preventing the operation of said last named means and for releasing said counting means in the event said predetermined impulse train is transmitted to said switch over the other of said pair of lines.

16. In a telephone system, a pair of lines, an impulse responsive line selecting switch accessible to said lines and adapted to have a predetermined impulse train comprising at least one impulse transmitted thereto over either of said lines, a plurality of lines accessible to said switch, said switch including a relay operative to condition said switch to extend a communication connection to a busy one of said plurality of lines, a circuit for energizing said relay, said relay being operative to complete said circuit, means operative to prepare said circuit when said switch is seized over one of said pair of lines, said last named means being inactive when said switch is seized over the other of said pair of lines, means for absorbing said predetermined impulse train when transmitted to said switch over said other line, and means operative in response to the transmission of said predetermined impulse train to said switch over said one line for energizing said relay, thereby to cause the completion of said circuit.

17. In a telephone system, a pair of lines, an impulse responsive line selecting switch accessible to said lines and adapted to have impulses transmitted thereto over either of said lines, a plurality of lines accessible to said switch, said switch including impulse counting means and a relay operative to condition said switch to extend a connection to a busy one of said plurality of lines, a circuit for energizing said relay, means operative to prepare said circuit when said switch is seized over one of said pair of lines, said last named means being inactive when said switch is seized over the other of said pair of lines, said relay being operative to complete said circuit in the event said counting means occupies a predetermined setting at the end of a predetermined digit transmitted to said switch over said one line, and means for releasing said counting means at the end of said digit regardless of the one of said pair of lines over which said digit is transmitted to said switch.

18. In a telephone system, a pair of lines, an impulse responsive line selecting switch accessible to said lines, a plurality of lines accessible to said switch, means operative to absorb an impulse transmitted to said switch over one of said pair of lines, and means operative in response to the transmission of a single impulse to said switch over the other of said pair of

lines for conditioning said switch to establish a communication connection between said one line and a busy one of said plurality of lines.

19. In a telephone system, a trunk line, a subscribers line, an impulse responsive line selecting switch accessible to said lines, a plurality of lines accessible to said switch, means operative to absorb an impulse transmitted to said switch over said subscribers line, and means operative in response to the transmission of a single impulse to said switch over said trunk line for conditioning said switch to establish a communication connection between said trunk line and a busy one of said plurality of lines.

15. 20. In a telephone system, a pair of lines, an impulse responsive line selecting switch accessible to said lines, a plurality of lines accessible to said switch, means operative to absorb the impulse or impulses of a predetermined first digit transmitted to said switch over one of said pair of lines, and means responsive to the impulse or impulses of said predetermined first digit when transmitted to said switch over the other of said pair of lines for conditioning said switch to establish a communication connection between said other line and a busy one of said plurality of lines.

21. In a telephone system, a trunk line, a subscribers line, an impulse responsive line selecting switch accessible to said lines, a plurality of lines accessible to said switch, means operative to absorb the impulse or impulses of a predetermined first digit transmitted to said switch over said subscribers line, and means responsive to the impulse or impulses of said predetermined first digit when transmitted to said switch over said trunk line for conditioning said switch to establish a communication connection between said trunk line and a busy called one of said plurality of lines.

30. 22. In a telephone system, a pair of lines, an impulse responsive line selecting switch accessible to said lines, a plurality of lines accessible to said switch, means operative to absorb the impulse or impulses of a predetermined first digit transmitted to said switch over one of said pair of lines, means responsive to the impulse or impulses of said predetermined first digit when transmitted to said switch over the other of said pair of lines for conditioning said switch to establish a communication connection between said other line and a busy one of said plurality of lines, and means responsive to a different predetermined first digit transmitted to said switch for causing said switch to seize an idle one of a particular group of said plurality of lines.

23. In a telephone system, a pair of lines, a connector switch accessible to said lines, a plurality of lines including a group of multiparty subscribers lines accessible to said switch, means operative to absorb the impulse or impulses of a predetermined first digit transmitted to said switch over one of said pair of lines, means responsive to the impulse or impulses of said predetermined digit when transmitted to said switch over the other of said pair of lines for conditioning said switch to establish a communication connection between said other line and a busy one of said plurality of lines, ringing apparatus for providing a plurality of ringing voltages having different station indicating characteristics, and means responsive to a different first digit transmitted to said switch for at least partially selecting the ringing voltage to be applied to a called one of said subscribers lines.

24. In a telephone system, a pair of lines, a

connector switch accessible to said lines, a plurality of lines including a group of multiparty subscribers lines and a group of trunk lines accessible to said switch, means operative to absorb the impulse or impulses of a predetermined first digit transmitted to said switch over one of said pair of lines, means responsive to the impulse or impulses of said predetermined digit when transmitted to said switch over the other of said pair of lines for conditioning said switch to establish a communication connection between said other line and a busy one of said plurality of lines, ringing apparatus for providing a plurality of ringing voltages having different station indicating characteristics, means responsive to a different predetermined first digit transmitted to said switch for at least partially selecting the ringing voltage to be applied to a called one of said subscribers' lines, and means responsive to another predetermined first digit transmitted to said switch for causing said switch to seize an idle one of said trunk lines.

25. In a telephone system, a pair of lines, an impulse responsive line selecting switch accessible to said lines, a plurality of lines accessible to said switch, said plurality of lines being divided into two groups each including a plurality of sub-groups, means operative to absorb the impulse or impulses of a predetermined first digit transmitted to said switch over one of said pair of lines, means responsive to the impulse or impulses of said predetermined first digit when transmitted to said switch over the other of said pair of lines for conditioning said switch to establish a communication connection between said other line and a busy one of said plurality of lines, and means responsive to a different predetermined first digit transmitted to said switch for selecting one of said two group of lines.

26. In a telephone system, a pair of lines, an impulse responsive line selecting switch accessible to said lines and including a plurality of group relays having contacts terminating different groups of lines, operating circuits for said relays, a group select relay including contacts individual to said circuits, said last-named contacts being connected to prepare a portion of said operating circuits when said group select relay occupies one position and to prepare another portion of said operating circuits when said group select relay occupies another position, means operative to absorb the impulse or impulses of a predetermined first digit transmitted to said switch over one of said pair of lines, means responsive to the impulse or impulses of said predetermined first digit when transmitted to said switch over the other of said pair of lines for conditioning said switch to establish a communication connection between said other line and a busy line in one of said groups of lines, and means responsive to a different predetermined first digit transmitted to said switch for determining the position of said group select relay.

27. In a telephone system, a pair of lines, an impulse responsive line selecting switch accessible to said lines and including a plurality of group relays having contacts terminating different groups of lines, operating circuits for said relays, a group select relay including contacts individual to said circuits, said last-named contacts being connected to prepare a portion of said operating circuits when said group select relay occupies one position and to prepare another portion of said operating circuits when said group select relay occupies another position,

means operative to absorb impulse or impulses of a predetermined first digit transmitted to said switch over one of said pair of lines, means responsive to the impulse or impulses of said predetermined first digit when transmitted to said switch over the other of said pair of lines for conditioning said switch to establish a communication connection between said other line and a busy line in one of said groups of lines, and means responsive to a different first digit or to a second digit transmitted to said switch following said predetermined first digit for determining the position of said group select relay.

28. In a telephone system, a plurality of lines, means including a plurality of links and equipment common to said links for setting up connections between said lines, means included in one of said links and adapted to be controlled by the impulse or impulses of an impulse digit transmitted to the link over a calling one of said lines for conditioning the link to establish a communication connection between the calling line and a busy called line, and means included in said common equipment for limiting the effective response of said last named means to impulses transmitted to said one link over predetermined ones of said lines.

29. In a telephone system, a plurality of lines, means including a plurality of links and equipment common to said links for setting up connections between said lines, means included in one of said links and adapted to respond to the impulse or impulses of the first impulse digit transmitted to the link over a calling one of said lines for conditioning the link to establish a communication connection between the calling line and a busy called line, and means included in said common equipment for limiting the effective response of said last named means to impulses transmitted to said one link over predetermined ones of said lines.

30. In a telephone system, a plurality of lines certain of which are arranged for special service, a plurality of links each including a finder switch having access to said lines, means included in one of said links and adapted to be controlled by the impulse or impulses of an impulse digit transmitted to said link over a calling one of said lines for conditioning the link to establish a communication connection between the calling line and a busy called line, and apparatus common to said links for controlling said finder switches to seize calling ones of said lines and including means for limiting the effective response of said last named means to impulses transmitted to said one link over the lines arranged for special service.

31. In a telephone system, a plurality of lines certain of which are arranged for special service, a plurality of links each including a finder switch comprising group relays and unit relays, equipment common to said links and including auxiliary group and unit relays operative to control the group and unit relays of said finder switches, means including said links and said common equipment for setting up connections between said lines, means included in one of said links and adapted to be controlled by the impulse or impulses of an impulse digit transmitted to said link over a calling one of said lines for conditioning the link to establish a communication connection between the calling line and a busy called line, and means controlled by at least a portion of said auxiliary relays for limiting the effective response of said last named means to impulses

transmitted to said one link over the lines arranged for special service.

32. In a telephone system, a plurality of lines certain of which are arranged for special service, a plurality of links each including a finder switch comprising group relays and unit relays, equipment common to said links and including auxiliary group and unit relays operative to control the group and unit relays of said finder switches, means including said links and said common equipment for setting up connections between said lines, a control relay included in one of said links and operative to condition the link to establish a communication connection between a calling line and a busy called line, a holding circuit for said control relay, means controlled by at least a portion of said auxiliary relays for preparing said holding circuit only when said one link is seized over a calling line arranged for special service, an operating circuit for said control relay, and means included in said one link and adapted to be controlled by the impulse or impulses of an impulse digit transmitted to said one link over the calling line for completing said operating circuit, thereby to cause said control relay to operate and complete said holding circuit.

33. In a telephone system, a plurality of lines certain of which are arranged for special service, a plurality of links each including a finder switch comprising group relays and unit relays, equipment common to said links and including auxiliary group and unit relays operative to control the group and unit relays of said finder switches, means including said links and said common equipment for setting up connections between said lines, a control relay included in one of said links and operative to condition the link to establish a communication connection between a calling line and a busy called line, a holding circuit for said control relay, means controlled by at least a portion of said auxiliary relays for preparing said holding circuit only when said one link is seized over a calling line arranged for special service, an operating circuit for said control relay, and impulse controlled means in said one link operative to complete said operating circuit, thereby to cause said control relay to operate and complete said holding circuit.

34. In an automatic telephone system including switching apparatus so connected and arranged that the revertive signaling of a called substation served by the same line as a calling substation is obtained in response to the dialing of the called substation's regular directory number at the calling substation, apparatus operative in response to the answering of the call for transmitting a signal to the answering substation.

35. In an automatic telephone system including switching apparatus so connected and arranged that the revertive signaling of a called substation served by the same line as a calling substation is obtained in response to the dialing of the called substation's regular directory number at the calling substation, apparatus operative in response to the answering of the call for transmitting a signal of limited duration to the answering substation.

36. In an automatic telephone system including switching apparatus so connected and arranged that the revertive signaling of a called substation served by the same line as a calling substation is obtained in response to the dialing of the called substation's regular directory

number at the calling substation, a timing device, means operative in response to the answering of said call for initiating the operation of said timing device and for transmitting a signal to the answering substation, and means controlled by said timing device for terminating said signal after a predetermined time interval.

37. In an automatic telephone system including switching apparatus so connected and arranged that the revertive signaling of a called substation served by the same line as a calling substation is obtained in response to the dialing of the called substation's regular directory number at the calling substation, means operative in response to the answering of said call for transmitting a signal to the answering substation, and means for releasing the automatic switching apparatus utilized in signaling the called substation, thereby to terminate said signal, a predetermined time interval after the call is answered.

38. In an automatic telephone system including switching apparatus so connected and arranged that the revertive signaling of a called substation served by the same line as a calling substation is obtained in response to the dialing of the called substation's regular directory number at the calling substation, a timing device, means operative in response to the answering of said call for initiating the operation of said timing device and for transmitting a signal to the answering substation, and means controlled by said timing device for releasing the automatic switching apparatus utilized in signaling the called substation, thereby to terminate said signal, a predetermined time interval after the call is answered.

39. In an automatic telephone system, a multi-party line, automatic switching apparatus including a connector switch controllable from a calling substation served by said line to impress upon said line ringing voltage designating a called substation also served by said line in routing a call from said calling substation to said called substation, and means operative in response to a call answering operation performed at one of said substations for removing the ringing voltage from said line and for transmitting a special signal to the answering substation.

40. In an automatic telephone system, a multi-party line, automatic switching apparatus including a connector switch controllable from a calling substation served by said line to impress upon said line ringing voltage designating a called substation also served by said line in routing a call from said calling substation to said called substation, said connector switch including a back-bridge relay operative in response to a call answering operation performed at one of said substations, and means operative in response to the operation of said back-bridge relay for removing the ringing voltage from said line and for transmitting a special signal to the answering substation.

41. In an automatic telephone system, a multi-party line, automatic switching apparatus including a connector switch controllable from a calling substation served by said line to impress upon said line ringing voltage designating a called substation also served by said line in routing a call from said calling substation to said called substation, said connector switch including a back-bridge relay operative in response to a call answering operation performed at one of said substations, a timing device operative in response

to operation of said back-bridge relay, means operative in response to operation of said back-bridge relay for removing the ringing voltage from said line and for transmitting a special signal to the answering substation, and means controlled by said timing device for terminating said special signal after a predetermined time interval.

42. In an automatic telephone system, a multi-party line, automatic switching apparatus including a connector switch controllable from a calling substation served by said line to impress upon said line ringing voltage designating a called substation also served by said line in routing a call from said calling substation to said called substation, a circuit for impressing a special signal voltage upon said line, said connector switch including a reverting call relay operative to prepare said circuit in response to a switch release operation performed at said calling substation and means operative in response to operation of said relay for impressing the ringing voltage upon said line, a back-bridge relay included in said connector switch and operative in response to a call answering operation performed at one of said substations, and means operative in response to operation of said back-bridge relay for completing said circuit and for removing the ringing voltage from said line.

43. In an automatic telephone system, a multi-party line, automatic switching apparatus including a connector switch controllable from a calling substation served by said line to impress upon said line ringing voltage designating a called substation also served by said line in routing a call from said calling substation to said called substation, a timing device operative in response to a call answering operation performed at one of said substations, means also operative in response to said call answering operation for removing the ringing voltage from said line and for transmitting a special signal to the answering substation, and means controlled by said timing device for releasing said switch, thereby to terminate said special signal, a predetermined time interval after the call is answered.

44. In an automatic telephone system, a multi-party line, automatic switching apparatus including a connector switch controllable from a calling substation served by said line to impress upon said line ringing voltage designating a called substation also served by said line in routing a call from said calling substation to said called substation, said connector switch including a back-bridge relay operative in response to a call answering operation performed at one of said substations, a timing device operative in response to operation of said relay, means operative in response to operation of said relay for removing the ringing voltage from said line and for impressing a special signal voltage upon said line, and means controlled by said timing device for releasing said connector switch, thereby to remove said special signal voltage from said line, a predetermined time interval after the call is answered.

45. In an automatic telephone system, a multi-party line, automatic switching apparatus including a connector switch controllable from a calling substation served by said line to impress upon said line ringing voltage designating a called substation also served by said line in routing a call from said calling substation to said called substation, a circuit for impressing a special signal

voltage upon said line, said connector switch including a reverting call relay operative to prepare said circuit in response to a switch release operation performed at said calling substation and means operative in response to operation of said relay for impressing the ringing voltage on said line, a back-bridge relay included in said connector switch and operative in response to a call answering operation performed at one of said substations, a timing device operative in response to operation of said back-bridge relay, means also operative in response to operation of said back-bridge relay for removing the ringing voltage from said line and for completing said circuit, and means controlled by said timing device for releasing said connector switch, thereby to open said circuit, a predetermined time interval after the call is answered.

46. In a telephone system, a plurality of subscribers lines divided into groups according to the classes of service rendered thereto, a plurality of trunk lines, a plurality of links for setting up connections between said lines, and apparatus common to said links and including means controlled in accordance with the character of calling ones of said subscribers lines for permitting the subscribers lines of one of said groups to obtain access to said trunk lines through said links and for preventing the subscribers lines of another group from obtaining access to said trunk lines through said links.

47. In a telephone system, a plurality of subscribers lines divided into groups according to the classes of service rendered thereto, a plurality of trunk lines, a plurality of links each including a finder switch comprising group and unit relays, equipment common to said links and including auxiliary group and unit relays operative to control the group and unit relays of said finder switches, and means controlled by at least a portion of said auxiliary relays for permitting the subscribers lines of one of said groups to obtain access to said trunk lines through said links and for preventing the subscribers lines of another group from obtaining access to said trunk lines through said links.

48. In a telephone system, a plurality of subscribers lines divided into groups according to the classes of service rendered thereto, a plurality of trunk lines, a plurality of links each including a finder switch comprising group and unit relays, equipment common to said links and including auxiliary group and unit relays operative to control the group and unit relays of said finder switches, right of way control circuits individual to said links and each including means for permitting calling lines to obtain access to said trunk lines through the associated link, and means comprising at least a portion of said auxiliary relays for controlling said circuits to permit the subscribers lines of one of said groups to obtain access to said trunk lines through said links and to prevent the subscribers lines of another group from obtaining access to said trunk lines through said links.

49. In a telephone system, a plurality of subscribers lines divided into groups according to the classes of service rendered thereto, a plurality of trunk lines, a plurality of finder-selector links each including a finder switch having access to said subscribers lines and a selector switch having access to said trunk lines, each of said switches including group and unit relays, one of the group relays of each selector switch terminating said trunk lines, equipment common to said links and

including auxiliary group and unit relays for controlling the group and unit relays of said finder switches, and means controlled by at least a portion of said auxiliary relays for controlling the trunk group terminating relays of said selector switches to permit the subscribers lines of one of said groups to obtain access to said trunk lines through said links and to prevent the subscribers lines of another group from obtaining access to said trunk lines through said links.

50. In a telephone system, a plurality of subscribers lines divided into groups according to the classes of service rendered thereto, a plurality of trunk lines, a plurality of finder-selector links each including a finder switch having access to said subscribers lines and a selector switch having access to said trunk lines, each of said switches including group and unit relays, one of the group relays of each selector switch terminating said trunks, an operating circuit for each of the trunk group terminating relays of said selector switches, each of said links including a control relay operative to prepare the associated one of said operating circuits, equipment common to said links and including auxiliary group and unit relays for controlling the group and unit relays of said finder switches, and means including at least one of said auxiliary relays for selectively energizing said control relays to permit the subscribers lines of one of said groups to obtain access to said trunk lines through said links and for preventing the subscribers lines of another group from obtaining access to said trunk lines through said links.

51. In a telephone system, a plurality of subscribers lines divided into groups according to the classes of service rendered thereto, a plurality of trunk lines, a plurality of finder-selector links each including a finder switch having access to said subscribers lines and a selector switch having access to said trunk lines, each of said switches including group and unit relays, one of the group relays of each selector switch terminating said trunk lines, an operating circuit for each of the trunk group terminating relays of said selector switches, each of said links including a control relay operative to prepare the associated one of said operating circuits, equipment common to said links and including auxiliary group and unit relays for controlling the group and unit relays of said finder switches, means including at least one of said auxiliary relays for selectively energizing said control relays to permit the subscribers lines of one of said groups to obtain access to said trunk lines through said links and for preventing the subscribers lines of another group from obtaining access to said trunk lines through said links, and circuits controlled through the finder switches of said links for energizing said control relays in response to the initiation of calls on predetermined ones of said lines independently of said last-named means.

52. In a telephone system, a plurality of subscribers lines divided into groups according to the classes of service rendered thereto, a plurality of trunk lines, a plurality of finder-selector links each including a finder switch having access to said subscribers lines and a selector switch having access to said trunk lines, each of said switches including group and unit relays, one of the group relays of each selector switch terminating said trunks, an operating circuit for each of the trunk group terminating relays of said selector switches, each of said links including a

control relay operative to prepare the associated one of said operating circuits, equipment common to said links and including auxiliary group and unit relays for controlling the group and unit relays of said finder switches, means including at least one of said auxiliary relays for selectively energizing said control relays to permit the subscribers lines of one of said groups to obtain access to said trunk lines through said links and for preventing the subscribers lines of another group from obtaining access to said trunk lines through said links, and circuits controlled through the contacts of predetermined corresponding group relays of said finder switches for energizing said control relays in response to the initiation of calls on predetermined ones of said lines independently of said last-named means.

53. In a telephone system, a plurality of subscribers lines, a group of trunk lines, a plurality of links each including a finder switch comprising group and unit relays, equipment common to said links and including auxiliary group and unit relays operative to control the group and unit relays of said finder switches, means at least partially controlled by at least a portion of said auxiliary group relays for conditioning said links to establish communication connections between predetermined calling ones of said lines and busy ones of said subscribers lines, and means also controlled by at least a portion of said auxiliary relays for permitting certain of said subscribers lines to obtain access to said trunk lines through said links and for preventing others of said subscribers lines from obtaining access to said trunk lines through said links.

54. In a telephone system, a plurality of lines including multiparty subscribers' lines and a group of trunk lines, an impulse responsive trunk selecting connector switch adapted for use in setting up connections between said lines; said switch including control apparatus connected and arranged to respond to the impulses of a first digit transmitted thereto to perform a variety of functions including the selection of said group of trunk lines, the partial selection of the character of the ringing voltage to be applied to a called subscriber's line or the selection of a particular group of subscribers' lines, depending upon the numerical value of the digit, and means included in said switch for absorbing all first digits having numerical values not assigned to one of said functions.

55. In a telephone system, a plurality of lines including multiparty subscribers' lines and a group of trunk lines, an impulse responsive trunk selecting connector switch adapted for use in setting up connections between said lines, said switch including an impulse counting chain operative in response to impulses transmitted to said switch; means controlled in accordance with the setting of said chain at the end of a first digit transmitted to said switch for conditioning said switch to perform one of a variety of functions including the selection of said group of trunk lines, the selection of a particular group of subscribers' lines and the partial selection of the character of the ringing voltage to be applied to a called subscriber's line; and means for automatically releasing said chain at the end of said first digit without operation of said last named means in the event said chain occupies, at the end of said digit, any one of a plurality of settings not assigned to one of said functions.

JOHN H. VOSS.
